UNITED STATES PATENT OFFICE

WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK

SYSTEM FOR AUTOMATICALLY CONTROLLING RAILWAY TRAFFIC

Application filed July 6, 1915. Serial No. 38,132.

This invention relates to systems for controlling railway traffic, and more particularly to such systems which will automatically give signals aboard a car or train while it is in motion, and which will, if necessary, automatically control the speed of the train to conform to the speed required by the traffic conditions ahead of the train.

At the present time it is possible to construct fixed signals, that is, signals permanently located along the trackway, which will respond with practicable accuracy to changes in traffic conditions; but while it is possible to set the proper signals for the engineer or the motorman, this alone does not assure that he will obey the signals, and in many cases serious accidents have been caused by the failure of the engineer to obey these fixed signals. The engineer may fail to see the signals, because fog, snow or other conditions obscure his sight of the signal; or he may see the signal and accidentally or carelessly fail to understand the character of the indication which it gives; or he may be incapacitated for some reason so as to be unable to see, understand, or obey the signal set for him. In any event, regardless of the efficiency of the signal system, the safety of the train in the final analysis is dependent on the engineer or motorman; and records show that the human machine has an appreciable percentage of failure. To obviate as far as possible, one source of error it is desirable to provide apparatus, appliances or means of some character whereby appropriate signals may be displayed or operated aboard the train so that the engineer or motorman cannot fail to see them; and it is also desirable to supplement the vigilance and reliability of the engineer or motorman by providing appropriate apparatus, appliances or means whereby the speed of the train will be automatically controlled in accordance with the conditions of traffic ahead of the train in case the engineer himself fails to control the speed of the train.

Various devices have been proposed for accomplishing either or both of the above mentioned objects and to obtain a clear understanding of the operation and usefulness

of the system of automatic speed control embodying this invention, as distinctive from these devices heretofore proposed, it will be instructive to consider briefly some of the principles which it is necessary to observe in regulating the movement of railway trains, and to explain briefly some of the requisites of an automatic speed control system which, it is believed, will add to the safety of railway traffic and which are necessary to secure a practicable system.

Generally stated, the fundamental principle of governing railway traffic consists in maintaining a certain space or distance between trains; and in the well-known block system of controlling railway traffic, to which system the system of automatic speed control embodying this invention is particularly applicable, the trackway is divided into blocks or sections and suitable fixed signals are provided for the purpose of keeping a certain number of blocks between trains. In this block system, as will be understood by those skilled in the art of railway signaling, these fixed signals are controlled by track circuits or other devices so that the system operates to display danger or stop signals at different points along the trackway behind a train, these stop signals indicating a point beyond which the following train should not proceed, at least without great care and at a low speed. Also, since it requires some distance to reduce the speed of a fast moving train, it is desirable to warn the operator by a caution signal when the train is at some distance from a stop signal, so that the operator may apply the brakes in time to bring his train to a stop before the stop signal is reached, and it is common practice to provide such warning signals in the block system of signaling.

The block system affords adequate protection by maintaining a proper interval of distance between two trains, providing the caution and stop signals are strictly obeyed. The characteristic of this block system and of all automatic cab signaling and automatic stop systems which are intended merely to obtain obedience to the signals of this block system, is that the train is controlled at certain fixed

points in its travel regardless of its speed at or between these points. The speed of the train is, however, a very important factor in regulating the spacing of the trains, since the 5 different trains passing over a railway may not, and generally do not, travel at the same speeds, and also because dangerous curves, stops at stations, and other fixed hazards prevent the same train from maintaining the 10 same speed throughout the length of the railway. Primarily, the purpose of any system for controlling railway traffic is to obtain safety, and having safety the object is to get the greatest capacity for that railway, that is, 15 the best facility for the movement of vehicles along that railway, and a practicable speed control system should be able to obtain as great a capacity as safety, cost of installation and other conditions will permit. Without 20 entering into any extended discussion of the factors affecting the maximum capacity of a railway, it is obvious that superior capacity may be obtained if the distance between the trains is reduced, for the reason that the 25 closer the trains are together the more of them may pass by a particular point along the railway in a given time. This closer spacing of the trains may be accomplished in the block system by using short blocks and by spacing 30 the fixed signals controlling the entrance of trains into these blocks closer together; but there is a limitation on the minimum length of a block, since in no case can a signal be closer to a point of danger than a distance 35 amply sufficient to allow the train to be brought to a stop by its brakes before the point of danger is reached. The distance required to bring a train to a stop, or to a speed low enough to make the damage from a collision 40 slight, depends, as is well known to those skilled in the art of braking trains upon a number of things, principally upon the speed at which the train is traveling at the time and the grade over which the train is traveling, 45 assuming a particular kind of braking equipment is used in each case. Because of this variable braking distance at different speeds and on different grades, a slow moving train at the same part of a railway having the same 50 grade can approach closer to the rear end of another train or a point of danger than a fast moving train; and also, when a train is traveling at the same speed, it cannot approach as close to the rear end of another train or a 55 point of danger when it is traveling down a steep down grade as it can when traveling on the level or on an upgrade. By proper location and spacing of the fixed signals of a block system it is possible to make allowance 60 for the variation in the braking distance due to the grades and other factors which are dependent on the physical condition of the trackway; but, since these signals must be spaced so as to protect the fastest and heaviest 65 train running on the railway, no proper allow-

ance is made by the fixed signals for the varying speed of the different trains, as for instance a fast express train and a slow moving freight train, with the result that the slower trains will be spaced apart by the signals a greater distance than is necessary for safety, and a corresponding reduction in capacity results. Also, under some conditions it is desirable to permit a train, even if it is capable of running at a higher speed, to reduce its speed and approach closer to a train ahead of it. For instance, assuming two trains at a certain distance apart are approaching a station or a part of the railway which on account of curves or other dangers must be traversed at a slow speed, then as the first train reduces its speed and takes more time to move a certain distance, the following train should be able to approach closer to the first train, providing it reduces its speed correspondingly, so that after both trains have passed the station or dangerous part of the railway the distance between them will be substantially the same as it was before the first train reduced its speed. This ideal condition of spacing trains at different parts of the railway according to the kind of train, its braking capacity, its speed and the physical characteristics of that part of the railway which is one of the things which serve 90 to increase capacity, cannot always be obtained; but the speed control system embodying this invention is of great assistance in obtaining a maximum capacity, as will be made clearer during the progress of the description. 95

Also, it is desirable that a speed control system should be so arranged and constructed that a train, once it has been placed under the dominance of the speed control system should continuously remain under this dominance until traffic conditions have become safe. For example, the speed of the train may be properly controlled with reference to one point in its travel, but this control at one point does not give any assurance that the speed will not be greatly increased after that point has been passed, thereby resulting in a dangerous condition; nor does this control of the speed at one fixed point afford proper facility for the movement of the train since the train may pass this point at a comparatively high speed and yet by the proper application of the brakes its speed may be reduced to a point of safety before the danger point or hazard is reached. 110

From these conditions it is clear that a practicable and efficient speed apparatus which will permit proper facility for the safe movement of trains along the railway should not only operate to give a warning signal in the operator's cab at a proper distance from each point of danger, and in addition automatically cause the speed of the train to be reduced in case the operator himself does not control the speed in obedience to 125 130

this warning signal; but also should make due allowance for the fact that this distance from the point of danger at which the warning signal should be given, and at which the brakes should be applied will vary, being dependent upon the class of the train and its kind of braking equipment, the speed of the train at the time, the grade of the track over which the train is traveling, and other factors, changing the braking distance of the train. The speed of a railway train is individual to that train and will vary widely at different points along the railway, so that its speed cannot be properly regulated solely with reference to fixed points; but the speed control system must be constructed so as to be dependent at each point in the travel of the train upon the speed at which the train is traveling at that point; or, in other words, the speed control system must be dependent upon the instantaneous actual speed of train. The grades and other factors which change the braking distance of the train will be different at different points along the railway, but will be the same in the effect they produce for every train, so that the speed control system should be responsive to the local conditions or individual physical characteristics of each part of the trackway.

There are other things to be considered in determining the requisites of an efficient and practicable speed control system which will aid in obtaining the greatest capacity for the movement of trains, and under some conditions some requisites may be more important than under other conditions, and consequently, the above discussion should not be understood to be comprehensive or invariable but merely illustrative for the purpose of obtaining a clearer understanding of the invention.

With the above mentioned and other requisites necessary for a practicable automatic speed control system for railway vehicles in view, one of the principal objects of this invention is to devise a system for controlling railway vehicles which will facilitate the movement of vehicles by allowing said vehicles to approach each other as closely as safety will permit.

A further object of the invention is to devise a system for controlling railway vehicles, in which the speed of the vehicle and the distance of said vehicle from a point of danger will be automatically involved in determining the operation of said system.

A further object of the invention is to devise a system for controlling railway vehicles in which the speed of the vehicle, the distance of said vehicle from the point of danger, and the physical characteristics of the trackway over which the vehicle is then passing will be automatically involved in determining the operation of the system.

A further object of the invention is to

devise a system for controlling railway vehicles which will give a suitable warning signal aboard the vehicle at any point in its travel, said warning signal being given at the proper point in the travel of said vehicle so that the vehicle will be safely controlled but will not be unnecessarily delayed if its speed is controlled in response to this signal.

A further object of the invention is to devise a system for automatically controlling railway vehicles which will give an operator of the vehicle a proper warning signal at any point in its travel, and which will, if the speed of the vehicle is not controlled by the operator in obedience to this warning signal, automatically reduce the speed of the vehicle, said warning signal and said automatic reduction of speed taking place at a proper point in the travel of said vehicle so that the vehicle will be safely controlled but will not be unnecessarily delayed.

A further object of the invention is to construct a system for automatically controlling railway vehicles which can be used to regulate the speed of the vehicle as it travels along the trackway according to the special requirements of speed demanded by the fixed hazards at the different points along the trackway over which the vehicle is passing.

A further object of the invention is to construct and arrange the parts of an automatic speed control system so that, in controlling the speed of the train, due compensation will be made for such local conditions along the trackway as affect the distance in which the vehicle can be brought to a stop by its brakes.

A further object of the invention is to construct and arrange the parts of an automatic cab-signalling and speed control system so that more than one vehicle equipped with this system may be used in the train, and so that, when more than one such vehicle is used, the systems of these vehicles will not interfere with each other in their operation.

A further object of the invention is to construct and arrange the parts of an automatic cab-signaling and speed control system so that adequate protection is afforded against failure of the important parts to operate properly, and so that such failure, if it occurs, will be immediately manifested.

A still further object of the invention is to provide a suitable device for cutting out of service a speed control system on a vehicle, in case this particular speed control system is out of order, and to construct and arrange the parts of this cut-out device so that its operation requires certain manipulations which make it difficult to carelessly cut a speed control system out of service.

Other objects and advantages will appear as the description of the invention progresses, and the novel features of the invention will be particularly pointed out in the appended claims.

Generally stated, the invention consists in a system for controlling railway vehicles, in which appropriate apparatus is carried on a moving vehicle, which apparatus is controlled at different points along the trackway by suitable devices in accordance with the traffic conditions along said trackway and the physical characteristics of the different parts of said trackway, said apparatus operating so that, as the vehicle reaches the point where the combined condition of the speed of the vehicle, its distance from the point of danger and other factors affecting the braking distance of the vehicle are such that the brakes should be applied, the engineer will be advised of this fact by suitable signals, and if these signals are disregarded the speed of the vehicle will be automatically reduced.

The invention further consists in the parts, and in the arrangements and combinations of parts, which will be set forth more fully hereinafter.

The speed control apparatus herein disclosed comprises cooperating devices on the vehicle and along the trackway to control the speed apparatus by means of certain electric circuits; a suitable device which is operated in accordance with the speed at which the vehicle is traveling; a device which is operated in accordance with the distance traveled by the vehicle from a predetermined point where said device was set into operation; a number of suitable cams, records, registering devices, or other instrumentalities having characteristic shapes, each block having a cam or the like conforming substantially to the individual characteristics of said block as regards the factors which affect the braking distance of the train; a selector actuated in any appropriate manner as the train moves along the trackway, which selector selects the cam or the like conforming nearest to the characteristics of the particular block or blocks into which the train will next proceed; and a system of electric circuits and other inter-connected apparatus which is subject to the joint action of the device responding to variations in speed, the device responding to variations in distance traveled by the vehicle, and the particular cam or the like selected, and which will cause signals to be displayed or sounded, and which, if the signals are not obeyed, will automatically control the speed of the train by applying the brakes.

In describing the invention in detail, reference is had to the accompanying drawing, wherein is illustrated a preferred physical embodiment of the invention, and wherein like characters of reference designate corresponding parts throughout the several views, and in which:

Figure 1 is a side elevation of a railway car equipped with speed control apparatus embodying the invention, parts of said car be-

ing broken away; Fig. 2 is a diagrammatic plan view showing the arrangement of the parts of the speed control apparatus on the car, parts of said car being broken away; Fig. 3 is an enlarged vertical transverse section near one end of a car equipped with the speed control apparatus and shows the arrangement and mounting of some of the parts of said speed control apparatus; Fig. 4 is a fragmentary enlarged side elevation of part of a car truck showing the manner of mounting thereon the contact shoe which constitutes a part of the speed control apparatus; Fig. 5 is an enlarged plan view of the contact shoe detached from the car, the cover for the casing of said shoe being removed; Fig. 6 is an enlarged vertical longitudinal section of the contact shoe, parts being shown in elevation for the sake of clearness; Fig. 7 is a horizontal section on the line 7-7 in Fig. 6; Fig. 8 is a diagrammatic perspective view showing the operative parts of the selector which constitutes a part of the speed control apparatus; Fig. 9 is a top plan view of the parts of the speed control apparatus which are mounted in casings, hereinafter termed the gear box and the cam box, the covers of said casings being removed; Fig. 10, is an enlarged vertical longitudinal section through the gear box and the cam box on the line 10-10 in Fig. 9 the speed indicator being removed; Fig. 11 is an enlarged vertical transverse section through the gear box substantially on the line 11-11 in Fig. 9, parts of said section being separated for the sake of clearness and the speed indicator being shown as partly turned; Fig. 12 is a top plan view of one of the units mounted in the cam box and hereinafter termed a block combination, together with its associated parts; Fig. 13 is an enlarged vertical transverse section through the cam box on the line 13-13 in Fig. 9 and shows a block combination and its associated parts in elevation; Fig. 14 is an enlarged vertical transverse section through the cam box taken on the line 14-14 in Fig. 9 and showing the multiplier combination in elevation; Fig. 15 is an enlarged fragmentary top plan view of the multiplier arm and its associated gears; Fig. 16 is a fragmentary vertical section on the line 16-16 in Fig. 12; Fig. 17 is a vertical section on the line 17-17 in Fig. 9; Fig. 18 is an enlarged fragmentary view showing the cam starter arm and its associated gears in elevation; Fig. 19 is a horizontal section through the speed indicator on the line 19-19 in Fig. 20; Fig. 20 is a vertical section through the speed indicator taken on the line 20-20 in Fig. 19; Fig. 21 is a diagrammatic view showing the wiring and electrical connections between the parts of the speed control system which are mounted on the car; Fig. 22 is a diagrammatic view showing the electrical connections between the parts of the speed control system which

are located along the trackway; Fig. 23 is a diagrammatic view showing the electrical connections for the contact shoe; Fig. 24 is an enlarged vertical section through the valve casing of the electrically operated valve shown in Fig. 25; Fig. 25 is a vertical diametrical section through an electrically operated valve suitable for use as a part of the speed control apparatus for causing an emergency application of the brakes, and Fig. 26 is a diagrammatic view illustrating, according to the well known method of plotting curves, certain factors and variable quantities with which the speed control apparatus has to deal, said Fig. 26 being drawn on the basis of certain assumed conditions.

Referring to the accompanying drawings, a system for controlling railway traffic embodying the invention is shown applied to an electrically propelled car of the type commonly used in subways or on elevated railways, but it is to be understood that both the invention and the particular physical embodiment shown are not limited in their application to this particular kind of vehicle and are as applicable to steam locomotives or other railway tractive apparatus as the particular kind of car shown. The car shown is arranged to be operated in either direction from a compartment or cab at either end. The arrangement of the parts of the speed controlling apparatus on the car is shown in the Figs. 1, 2, 3 and 4. The contact shoes B are carried by the car, and are preferably secured to yokes 37 secured in any suitable way to the trucks 5 of the car, at each end and on opposite sides of the car. The selector SR is also carried by the car, and is preferably secured to one of the trucks 5 between the wheels as shown in Fig. 3, the operating parts of said selector SR being enclosed in a suitable casing. The other parts of the speed control apparatus, including the speed indicating device SI, its associated gearing and the cam mechanism, are located in metallic casings 6 and 7 (Fig. 3), which are supported in some accessible place, being preferably mounted on cushioning springs 8, and secured to the frame of the car underneath a seat, as shown in Fig. 1. These casings 6 and 7 are joined together so as to be in effect one casing having a partition wall extending transversely thereof (Fig. 9); but for convenience in description the respective casings will be hereinafter termed the gear box 6 and the cam box 7.

On one of the axles of the car is mounted a gear casing 9, (Figs. 1 and 3) in which is contained suitable gearing which operatively connects said axle with a shaft 10 (Fig. 3) through an intermediate universal coupling 11. Telescoping over the shaft 10 is a tubular shaft 12 having a longitudinal slot therein through which passes a pin 13 fixed to the shaft 10, thereby permitting said tubular

shaft 12 and said shaft 10 to slide longitudinally relatively to each other, but compelling said tubular shaft and said shaft 10 to turn together. The tubular shaft 12 is connected by a universal coupling 14 to a vertical shaft 15 leading to the speed indicating device SI in the gear box 6. The pin and slot connection between the tubular shaft 12 and shaft 10 and the universal couplings 11 and 13 permit the parts of the apparatus secured to the car body to follow the usual movements of said car body relatively to the truck 5 without binding the parts or interfering with their operation.

Near one end of the gear box 6 and the cam box 7 is a junction box 16 which is connected to the cam box 7 by a conduit 17. Each of the contact shoes B is connected by a length of flexible conduit 18 to a length of rigid conduit 19 bent into an angle and extending to a point near the pivot axis of the truck; and connected to the rigid conduit 19 by a loop of flexible conduit 20 is another length of rigid conduit 21 which leads to the junction box 16. The selector SR is also connected to the junction box 16 by lengths of rigid conduit 23 and 25 and flexible conduit 22 and 24 in the same way as the shoes B. Near the middle of the car and at one edge of the floor thereof, is supported a casing 26 (Figs. 1 and 2) in which are a valve EB (shown in Figs. 24 and 25) for controlling the emergency application of the brakes of the car, a device for cutting the speed control apparatus on the car out of service, a device P for shutting off power to the car and a valve SB for controlling the service application of the brakes; and this casing 26 is connected to the junction box 16 by a conduit 27. The car is shown as provided with pneumatic brakes of well known construction, this system of brakes comprising a train pipe 28, brake cylinders and auxiliary reservoirs 29, suitable automatic controlling valves 30, and lengths of flexible hose 31, by means of which two or more cars can be connected so that the brakes will be applied simultaneously on all of the cars of the train by venting the train pipe 28. In each cab or compartment for the motorman is placed a signal panel, preferably in the form of a casing 32 (Fig. 2) adapted to contain lights, movable indicating parts or the like; and these panels are connected by conduits 33 to the junction box 16. The junction box 16 is connected by a conduit 34 to a car junction box 35 which is usually provided on electrically propelled cars, and an arrangement of conduits and couplers, not shown, is made whereby suitable continuous conductors or busses running the full length of the train are provided. The electrical connections between the different parts of the speed control apparatus are not shown in the figures illustrating the construction of these parts in order to avoid

confusion; but are shown diagrammatically sulated therefrom. In Figs. 21 and 22; and the electrical circuits, as well as the relation which the operative parts of the speed control apparatus and the electrical wiring bear to the entire operative scheme, will be pointed out hereinafter at length in the description of the operation.

The contact shoe

Referring particularly to Figs. 3 to 7 inclusive, the contact shoe B is supported by a bar 36 of wood or other suitable insulating material, which is adjustably supported on a yoke 37 fixed to a side frame of one of the car trucks 5. The adjustable connection between the bar 36 and the yoke 37, as shown in Figs. 3 and 4, is preferably made by providing the arms of the yoke 37 with a plurality of grooves 38 and by supporting the ends of said bar 36 in a clip 39 which is clamped by bolts 40 to the arms of said yoke and which has teeth adapted to cooperate with said grooves of said yoke. Referring to Figs. 5, 6 and 7, the shoe B comprises a support 41, a movable arm 42 and a foot 43. The shoe support 41 has spaced ears 44 adapted to straddle the bar 36; and a washer or clip 45 having ears corresponding to the ears 44 is disposed on the opposite side of said bar, clamping bolts 46 passing through said washer and said shoe support. In the shoe support 41 is a vertical circular hole in which is swiveled a turning stud 47, which has an enlarged head at its lower end and is provided with a collar 48 at its upper end, pinned to said turning stud 47 and serving to hold it in place. The movable arm 42 is bifurcated at one end and straddles the head of the turning stud 47; and a hinge pin 49 pivotally connects said arm and said stud. The foot 43 of the shoe B or the portion thereof which contacts with the ramp, is disk-like in form, having a central stud 50 mounted in antifriction bushings 50¹ supported in the movable arm 42 near the outer end thereof so that said foot 43 is freely revoluble, a nut 51 serving to hold said foot 43 in place. Extending downwardly from the shoe support 41 above the middle of the arm 42 is a hollow post 52 through which passes a plunger 53. Fixed to the upper end of the plunger 53 is a collar 54 which limits the downward movement of said plunger. Secured to the lower end of the plunger 53 is a lateral finger 55; and secured to the arm 42 is a guide 56, Z-shaped in cross-section and adapted to cooperate with said finger 55. A compression spring 57 encircles the plunger 53 and bears against the finger 55 and the upper end of the hollow post 52. Secured to the support 41 for the shoe B is a block 58 of insulating material, to which are secured two springs 59; and arranged to cooperate with these springs 59 is a contact disc 60 which is fixed to the upper end of the plunger 53 but is in-

turning stud 47 is fixed a cylindrical piece of insulating material to which is fastened a contact block 61; and secured to the insulating block 58 are two contact springs 62 and 63 arranged to make contact with the contact block 61 in a certain turned position of the arm 42 and the stud 47. The upper portion of the shoe support 41 is covered by a protecting cover 64 secured in place by bolts 65 (Fig. 4). The flexible conduit 18 leads to a plug coupling 66 which is fixed to the shoe support 41 by a bar 67, as shown in Fig. 4, the base or socket of the coupling 66 extending into the interior of the casing 64. This shoe structure has been claimed in a divisional application, which matured into Patent No. 1,308,544, dated July 1, 1919.

The ramps R used in this embodiment of my invention preferably comprise lengths of angle iron mounted on wooden blocks, or other supports of insulating material, the ends of said ramps being curved downwardly gradually, as shown in Fig. 4, so as to enable the foot 43 of a shoe B to pass over a ramp without severe shock, and to permit said foot 43 to drop a certain distance to its normal lower position shown in Fig. 6 before the foot 43 breaks electrical contact with the ramps R, for the reason which will be fully explained hereinafter.

The selector

The operative parts of the selector SR are shown diagrammatically in Fig. 8, and comprise a horizontal supporting member 68 extending transversely of the car and track and disposed a short distance above the road bed between the rails of the track. A plurality of selector tappets 69 are pivoted at one end to the horizontal supporting member 68 and have downwardly extending projections 70 at their other ends. Above the selector tappets 69 are pivotally supported in any suitable manner two horizontally disposed floating levers 71 and 72, one lever 71 being connected by links 73 at its ends to the two outer selector tappets 69, and the other lever 72 being connected by links 74 at its ends to the two selector tappets located between the middle selector tappet 69^a and the outer selector tappets. To the middle of the lever 72 is pivotally connected a rack bar 75, the teeth of which mesh with a gear 76 secured to a rotary contact drum 77, said drum being supported in suitable fixed bearings, not shown. A similar construction is used for the floating lever 71, which is connected to a rack bar 78, which turns a contact drum 79. The contact drums 77 and 79 are made of suitable insulating material and are provided with arcuate contact strips 80 which cooperate at appropriate positions of the drums 77 and 79 with a corresponding pair of contact springs 81, which are secured

to blocks of insulating material 82 fixed adjacent to said drums. Each of the links 73 and 74 has an integral tooth or stop 83, the lower edge of which is beveled. Extending 5 parallel with the supporting member 68 and above the selector tappets 69, is supported in any suitable way a rotary shaft 84, on which are loosely mounted a number of latches or detents 85, the outer ends of each 10 latch being adapted to cooperate with the beveled face of the stop 83 of the corresponding link, 73 or 74, as the case may be, when said link is in its upper position. The latches 85 are pressed towards the links 73 and 74 by 15 springs 86 connected to the supporting member 68 and to downwardly projecting pins or arms 87 integral with said latches. Fixed to the shaft 84 are four collars 88 having laterally projecting pins 89 each of which extends 20 underneath the adjacent latch 85. The middle selector tappet 69^a operates a short releasing plunger 90 which is provided with a stop 91 having both faces thereof beveled; and these beveled faces of the stop 91 co- 25 operate with a release arm 92 fixed to the shaft 84. At appropriate places along the trackway are secured short selector ramps 93 which have beveled ends and which are preferably resiliently mounted on supporting 30 springs 94, as shown in Fig. 3, said selector ramps being arranged and adapted to raise the selector tappets 69.

The speed indicator

35 Referring more particularly to Figs. 9, 11, 19 and 20 the device which is operated in accordance with the speed of the train and which is conveniently termed a speed responsive device or speed indicator SI is of the centrifugal type and is mounted in the gear box 40 6 to rotate on a vertical axis. The speed indicator SI is driven by the shaft 15 which, as hereinbefore described, is connected to a car axle, and secured to the upper end of the shaft 15 is a short driving spindle 95 (Figs. 45 11 and 20) which is mounted in bushings 96 supported in a bossed hole in the bottom 6^b of the gear box 6. Surrounding the driving spindle 95 and fastened thereto by a pin 97, or other means, is a rotary sleeve 98, which is 50 provided with two pairs of vertical standards 99, 99^a, 100 and 100^a arranged at diametrically opposite points thereon. Between each pair of the standards 99, 99^a and 100, 100^a are disposed two supporting arms 101 having weights at their outer ends and arranged crosswise of each other; and these 55 101 are pivotally connected at their middles to the corresponding pair of standards 99, 99^a or 100, 100^a, as the case may be, by a pin 102 fixed in said standards. The corresponding arms 101 on opposite sides of the rotary sleeve 98 are spaced apart by washers 103¹ at their lower ends and are connected 60 by bolts 103 (Fig. 19) and at their upper

ends by similar bolts 104, on each of which bolts 104 is revolvably mounted a flanged wheel 105 (Fig. 11).

Extending transversely of the gear box 6 and above the speed indicator SI is a cross bar 106 (Fig. 9), which is integral with the sides 6^s of the gear box 6 or secured thereto, and to which the upper end of a guiding rod 107 is pinned. The lower end of the guiding rod 107 is journaled in a recess in the upper end of the driving spindle 95; and slidably mounted on said guiding rod 107 is a movable collar 108, on which is journaled a collar 108^a (Fig. 20) which has two oppositely projecting curved arms 109 (Fig. 11), on the upper edges of which rest the flanged wheels 105 of the weighted arms 101. A compression coil spring 110 encircles the guiding rod 107, and is interposed between the under face of the movable collar 108 and the rotary sleeve 98. The movable collar 108 is provided at its upper end with spaced annular flanges 111; and straddling the upper end of said collar 108 is the bifurcated end 70 75 80 85 90 95 100 105 110 115 120 125 130 of an arm 112, to which are secured pins carrying loose rollers 113 (Fig. 11), said rollers 113 entering the space between the annular flanges 111.

The operation of the centrifugal speed indicator SI shown and described is like that of the well-known ball governor. As the sleeve 98 is revolved by the driving spindle 95 and the shaft 15, the outer weighted ends of the arms 101 are thrown outwardly by centrifugal force and the rollers 105 carried by the upper ends of said arms press down on the curved arms 109 of the collar 108^a. The curvature of these arms 109 is designed with due regard to the varying centrifugal force and the varying force of the spring 110 so that the collar 108 will be moved up and down substantially uniformly in correspondence with the variations in the speed of rotation of the car axle; and the outer end of the arm 112, being operatively connected to the collar 108, is moved up and down with said collar.

The cam operating gearing

Referring to Figs. 9, 10 and 11, the lower end of the sleeve 98 of the speed indicator SI is provided with a downwardly projecting annular flange 114, on the outer surface of which are formed helical teeth 115 constituting a worm wheel, as shown in Fig. 11. This worm wheel 115 meshes with a small gear 116 fixed to a shaft 117, which extends transversely of the gear box 6, and which is journaled at one end in a boss 118 integral with a side of a depressed portion or oil reservoir 120 in the bottom 6^b of the gear box 6, and at its other end in the opposite sides of said depressed portion. The shaft 117 carries a small gear 119, as shown in Fig. 10, which meshes with a larger gear 120, which is 125 130

mounted loosely on a shaft 121, and which is secured to a smaller concentric gear 122. A rocker arm 123, hereinafter termed the multiplier arm, is pinned to the shaft 121 and carries at one end a gear 124 (Figs. 11 and 15) journaled on a pin or stud 125 fixed in said multiplier arm 123. At the other end of the multiplier arm 123 are two gears 126 and 127, respectively, of different sizes fastened together and journaled concentrically on a pin or stud 128 fastened in said multiplier arm 123. The larger gear 127 of the two gears 126 and 127, at one end of the multiplier arm 123 and the gear 124 at the other end of said multiplier arm mesh at all times with the small gear 122 which is secured to the large gear 120. By reason of this construction, the gears 124 and 127 at both ends of the multiplier arm 123 are driven by the small gear 122, and said multiplier arm 123 and the gears 124, 126 and 127 may be rocked about the axis of the gear 122 without altering the meshing of said gears 124 and 127 with said gear 122. Above the shaft 121 is a stud or spindle 128 (Figs. 10 and 11) fixed to an adjustable hanger sector 129 and journaled on this stud 128 are two gears 130 and 131, respectively, of different sizes and connected to each other, the larger gear 130 being arranged in the same plane as the gears 124 and 126 carried by the multiplier arm 123, so that either of said gears 124 or 126 may be thrown into mesh with said large gear 130.

At one side of the stud 128 is located a shaft 132 (Fig. 11) extending transversely of the gear box 6, one end of which is journaled in a boss 133 formed on the inner side wall 6^a of said gear box 6, and the other end of which is journaled in a bearing block or support 134 (Figs. 9 and 10) fixed to the bottom 6^b of said gear box. Fixed to the shaft 132 at one end, is a large gear 135, which meshes with the small gear 131, mounted on the stud 128. The hanger sector 129 is pivotally mounted near its lower corner on the shaft 132, and is provided with an arcurate slot 136 near its upper corner (Fig. 11), a tap-bolt 137 passing through said slot into the inner side wall 6^a of the gear box 6 and serving as a means for clamping said hanger sector in its different adjusted positions. By adjusting the hanger sector 129 the gears 130 and 131 may be moved up and down about the axis of the shaft 132 as a center to change the relative positions of the gears 130 and 131 and the gears 124 and 126 carried by the multiplier arm 123 and thereby alter the amount of movement of the multiplier arm 123 necessary to shift one of the gears 124 or 126 out of mesh with the gear 130 and bring the other of said gears 124 or 126 into mesh with said gear 130. Near the middle of the shaft 132 is fixed a small gear 138 (Fig. 10), and loosely mounted on the shaft 132 between the bearing block 134 and this small gear 138 is a sleeve 139 having two integral arms 140 and 141, respectively, projecting in the same direction therefrom near each end. The arm 140 adjacent to the gear 138 has fixed thereto two studs or pins 142 and 143, as shown to the best advantage in Fig. 18, upon which are journaled two intermeshing gears 144 and 145, respectively, which are of different sizes, the gear 144 being also in mesh with the gear 138 on the shaft 132. Above the shaft 132 is a cam shaft 146, which extends transversely of the gear box 6 from side to side thereof, being journaled at one end in an inwardly projecting boss 147 (Fig. 10), and extending through the opposite side wall into the cam box 7. Secured to this cam shaft 146 is a large gear 148 meshing at times with the small gear 145 carried by the arm 140, hereinafter termed the cam starter arm, said large gear 148 having a semi-circular portion of its circumferential edge cut away as indicated at 149 (Fig. 11). The large gear 148 is arranged in the same plane as the small gear 145 carried by the cam starter arm 140 so that said arm may be rocked up and down to move said small gear into and out of mesh with the large gear 148, the parts being so proportioned that the movement of said small gear about the axis of the shaft 132 is substantially radial of the large gear 148.

The cam-starter arm 140 and the sleeve 139 are actuated by an electromagnet 150 having two coils which are suitably fastened to projecting lugs or brackets 151 integral with the end wall 6^a of the gear box 6. The armature 152 of the electromagnet 150 is guided by short pins 153 (see Fig. 10) projecting upwardly from the pole pieces of the coils of said electromagnet; and near the middle of said armature is fastened a plunger 154 which extends downwardly between the coils of said electromagnet and is pivotally attached at its lower end to the arm 141 of the sleeve 139. A compression spring 155 is mounted on an upwardly projecting stud 156 integral with the bottom 6^b of the gear box 6; and the upper end of this spring 155 bears against a cap 157 (Fig. 11) on the lower end of the plunger 154, whereby said plunger is pressed upwardly by said spring 155 to move the teeth of the gear 145 into mesh with the teeth of the large gear 148.

The cam shaft 146 is provided with a mechanism for restoring it to its normal position after it has been actuated, as shown in Figs. 10 and 17, said mechanism comprising a pinion 158 secured to said cam shaft 146 and a reset arm 159 having a sector gear 160 at its upper end meshing with the said pinion, said reset arm being fastened to a shaft 161 by a pin 162, as shown in Fig. 17. The reset arm 159 is provided at its lower end with a horizontal lifting piece 163 extending

longitudinally of the shaft 161. The shaft 161 is journaled at one end in the outer side wall 6^s of the gear box 6 and at its other end in the bearing block 134. Loosely mounted on the shaft 161 are two weighted arms 164 (Figs. 9 and 17) arranged over the lifting piece 163 of the reset arm 159, said weighted arms 164 being held against movement lengthwise of the shaft by a short pin 165 (Fig. 10). Extending through each weighted arm 164 near the outer end thereof, is a rod 166 which has its lower end pivotally secured in a stud 167 integral with the bottom 6^b of the gear box 6, and which has a collar 168 near its upper end held in place by a pin; and interposed between the collar 168 on each rod 166 and the upper face of the corresponding weighted arm 164, is a compression coil spring 169, which acts to press the corresponding weighted arm downwardly. The downward movement of the weighted arms 164 is limited by the upper edges of the studs 167, in which the rods 166 are secured, so that the reset arm 159 and the sector gear 160 are normally held in their middle position, as shown in Fig. 17; but when said reset arm 159 is displaced from its middle position by movement of the cam shaft 146 one of the springs 169 is put under tension so as to tend to return said reset arm to its middle position, and also to cause the cam shaft 146 and the large gear 148 secured thereto to return to their normal positions.

Above the cam shaft 146 is a speed shaft 170, which extends transversely of the gear box 6 and is journaled at one end in a boss 171 formed on the outer side wall 6^s thereof and extends through the other side wall 6^s into the cam box 7. To this speed shaft 170 is fixed the arm 112, hereinbefore described, which extends to the speed indicator SI; and also fixed to this speed shaft 170 is a finger 172 (Figs. 9, 10 and 11) having a tip of insulating material. Secured to the end wall 6^e of the gear box 6 and suitably insulated therefrom, are two contact springs 173 and 174 (Fig. 11), which are arranged to be closed by the finger 172 on the speed shaft 170. These contact springs 173 and 174 and the finger 172 are arranged so that said contact springs will be pressed together in the positions of the arm 112 corresponding to any speed less than a predetermined speed, as for instance, five miles an hour; but so that said contact springs will be separated by their inherent resiliency in the positions of the arm 112 corresponding to speeds greater than said predetermined speed. In other words, the contact springs 173 and 174 are pressed together when the speed of the train is below a certain predetermined speed and are separated when the speed of the train is greater than said predetermined speed.

In the cam box 7 are arranged certain other operating parts of the speed control appa-

ratus, certain of these parts being intimately associated with the devices hereinbefore described and located in the gear box 6, the mechanical connection between the devices in the gear box 6 and the associated devices in the cam box 7 being obtained by means of the shafts 121, 146 and 170 running from one to the other. The devices in the cam box 7 comprise a mechanism for actuating the multiplier arm 123 and hereinafter termed the multiplier combination; a plurality of cams and their associated mechanisms arranged in units and hereinafter termed the block combinations; and car relays of appropriate construction.

Multiplier combination

Referring to Figs. 9, 10 and 14, the shaft 121 to which the multiplier arm 123 is secured, passes through the inner side wall 6^s of the gear box 6 into the cam box 7, and is mounted in a bearing 175 integral with the bottom 7^b of the cam box 7. Loosely mounted on the shaft 121 is an angle lever (Fig. 14) one arm 176 of which extends horizontally and the other arm 177 of which extends vertically. Above the outer end of the horizontally extending arm 176 is solenoid 178 which is secured to a stand 179 suitably fastened to the bottom 7^b of the cam box 7 and which has its core 180 pivotally connected to a link 181, which in turn is pivotally connected to said horizontally extending arm 176 of the angle lever. Pinned to the shaft 121 is a vertically extending tilting arm 182, which is adjustably connected to the vertically extending arm 177 of the angle lever by a bolt 183 extending through a hole in said vertically extending arm 177 and through an arcuate slot 184 in said tilting arm 182. This construction provides for the adjustment of the amount of movement of the core 180 of solenoid 178 necessary to produce a certain angular movement of the shaft 121.

Fastened together and to the stand 179 by clamping bolts 185 is a plurality of blocks 186 of insulating material, constituting a contact holder; and a number of contact springs 187¹, 187² and 188, arranged in two rows, are gripped between said blocks 186. These contact springs are arranged in each row in groups of three, the two outer springs 187¹ and 187² of each group having contact blocks 189 extending toward each other, and the middle contact spring 188 of each group having oppositely disposed contact pieces arranged to engage the contact blocks 187¹ or 187² of either of the two outer contact springs of that group as said middle contact spring 188 is rocked back and forth. The upper end of the tilting arm 182 is bifurcated, and in each bifurcation thereof is fixed a pin 190 (Fig. 14) which fits in a short slot 191 in an operating bar 192. There are two of these operating bars 192 arranged parallel to each

other and extending from the upper end of the tilting arm 182 toward the solenoid 178; and these two operating bars 192 are guided by pins 193 secured to a cap 194 (Fig. 9) attached to said solenoid. Extending between the operating bars 192 at intervals are pins 195, upon which are mounted rollers 196 of insulating material, said rollers 196 being arranged in pairs and spaced so that the middle contact spring 188 of each group of three contact springs is located between a pair of the rollers 196. By reason of this construction the middle contact springs 188 are swung back and forth as the tilting arm 182 is tilted in opposite directions.

Block combination

Arranged in the cam box 7 are a number of units, one of which is shown, each unit including cams of a certain configuration and their associated parts, and being designed for use for a particular block or blocks having substantially the same physical characteristics as regards grades, curves and like factors which affect the braking distance of the train. These units, which are conveniently termed block combinations, are each constructed the same, and a description of one will suffice for all, it being understood, however, that the specific shape of the cams in these different block combinations is slightly different.

Referring to Figs. 9, 10, 12 and 13, each block combination comprises a stand or supporting frame 197 fastened to the bottom 7^b of the cam box 7; and secured on this stand 197 is an electromagnet 198 arranged vertically and having the lower end of its core extending downwardly into the upper part of said stand. The armature 199 of the electromagnet 198 is arranged vertically and is mounted at its lower end on a pin 200 fixed in the stand 197, a compression spring 201 being arranged between the outer face of said armature and a small transverse pin in said first mentioned pin 200, whereby the lower end of said armature 199 is pressed against the stand 197. At a short distance above the pin 200 and the spring 201, the stand 197 is formed with a shoulder 202 which constitutes the pivot point or fulcrum for the armature 199. The armature 199 has a hole near its upper end which fits loosely over a pin 203 of non-magnetic material which has an enlarged head serving to limit the outer movement of the upper end of said armature, said pin 203 being suitably secured to the upper pole piece 204 of the electromagnet 198.

Riveted to the stand 197 is a sheet metal bracket having two upper parallel arms 205 and two lower parallel arms 206 which are shorter than said upper arms. Between the lower arms 206 of the bracket is disposed a contact holder 207 comprising a row of blocks 65 of insulating material which are clamped to-

gether by bolts 208; and a number of contact springs arranged in two rows are gripped between said blocks. Also secured to the contact holder 207, by being clamped between the insulating blocks thereof, is a downwardly 70 projecting hinge member 209, the ears of which are pivotally connected by pins 210 to the lower pair of arms 206 of the bracket, so that said contact holder 207 may tilt as a whole relatively to said bracket. An inverted U-shaped member 211 is also fastened to the contact holder 207 by having its lower ends gripped between the insulating blocks of said contact holder; and said member 211 is connected to the armature 199 of the electromagnet 198 at its upper end by two links 212, each of which are pivotally connected at their respective ends to said U-shaped member 211 and to said armature 199.

The contact springs secured to the contact holder 207 are constructed substantially the same, but other devices associated with them cause them to have different operations, so that it is necessary to refer to these contact springs separately in pairs. The two pairs of contact springs 213 and 214, which are arranged in one row and are shown in Fig. 13, are designed to control the circuits for the warning signal and for causing an automatic service application of the brakes, which circuits will be more fully set forth hereinafter. The circuit for the service application of the brakes is controlled by the pair of contact springs 214 which are nearest the electromagnet 198, at the right hand side in Fig. 13. 90 These contact springs 214 are normally separated, and when the contact holder 207 is rocked, these contact springs 214 move with it but remain separated. The other pair of contact springs 213 control the circuit for the warning signal, and also serve to move the above mentioned pair of contact springs 214 into contact with each other by means of a block 215 of insulating material which is fixed to the inner contact spring 213 in position to 95 press against the outer contact spring 214 after the contact springs 213 have been moved together and then further a short distance in the direction of the other pair. The outer contact spring 213 is mounted loosely on a pin 216 secured to a supporting clip 217, which clip is fastened to the contact holder 207, a small compression spring 218 being arranged to hold said outer contact spring 213 normally in alignment with said supporting clip. The outer contact spring 213 has fixed thereto near its upper end a freely revoluble roller 219. The outer pair of contact springs 213 are also normally separated so as to maintain a break in the circuit for the warning signal, 110 and when the contact holder 207 is rocked they remain separated until actuated by other mechanism hereinafter described.

The two pairs of contact springs 220 and 221 which are arranged in the other row are 115

shown in Fig. 16, these pairs of contact springs 220 and 221 being arranged to control the circuits for the automatic emergency application of the brakes and the stick circuit 5 for the electromagnet 198, respectively. Secured to one of the upper arms 205 of the bracket is a pin 222 upon which is mounted a roller 223 of insulating material, said pin and roller being disposed between the pairs 10 of contact springs 220 and 221; and the outer contact spring 220 is provided near its upper end with a freely revoluble roller 224. The two pairs of contact springs 220 and 221 are separated when the contact holder 207 15 is in its normal position, shown in Fig. 16, but when the electromagnet 198 is energized and the contact holder 207 is rocked, the pair of contact springs 221 are pressed together, since the outer spring adjacent to the roller 20 223 is held immovable while the inner contact spring is moved with the contact holder 207.

Extending between the outer ends of the upper arms 205 of the bracket is a fixed pin 225, on which are journaled two sectors 226 25 and 227 which are spaced apart by a sleeve 228, (Fig. 12) and which have downwardly projecting arms 229, said arms 229 being connected to the upper arms 205 of the bracket by tension springs 230. Also journaled on the pin 225 are sector-shaped plates 30 or contact closers 231, 232 and 233. Two of these contact closers 231 and 232 are adjustably secured to the sector 226 by a clamping bolt 234 extending through a hole in said 35 sector and through an arcuate slot 235 in each of said contact closers; and the other contact closer 233 is adjustably secured to the other sector 227 in a similar manner by a bolt 236 passing through a hole in said 40 sector 227 and through a slot 237 in said contact closer. The outer edges of these contact closers 231, 232 and 233 are arranged to cooperate with the rollers 219 and 224 to effect proper movement of the pairs of contact 45 springs 213, 214, 220 and 221; and for this purpose the outer edge of each of said contact closers comprises two portions at a different distance from the pivot pin 225, the place where said portions merge constituting abrupt shoulders, so that as said 50 sectors 226 and 227 are rocked these shoulders are brought against the rollers 219 or 224, as the case may be, thereby causing said rollers to move radially of said sectors and to open 55 and to close the respective pairs of contact springs controlled by said rollers at proper intervals accordingly as said sectors are rocked.

Adjacent to each block combination on the cam shaft 146 is pinned a collar 238 (Fig. 12) 60 and fastened to this collar by bolts 239 are two cams 240 and 241. Also adjacent to each block combination on the speed shaft 170 is pinned a downwardly extending speed-arm 242 which carries at its lower end a horizontal 65 pin 243 which projects from said arm in op-

posite directions (Fig. 10). Journaled at their lower ends on the projecting portions of the pin 243 are two floating levers 244, one being located on each side of the speed-arm 242 and being held in place by a small transverse pin passing through the pin 243. Each of the floating levers 244 carries a freely revoluble flanged roller 245 at its upper end, which roller is arranged to bear against the edge of the corresponding cam 240 or 241, as the case may be. Near the middle of each floating lever 244 is pivoted one end of a link 246, the other end of which is pivoted to the lower end of the downwardly projecting arm 229 of the corresponding sector 226 or 227, as the case may be. 70 75 80

Other parts of the speed control apparatus

The other operating parts of the speed control apparatus comprise a car relay of suitable construction, which is preferably arranged to respond to alternating current of different voltages, and is provided with suitable devices so that it can be retained in its normal or inactive position by energizing from a battery or other local source of electric current carried by the train. In the particular construction shown in the accompanying drawings, this car relay comprises two units S and K, shown diagrammatically in Fig. 21, each consisting of two separate coils or windings, one of said coils in each unit being designed for alternating current, and the other coil for direct current. It is to be understood that these coils and the parts of the relay are properly designed for the purposes for which they are used, the turns of wire, the magnetic fields and the like being duly proportioned according to the result to be obtained. The car relay unit S herein-after termed the stop relay, is so designed that a voltage higher than a predetermined low voltage will send sufficient current through its alternating current coil S^a to establish a tractive force strong enough to pick up its armatures. The other unit K of the car relay, herein-after termed the control relay, is so designed that a high voltage will send sufficient current through its alternating current coil in series with an impedance 302 (Fig. 21) to establish a tractive force strong enough to pick up its armatures and with medium voltage and with the impedance 302 shunted, the tractive force of said control relay K will hold its armatures raised; but with low voltage and the impedance 302 shunted, the tractive force is not strong enough to hold its armatures raised. These two units act substantially as described in the application of W. K. Howe, Ser. No. 6,248, filed February 5th, 1915. 90 95 100 105 110 115 120 125

Another operating part of the speed control system is a transformer T, shown diagrammatically in Fig. 21, which is mounted upon the car in some suitable place, prefer- 130

ably in the junction box 16; and this transformer is arranged in certain circuits to be hereinafter set forth, whereby the action of setting said speed control apparatus into 5 operation is effected by alternating current, the kind of operation produced depending upon the voltage of this alternating current.

Referring to Fig. 21, the signals in the panel 32 in each motorman's compartment 10 are shown diagrammatically and comprise a suitable warning signal A; a green lamp G for giving a "proceed" indication; a yellow lamp Y for giving a "caution" indication; suitable indicators 1^a, 1^b, 1^{b_m} for showing the 15 particular block combination corresponding to the block in which the train is running, or is about to enter; and a suitable device N. S. for giving an indication when the train is passing through unsignalled territory. A 20 switch U, shown diagrammatically with its connections in Fig. 21, is provided in each motorman's compartment, and is operatively connected in some suitable manner, not shown, to the car controller in that compartment 25 so as to be closed when said controller is being operated, to control the train, thereby causing the signals in the compartment from which the train is being run to be operated, while the signals in all of the other compartments of the cars of the train will not be 30 operated.

The mechanism in the casing 26 for controlling movement of the train comprises a device P for shutting off the power to the vehicle, which may be any one of the several 35 devices well known in the art for accomplishing this purpose, as for instance, an electrically operated circuit breaker which interrupts the operating circuit for the electric 40 motors propelling the train. The device P is operated simultaneously with either the service or the emergency application of the brakes, as hereinafter fully explained, and is shown in the particular embodiment of the 45 invention illustrated in Fig. 21 as arranged so as to be operated when supplied with electric energy and to be inoperative when deenergized. The electrically operated valves 50 EB and SB for controlling the emergency and service applications of the brakes, respectively, are of any suitable construction adapted for this purpose. The emergency valve EB is shown in the particular embodiment of the invention illustrated in Fig. 21 55 as arranged to be operated to vent the train pipe when the electric current normally supplied to it is cut off; whereas the service valve SB is shown as arranged to be operated to vent the train pipe when supplied with electric current. The construction and operation 60 of the device for cutting the speed control apparatus of a car out of service will be set forth after the operation of the speed control apparatus under normal conditions has been 65 described.

Operation

Before setting forth specifically the operation of the different parts and the details of the electric circuits, a general outline of the scheme of operation will be given as follows: 70

As the vehicle approaches each block or a number of blocks having the same physical characteristics, it passes over a number of selector ramps 93 arranged in a predetermined way between the rails to effect a certain movement of the selector circuit controller drums 77 and 79 so as to prepare a circuit for a particular block combination corresponding to the block or blocks next ahead, that is, a train on the block C approaching block D (Fig. 22) would have the selector circuit controller drums moved to prepare the circuit for the block combination corresponding to the block D. The selector ramps are preferably located as far in advance of the beginning of the block to which they correspond as possible, in order that the entire length of a train may pass said selector ramps and have all of its selector circuit controllers properly actuated before the train reaches the entrance to that block. For this reason the selector ramps 93 for each block are preferably located near the entrance of the preceding block, as shown in Fig. 22, the limitation upon the distance these selector ramps 93 can be in advance of the entrance of their block being fully explained hereinafter. Then, as the train approaches the block D, the first contact shoe B of the train strikes the ramp R at the entrance to this block D, and by certain circuits and movements of the parts provides for the automatic signaling and control of the train as follows:

First, the parts of the speed control apparatus, if the train has been running under the dominance of this speed control, are restored to their normal or idle positions so as to relieve the train from the speed control to which it may have been subjected in passing through the block it now occupies, that is, the block C. However, if danger conditions exist in the next block D the parts are not reset or restored to their normal positions; and if the train enters this next block D it 115 must do so at the low speed to which it is restricted by the control imposed upon it in the preceding block.

Second, if danger conditions exist in the second block ahead, that is, in the block E, 120 (Fig. 22) the operative parts of the speed control apparatus are set into operation in accordance with the block combination of the block D; and the operation of these parts causes the green lamp G to be extinguished, the yellow lamp Y to be lit; then later, when the combined conditions of the speed of the train and its distance from the point of danger are such that the brakes should be applied, the warning signal A is actuated, then, if this 130

warning signal is disregarded, the power is shut off and service application of the brakes is automatically given; and, as a safeguard or as an alternate arrangement, an emergency application of the brakes may be given later.

Third, if no danger conditions exist either in the next block D or in the second succeeding block E, the operative parts of the speed control apparatus are retained in their normal or idle positions, and the train may proceed unrestrained, except as to a predetermined maximum speed limitation hereinafter explained, until it reaches the entrance to the second succeeding block E, whereupon the same operation may take place according to traffic conditions ahead.

Numerous safeguards are provided to prevent improper operation by reason of interference between the parts of the speed control apparatus, or by failure of the parts to operate properly; and these, together with certain other features of the construction and arrangement of parts, will be pointed out more fully in the following description of the operation.

The speed control apparatus embodying the invention may be used with or without the well-known fixed signals and their controlling circuits; but in the particular arrangement illustrated no fixed signals are used and the speed control apparatus is operated by a system of circuits along the trackway by means of which the movements of the vehicles are controlled. Referring more particularly to Fig. 22, wherein is shown diagrammatically the circuits along the track for the speed control system, one rail 250 of the two track rails 250 and 251 is divided by insulating joints 252 into blocks C, D, E, F, of appropriate length. Although only two blocks D and E and the adjacent ends of the blocks C and F are shown in Fig. 22 it is to be understood that the entire length of the trackway to be protected by the speed control system is divided into blocks in the same way. The electrically operated parts and the conductors connecting said parts are the same for each block and for clearness these parts and conductors associated with the blocks E and F will be given the same reference characters as the corresponding parts and conductors of the block D, with distinctive exponents "1" and "2" added to said reference characters.

The contact rail or ramp R is supported by members of insulating material adjacent to the entrance to each block. The energy for operating the circuits along the trackway is supplied from an alternating current line 253; and by means of a transformer 254 and wires 255 and 256 a difference of potential is maintained across the rails 250 and 251 of each block. Also connected across the rails of each block is an alternating current relay 257, whose armatures govern the controlling circuits. A transformer 258 is provided for

each block and its secondary is provided with taps by means of which the high, medium and low voltages suitable for the operation of the car relays may be obtained. The wiring connecting the ramps R, the armatures and contacts of the track relays 257 and the transformers 258 will be pointed out fully as the description of the operation progresses.

Referring to Fig. 21 wherein is illustrated diagrammatically the various parts of the speed control apparatus carried on the car and the electric wiring connecting them, these parts are shown in their normal position in which the speed control apparatus does not control the speed of the train, and except for the arrangement which imposes a limitation upon the maximum speed which the train may attain at any time which is explained hereinafter, the train may be driven at any speed desired. As outlined hereinbefore, the operation of the speed control apparatus may be divided into certain steps, and for convenience and clearness these steps will be considered separately.

The operation of setting up a block combination

This operation is accomplished by the selector ramps 93 located along the trackway between the rails, the position of these ramps between the rails furnishing the basis for the selection. The first position or selection of the selector SR is that in which all of the selector tappets 69 are in their lowest position, as shown in Fig. 8. As the car passes along the trackway one of the selector tappets 69, for instance, the right hand tappet in Fig. 8, is raised by a selector ramp 93, and the link 73 corresponding to this tappet is raised, thereby raising the corresponding end of the floating lever 71 about its other end as a fulcrum. After the link 73 is raised it is held in its raised position by the engagement of the latch 85 with the stop 83 on said link. The floating lever 71, when moved, actuates the link 78 and causes the controller drum 79 to rotate through a small angle, bringing certain contact strips 80 into contact with the corresponding pairs of contact springs 81. This constitutes the second position of the selector controller drum 79, which may control one or more circuits which are designed to be closed simultaneously. A third position or selection for the controller drum 79 is obtained by raising both ends of the floating lever 71 by arranging two ramps 93 so as to raise both of the end selector tappets 69 as the train passes over them. The other pair of selector tappets 69 operate in the same way to rotate the controller drum 77 to any one of three different positions; and by proper interconnection between the contact springs 81 of the two drums 77 and 79 a number of circuits may be controlled at different times. The arrangement shown has a capacity of con-

trolling nine different sets of circuits. In the wiring diagram shown in Fig. 21 the selector circuit controllers are represented as sliding bars carrying contact members each arranged to bridge any one of three pairs of contacts, and are designated generally S^1 and S^2 respectively, which correspond to the drums 77 and 79 and their associated parts.

After the selector drums 77 and 79 have been actuated to set up a certain block combination, these drums will be held in their operated position by reason of the fact that the latches 85 hold up whatever links have been raised; and this block combination will be maintained until these latches are released. The release of the latches 85 is accomplished by locating a selector ramp 93 at the proper place between the track rails to lift the middle selector tappet 69^a which raises the releasing plunger 90 and rocks the shaft 84 by means of the collar 92 so that the collars 88 carried by said shaft 84 will be rocked to bring the pins 89 into engagement with the under faces of the latches 85 and to turn them out of engagement with the stops 83 of their respective links. For this reason a middle selector ramp is used at each point where a change of combination is made, as shown in Fig. 22. When the latches 85 are released the levers 71 and 72 and the controller drums 77 and 79 return by gravity to their lowest or first position as shown diagrammatically in Fig. 21. In the particular embodiment of the invention shown and described, in this first position the circuit for a block combination for the worst block conditions will be set up, that is, the block combination which is determined on the basis of the most difficult conditions for stopping the train, and which corresponds to the block which is shortest and must be entered at the lowest speed. However, it is to be understood that the use of the lower or first position of the selector circuit controllers for the purpose specified is not compulsory because, when desired, this first or lower position may be selected as the one to perform some other function.

Setting the speed-control apparatus into operation

Assume that a train occupies the block E (Fig. 22) and that the train in question is in the block C approaching the block D. Before the shoe B of the train in question engages the ramp R, this ramp will receive high potential electromotive force from the associated transformer secondary terminals 267 and 451. The shoe B engages the ramp R before the front wheels touch the rails of section D. Then, as the front wheels of the vehicle pass on the rails of the section D, the current from the secondary of the transformer 254¹ will pass through said wheels and axle, and the track relay 257 will be de-energized, and its armatures will drop, as

will be clearly understood by those skilled in the art of railway signaling. Likewise, the train in the block E deenergizes the track relay 257¹ and causes its armatures to drop. A difference of potential is maintained between the ramp R at the entrance to the block D and the rail 251 equal to the low voltage by the following partial circuit:

Circuit number one

From the ramp R, conductor 261, armature 262 of the track relay 257 in its lower position, conductor 263, armature 264¹ of the track relay 257¹ in its lower position, conductor 265¹, the low voltage tap 266¹ of transformer 258¹ and conductor 267¹ to the track rail 251.

As the foot 43 of the shoe B of the vehicle strikes a ramp two things are accomplished: First, it is raised, and second, electrical contact is made with the ramp. Referring to Fig. 21, the raising of the foot 43 of the shoe B interrupts the multiple circuits through the direct current holding coils S^d and K^d of the stop relay S and the control relay K, the multiple circuit for the direct current holding coil S^d of the stop relay S being as follows:

Circuit number two

Local battery 268, conductor 269, positive bus 270, conductor 271, contact springs 272 and 273 of the car cut-out, conductor 274 to local positive wire 275, then by conductor 276 to contact spring 59 of the shoe B, contact disk 60 and the other contact spring 59 of said shoe, conductors 277 and 278, armature 279 of the stop relay S in its upper position, conductors 280 and 281, direct current holding coil S^d of the stop relay S, conductors 282 and 282¹ to the common return wire 283, and conductor 284 back to the battery 268.

The circuit in multiple with this circuit includes the direct holding coil K^d of the control relay K as follows:

Circuit number three

Local positive wire 275, conductor 276, contact spring 59, contact disk 60, contact spring 59, conductors 277 and 285, armature 286 of the control relay K in its upper position, conductor 287, the direct current holding coil K^d of the control relay K and conductors 288 and 282¹ to the common return wire 283.

Thus, the raising of the foot 43 of the shoe B breaks the circuit through the direct current holding coils S^d and K^d of the car relays, and unless alternating current is simultaneously supplied to the alternating coils S^a and K^a of said relays, the respective armatures of the car relays will drop. This alternating current is supplied to the alternating current coils S^a and K^a of the car relays through the transformer T when the foot 43 of the contact shoe B engages a ramp between which

and the track rail 251 a difference of potential exists. Assuming that the foot 43 of the shoe B is in contact with the ramp R between which and the track rail 251 a low difference of potential exists according to the partial circuit (number one), then alternating current will flow through the primary 291 of the transformer T along the following partial circuit:

10 *Circuit number four*

From the ramp R through the foot 43 to the body or frame of the contact shoe B, conductors 289 and 290, primary 291 of the transformer T, conductor 292 to the frame or axle of the car and to the track rail 251.

15 The frame of the shoe B is also connected by the conductors 289 and 293 to a conductor or bus extending through the entire length of the train, and termed the "pick-up" bus. It is noted here that the primaries of the transformers T on each car are connected across the "pick-up" bus and the frames of the car, and that the frame of each shoe B is also connected to the "pick-up" bus. Consequently, when the foot 43 of any one shoe B on a train of a number of cars is in contact with a ramp between which and a track rail a difference of potential exists, current will flow from the ramp through this shoe and along said "pick-up" bus through the primaries of the transformers T on each of the cars simultaneously.

35 When alternating current flows in the primary 291 of the transformer T on a car, an alternating current is induced in the secondary 294 of that transformer which flows through the alternating current coil S^a of the stop relay S along the circuit traced as follows:

40 *Circuit number five*

From one terminal of the secondary 294 of the transformer T, conductors 295 and 296, the alternating current coil S^a of the stop relay S and conductors 297 and 298 back to the other terminal of the secondary 294.

45 The alternating current in the secondary 294 of the transformer T also flows through the alternating current coil K^a of the control relay K along the circuit traced as follows:

50 *Circuit number six*

55 One terminal of the secondary 294, conductors 295 and 299, the alternating current coil K^a of the control relay K, conductors 300 and 301, impedance 302, conductors 303, 304 and 298, back to the other terminal of the secondary 294.

60 A shunt for the impedance 302 is established when the control relay K is energized for the reason pointed out at length in the application Serial No. 8,246 hereinafter mentioned, according to the following circuit:

Circuit number seven

Conductor 305, armature 306 in its upper position and conductor 307.

In the particular instance assumed, the ramp R is connected to the low voltage tap 266¹ of the track transformer 258¹, and since this low voltage is not sufficient to hold up the armatures of the control relay K, even with the impedance 302 shunted, and since the direct current holding circuits (numbers 70 two and three) are broken at the contact springs 59 of the shoe B, said armatures of the control relay K will drop; whereas, since low voltage is sufficient to keep the armatures of the stop relay S up, its armatures will be held in their raised or normal position.

The dropping of the armatures of the control relay K produces the following results:

(1) When the armature 306 of the control relay K drops, the shunt circuit (number 75 seven) around the impedance 302 hereinbefore set forth, is broken, so that said impedance is in series with the alternating current coil K^a of the control relay K. When the impedance 302 is in series with the alternating current coil K^a of the control relay K, a high difference of potential across the primary 80 of the transformer T is necessary to pick up the armatures of said control relay; and hence if the foot 43 of a shoe B engages a ramp between which and the track rail 251 only a medium difference of potential exists, the armatures of said control relay will not be picked up. The object of this arrangement 85 will appear as the description of the operation progresses and is fully explained in the application Serial No. 6,248 hereinbefore mentioned.

(2) When the armature 286 of the control relay K drops, the circuit (number three) 90 through the direct current coil K^d of the control relay K is broken. Consequently, when the shoe B leaves the ramp R and electrical contact is re-established between the contact disk 60 and the contact springs 59, one break 95 in the direct current holding circuit (number three) hereinbefore described, is closed but another break exists at the armature 286 of the control relay K so that current will not flow through the direct current coil K^d of said 100 control relay, and the armatures of the control relay will remain in their lower position. In other words, the armatures of the control relay, when once dropped, will not be raised again until the shoe touches another 105 ramp between which and a track rail a high difference of potential exists.

(3) When the armature 309 of the control relay K drops, the connection between the local positive wire 275 and the selector circuit controllers S¹ and S², by which current 110 is supplied to said selector circuit controllers is interrupted, and simultaneously a shunt 115 stick circuit for the particular block combination for which the selector is set, will be 120 125 130

established. The purpose of this operation will be pointed out after the circuits and the operation of the block combinations have been set forth. When the selector circuit controllers S^1 and S^2 are moved to a position to make the selection of a particular block combination, a path for electrical current is set up through said selector circuit controllers to the electromagnet 198 of the particular block combination selected. In Fig. 21 the selector circuit controllers S^1 and S^2 are shown diagrammatically and are illustrated in the position to select a block combination indicated in said figure by b .

Assume that the selector circuit controllers S^1 and S^2 occupy this position shown, then before the armatures of the control relay K dropped, current was supplied to the electromagnet 198 of the block combination b along the following circuit:

Circuit number eight

Local positive wire 275, conductor 308, armature 309 of the control relay K in its upper position, conductor 310, 311 and 312, lower contact bar 313 of the selector circuit controller S^1 which bridges the lower contacts of the lower group of three contacts of said circuit controller, conductor 314, lower contact bar 315 and lower pair of contacts of the lower group of three contacts of the circuit controller S^2 , conductors 316, 317, 318 and 319, electromagnet 198 of the block combination b , and conductor 320 to common return wire 283.

The electromagnet 198 of the block combination b being energized by this circuit, its armature 199 is actuated to rock the contact holder 207. The pair of contact springs 221 are closed, (see Fig. 16), since the insulating roller 223 carried by the arm 205 of the bracket holds one contact spring of this pair while the other is moved. When the armature 309 of the control relay K drops, this pair of contact springs 221 closes the following stick circuit for the electromagnet 198 of the block combination b under consideration as follows:

Circuit number nine

Local positive wire 275, conductor 308, armature 309 of the control relay K in its lower position, conductors 321, 322 and 323, the pair of contact springs 221, conductors 324 and 319, electromagnet 198, and conductor 320 to common return wire 283.

It will be noted that the last mentioned circuit (number nine) is only established when the armature 309 of the control relay K is dropped. Under normal conditions the electromagnet 198 of the block combination for which the selector circuit controllers S^1 and S^2 are set up, in this instance block combination b , is energized by the circuit (number eight) hereinbefore set forth; but when

the control relay K is deenergized, the armature 309 controlled thereby drops, thereby breaking this circuit (number eight) through the selector circuit controllers, and simultaneously establishing the stick circuit (number nine) hereinbefore set forth, for the electromagnet 198 of the particular block combination selected. From this it can be seen that when the control relay K is deenergized it closes the stick circuit for the particular block combination selected by the selector circuit controllers S^1 and S^2 at the time and also shuts off the supply of current to said selector circuit controllers so that said selector circuit controllers may be actuated to other positions without affecting the electromagnets of any of the other block combinations, or deenergizing the electromagnet 198 of the block combination selected. In this way, as a train passes through a block under the control of a particular block combination, the selector circuit controllers S^1 and S^2 may be actuated to set up another block combination for the succeeding block without affecting the particular block combination under which the train is being controlled at the time. In other words, the circuits are arranged so that the electromagnets 198 of two inconsistent block combinations cannot be energized at the same time.

The selector circuit controllers S^1 and S^2 not only determine which block combination shall be effective but also determine whether the block combination selected shall be used with or without the multiplier combination. This multiplier combination is set into operation by energizing the electromagnet 178 (see Fig. 14); and the effect of the multiplier combination is to change the ratio of the gearing between the shaft 15 connected to the axle of the car and the shaft 146 to which the cams are fixed. This change of ratio is accomplished by energizing the electromagnet 178, the core 180 of which rocks the shaft 121 through the intermediate connections of the link 181 and the horizontally extending arm 176 of the angle lever connected to said shaft. The rocking of the shaft 121 swings the multiplier arm 123 (see Figs. 10, 11 and 15) so as to bring the gear 126 into mesh with the gear 130 and to move the gear 124 out of mesh with the gear 130; and since the gear 124, which is normally in mesh with the gear 130, is smaller than the gear 127, the number of turns of the shaft 15 necessary to produce one turn of the shaft 146 is increased. The effect of this change of the ratio of the gearing is to flatten the speed-distance curve to which the shape of the cams correspond, which will be explained fully hereinafter. The circuit of energizing the electromagnet 178 which moves the multiplier arm 123 into its multiplying position, is as follows:

Circuit number ten

Local positive wire 275, conductor 308, armature 309 of the control relay K in its upper position, conductors 310 and 325, middle contact bar 326 of the selector circuit controller S¹ in its first position corresponding to the first position of the contact bar 313, conductors 327 and 328, electromagnet 178 and conductor 329 to common return 283.

10 This circuit (number ten) is closed when the selector circuit controller S² is in its first or lower position; and in this position of the selector circuit controller S¹, the circuit (number eight) for energizing the electro-
15 magnet 198 of the combination b is also closed.

Although in the first position of the selector circuit controllers S¹ and S², as shown in Fig. 21, the multiplier combination is used in conjunction with the block combination b, 20 it is to be understood that this is not necessarily so, because by a rearrangement of circuits the block combination b may be used alone with the selector circuit controllers S¹ and S² in their first or lower position.

25 By moving the selector circuit controller S¹ to its second position the circuit (number ten) for the multiplier combination magnet 178 is interrupted at the contact bar 326; but another circuit for energizing the block 30 combination b is established as follows:

Circuit number eleven

Local positive wire 275, conductor 308, armature 309 of the control relay K in 35 its upper position, conductors 310, 311 and 330, lower contact bar 313 of the selector circuit controller S¹ in its middle or second position, conductors 331 and 332, middle contact bar 333 of the selector circuit controller 40 S² in its lower or first position, conductors 334, 317, 318 and 319, electromagnet 198 of block combination b and conductor 320 to the common return wire 283.

In this way, the block combination b may 45 be used either with or without the multiplier combination.

The circuit for energizing the electromagnet 198 of the block combination a is established as follows:

Circuit number twelve

Local positive wire 275, conductor 308, armature 309 of the control relay K in its upper position, conductors 310, 311 and 330, 55 lower contact bar 313 of the selector circuit controller S¹ in its middle or second position, conductors 331, 335, middle contact bar 333 of the selector circuit controller S² in its second position, conductors 336, 337 and 338, electromagnet 198 of the block combination 60 a and conductor 339 to the common return wire 283.

In the particular wiring diagram shown in 65 Fig. 21 the block combination a is not used with the multiplier combination, since the

circuit controller S¹ must be in its second position to close the circuit for this block combination a and in this second position the circuit (number ten) for the multiplier combination is broken at the contact bar 326 of the selector circuit controller S¹. It is to 70 be understood, however, that by simple rearrangement of wiring, which will be apparent to one skilled in the art, the block combination a may also be used with the multiplier combination. It will also be apparent to one skilled in the art that, when a number of block combinations are used, suitable wiring and an appropriate number of contacts on the selector circuit controllers may be provided, whereby any desired number of these block combinations may be used either with or without the multiplier combination.

The stick circuit for the block combination a is also controlled by the armature 309 of the control relay K by means of the following 75 circuit:

Circuit number thirteen

Local positive wire 275, conductor 308, armature 309 of the control relay K in its 90 lower position, conductors 321, 322 and 339, contacts 221 of the block combination a, conductors 340 and 338, electromagnet 198 of said block combination a, and conductor 339 to the common return wire 283.

When the electromagnet 178 of the multiplier combination is energized, its core 180 is raised and the vertically extending tilting arm 182 is actuated by the angle lever connected to said core by the link 181 and is rocked to move the contact springs 188 into contact with the contact springs 187¹ to close certain circuits. These circuits controlled by the multiplier combination are: first, a stick circuit for the multiplier electromagnet 178; and second, circuits controlling the block indicators to show whether the block combination selected is being used with or without the multiplier combination. The stick circuit for the multiplier combination is as follows:

Circuit number fourteen

Local positive wire 275, conductor 308, armature 309 of the control relay K in its lower 115 position, conductors 321 and 341 to one contact spring 188, contact spring 187¹, conductors 342 and 328, electromagnet 178 of the multiplier combination, and conductor 329 to the common return wire 283.

This stick circuit (number fourteen) is controlled at two places, one at the multiplier combination by the contact springs 188 and 187¹, and one at the armature 309 of the control relay K. The break at the multiplier 120 combination is closed when the multiplier electromagnet 178 is energized by the circuit (number ten) through the selector circuit controller S¹, as hereinbefore set forth, and the break at the control relay K is closed when 125

said relay is deenergized. Consequently, after the multiplier electromagnet 178 has been energized through the proper circuit (number ten) through the selector circuit controller S^1 , and then the control relay K is deenergized, the stick circuit (number fourteen) for the multiplier electromagnet 178 will be established so as to hold said multiplier combination in its multiplying position until the relay K is again energized, even though the selector circuit controllers S^1 and S^2 should be moved in the meantime.

Block indicators

- 15 As the train enters each block, it is desirable to inform the motorman of the braking conditions existing in that block, so that he may regulate the speed of the train himself and keep the train safely under control without 20 the aid or interference of the automatic speed control apparatus. This is accomplished sufficiently for practicable purposes by indicating in the motorman's cab what block combination has been set up for that block. The 25 block combinations indicators 1^a , 1^b , 1^{bm} may be of suitable construction as for instance, electric lamps having transparent lettered plates in front of them, and are arranged to be operated when electric current is applied 30 to them. Since the block combination b may be used with or without the multiplier combination, it is necessary to provide two block indicators 1^b and 1^{bm} for said block combination, the block indicator 1^{bm} indicating that 35 the block combination b is being used with the multiplier combination, and the block indicator 1^b indicating that said block combination is being used without the multiplier combination.
- 40 The circuit for the block indicator 1^{bm} when the control relay K is energized is as follows:

Circuit number fifteen

Local positive wire 275, conductor 308, armature 309 of the control relay K in its upper position, conductors 310, 311 and 312, lower contact bar 313 of the selector circuit controller S^1 in its first or lower position, conductor 314, lower contact bar 315 of the selector circuit controller S^2 in its first or lower position, conductors 316, 317 and 343, contact springs 188 and 187¹ of the multiplier combination, conductor 344, to the 1^{bm} bus 345, through the 1^{bm} in the compartment from which the motorman is controlling the train, signal common return 346, controller switch U in the compartment where the motorman is, controller switch bus 347, conductors 348, 349 and 350, upper contact bar 351 of the selector circuit controller S^1 in its lower or first position, conductors 352, 353 and 354 to the common return wire 283.

The circuit for the block indicator 1^{bm} when the control relay is deenergized, is as follows:

Circuit number sixteen

Local positive wire 275, conductor 308, armature 309 of the control relay K in its lower position, conductors 321, 322 and 323, contact springs 221, conductors 324, 318, 343, contact spring 188, contact spring 187¹ of the multiplier combination, conductor 344 to the block indicator 1^{bm} bus 345, through the block indicator 1^{bm} in the compartment from which the train is being controlled, signal common return 346, controller switch U, controller switch bus 347, conductors 348, 349 and 350, upper contact bar 351 of the selector circuit controller S^1 in its lower first position, conductors 352, 353 and 354 to common return wire 283.

It is noted here that the circuits for all of the signals in the motorman's compartment, except the no-signal indicator N. S., include the path from the signal common return 346 through the selector circuit controllers S^1 and S^2 to the common return wire 283, as traced in the latter part of the two last-mentioned circuits; and to avoid unnecessary repetition this partial circuit from the signal common return 346 to the common return wire 283 will hereinafter be referred to as partial circuit "signal ground" number seventeen.

The circuit for the block indicator 1^b when the control relay K is energized is as follows:

Circuit number eighteen

Local positive wire 275, conductor 308, armature 309 of the control relay K in its upper position, conductors 310, 311 and 330, lower contact bar 313 of the selector circuit controller S^1 in its middle or second position, conductors 331 and 332, middle contact bar 333 of the selector circuit controller S^2 in its lower or first position, conductors 334, 317 and 343, contact springs 188 and 187², since the electromagnet 178 of the multiplier combination is deenergized, conductor 355 to the 1^b bus 356 and thence along the partial circuit signal ground number seventeen.

The circuit for the block indicator 1^b when the control relay K is deenergized as follows:

Circuit number nineteen

Local positive wire 275, conductor 308, armature 309 of the control relay K in its lower position, then as in circuit number sixteen to the contact spring 188 of the multiplier combination which is in contact with the contact spring 187², since the electromagnet 178 of said multiplier combination is deenergized, conductor 355 to the bus 356 for the block indicator 1^b and then from signal common return 346 along the partial circuit signal ground number seventeen.

The circuit for the block indicator 1^a when the control relay K is energized is as follows:

Circuit number twenty

Local positive wire 275, conductor 308,

5 armature 309 of the control relay K in its upper position, conductors 310, 311 and 330, lower contact bar 313 of the selector circuit controller S¹ in its middle or second position, conductors 331 and 335, middle contact bar 333 of the selector circuit controller S² in its middle or second position, conductors 336 and 500 to 1^a bus 501, through 1^a indicator to signal common return 346 and 10 thence as in partial circuit signal ground number seventeen.

The circuit for the block indicator 1^a when the high voltage car relay is deenergized is as follows:

15 *Circuit number twenty-one*

Local positive wire 275, conductor 308, armature 309 of the control relay K in its lower position, conductors 321, 322 and 339, contact springs 221 of the block combination 20 a, conductors 340, 337 and 500 to the 1^a bus 501, through the 1^a at the end of the car where the motorman is and from the signal common return 346 to the common return 25 wire 283 as in the partial circuit signal ground number seventeen.

There are several possible paths for the current to flow from the conductor 348 through the selector circuit controllers to the common return wire 283 along the partial circuit signal ground, these different paths being arranged so that as said circuit controllers are moved alternately one at least of these paths is complete, thereby retaining a continuous conducting path from the conductor 348 to the common return wire 283 while combinations are being changed, so that while block combinations are being changed, the audible signal, the green lamp and the yellow lamp may still be operated. While the selector circuit controller S² is being moved the current has a continuous path from the conductor 348 to the common return wire 283, either along conductor 357, contact bar 359 in its lower position, conductors 361, 362, 353, and 354 to the common return wire 283; or along conductor 358, contact bar 359 in its middle position, conductors 360, 362, 353 and 354 to the common return wire 383. 40 While the selector circuit controller S² is being moved, the current has a continuous path from the conductor 348 to the common return wire 283 either along conductors 349 and 350, contact bar 351 in its first position, conductors 352, 353 and 354 to the common return wire 283; or along conductors 349 and 363, contact bar 351 in its second position, conductors 364 and 354 to the common return wire 283. It will be apparent to one skilled in the art that this particular arrangement of circuits shown is not compulsory, since make before break contacts may be used on the selector circuit controllers or some other means may be employed 50 whereby the partial circuit signal ground

number seventeen will not be interrupted unless the selector circuit controllers S¹ and S² are operated to some one certain position.

70 (4) When the armatures of the control relay K drop, the proceed signal displayed in the cab or motorman's compartment, which in the particular construction shown is a green lamp G, is extinguished so that the motorman is advised that he may no longer proceed at unrestricted speed. This is accomplished by the dropping of the armature 364 of the control relay K which interrupts the following circuit to the green lamp G:

75 *Circuit number twenty-two*

Local positive wire 275, conductor 365, armature 364, of the control relay K in its upper position, conductors 366 and 367, signal bus 368 for the green lamp G, signal common return 346, and controller switch U, controller switch bus 347, conductors 348 and 349, and thence as in partial circuit signal ground number seventeen to common return wire 283.

80 (5) At the same time that the green lamp G is extinguished the armature 600 of the control relay K drops and the caution signal, in this instance, a yellow lamp Y is lit by the following circuit:

85 *Circuit number twenty-three*

Local positive wire 275, conductor 276, contact spring 59 of the shoe B, contact disk 60 of said shoe, other contact spring 59 of 90 said shoe, conductors 277 and 601, armature 600 of the control relay K in its lower position, conductor 369, signal bus 370 for the yellow lamp Y, signal common return 346, controller switch U, and thence as in the 95 partial circuit signal ground number seventeen. The reason for controlling the circuit for the yellow lamp Y by the shoe B will be explained hereinafter.

100 (6) The armature 364 of the control relay K in dropping interrupts the following normally closed circuit through the electromagnet 150 governing the meshing of gears 145 and 148, hereinafter termed the cam starter electromagnet:

105 *Circuit number twenty-four*

Local positive wire 275, conductor 365, armature 364 of the control relay K in its upper position, conductors 366 and 371, the 110 cam starter electromagnet 150 and conductor 372 to the common return wire 283.

115 When the electromagnet 150 is deenergized the spring 155 (Figs. 10 and 11) presses the plunger 154 upwardly and rocks the arm 141, 120 the sleeve 139 and the cam starter arm 140, thereby moving the gears 145 and 144 carried by said cam starter arm 140 into position, as shown in Fig. 18, where the gear 145 meshes with the cam-gear 148.

Automatic operation

The operation of the speed controlling apparatus so far considered advises the motorman of the train by the extinguishment of the green light and the lighting of the yellow light that he must proceed at restricted speed into the block into which the train has just entered, and that he must take such measures as will bring the train to a stop before the entrance to the next block is reached, or in other words, before the end of the particular block through which the train is passing. As pointed out in the preliminary discussion, certain factors, the most important of which is the speed of the train, determine at what distance from the end of a block the brakes should be applied to bring the train to a stop before it reaches the end of that block. Since the block indicator for the block through which the train is passing has been operated, as explained hereinbefore, the motorman is advised of the conditions ahead of the train which require an earlier or a later manual application of the brakes necessary to bring the train to a stop at the end of the block; and judging from the information furnished by this block indicator and the speed of the train, the motorman may regulate the speed of the train so that, while no unnecessary delay is made, nevertheless the train will be brought to a stop by the time it reaches the end of the block. However, the motorman may not be able to use the nicety of judgment required to regulate the speed of the train so as to satisfy the special requirements of the block through which the train is passing; and he may either reduce the speed of the train more than is necessary, or fail to reduce the speed enough to be able to stop before the end of the block is reached. In the first case, unnecessary delay is caused, and in the second case, dangerous conditions will result. Consequently, in order to obtain maximum capacity, that is, facilitates to the greatest extent the movement of the trains, and also to bring the train to a stop automatically at the end of the block in spite of poor judgment or neglect of the motorman, the apparatus hereinbefore described is used.

The principles of the action of the automatic devices may be easier understood in connection with the diagram shown in Fig. 26 which illustrates graphically certain factors on which the control of the train depends, these factors being determined on the basis of certain assumed conditions and being illustrated according to the well-known method of plotting curves. In this Fig. 26, the horizontal distances represents different distances in the travel of the train, and vertical distances represent the different speeds at which the train may travel. This diagram illustrates the factors for a block X in which certain conditions affecting the braking dis-

tance of the train are assumed to exist. The insulating joint 252 which determines the physical beginning of the block, is shown at the lefthand part of Fig. 26, and a ramp R for the particular block X is shown as extending some distance beyond this insulated joint 252 in the direction in which the train travels, said direction of travel being indicated by an arrow in said figure designated as "direction of traffic." The beginning of the theoretical or imaginary block is indicated by the line $c-d$, and represents the point in the travel of the train at which the armatures of the control relay K are dropped, and the cam shaft 146 set in motion, assuming that traffic conditions are such that the train be brought to a stop at the end of the block X. It is noted that this line $c-d$ showing the beginning of the imaginary or theoretical block is at some distance from the insulating joint 252; and in practice, with the particular arrangement of circuits and controlling devices along the trackway shown in Fig. 22 and described herein, it will be found that this distance will vary slightly, for the reason that, as will appear from a consideration of the operation of de-energizing the control relay K set forth hereinbefore, the control relay K is deenergized a certain time after the first wheels of the train have passed over the insulating joint 252 into the block X, this time being that required for the track relay of the block X and the control relay K to become deenergized; and the distance traveled by the train during this time will vary according to the speed of the train. It is noted here also that the selector ramps 93 can not be located farther in advance of the ends of a block than the beginning of the imaginary block represented by the line $c-d$, since the armatures of the control relay, if they are to drop, will drop at this point; and, as explained hereinbefore, the dropping of the armature of the control relay sticks up the block combination selected at that time and renders any subsequent movement of the selector circuit controllers ineffective to change the block combination stuck up. The length of the imaginary block is represented by the distance between the line $c-d$ and the line $e-f$, this distance being arbitrarily chosen for illustrative purposes as representative of certain conditions; and it is to be understood that the lengths of the blocks will vary at different points along the trackway according as the conditions affecting the braking distance of the train vary, and according as crossings, stations and other things requiring certain stops or limited speeds occur.

The control of a train in the block X is determined with reference to a certain point near the end of the block designated g and located a certain distance from the end of the block, this distance being any desired

amount and being used as a margin of safety. In other words, the speed control apparatus, when set into operation, is designed with a view of automatically bringing the train to a stop at or before it reaches the point g . The 5 curve designated in Fig. 26 as the "emergency braking" curve is a speed-distance curve described by the first car of the train under an emergency application of the brakes when the first car of the train is stopped at the 10 point g . This emergency braking curve is a graphical representation of the rate at which the speed of the train is reduced when the emergency brakes are exerting their full 15 braking effect and indicates graphically for each speed of the train a point in its travel where the emergency brakes should acquire their full braking effect in order to bring the train to a stop at the point g . The data for 20 this curve can be determined with practicable accuracy by experiment and calculation, which will be understood by those skilled in the art of braking trains. In the present discussion it is assumed that this emergency 25 braking curve represents the speed-distance curve of the train after the emergency brakes have attained their full braking effect; and it is also to be understood that this emergency braking curve is not of universal application, but is based on certain special conditions, such as a particular kind of braking equipment, grade of the track, and the like; nor is it intended that this curve should be 30 quantitatively precise, since this curve, as 35 well as the other curves hereinafter described, are shown merely for the purposes of illustration. In the same way the curve designated "service braking" is a speed-distance curve described by the first car of the train 40 under a service application of the brakes when the train is to be stopped at the point g .

The curve designated "service cam" in Fig. 26 shows the speed at each point in the travel of the train at which the service application 45 of the brakes should be started. For example, suppose a train enters the block X at a speed of about 28 miles per hour as represented by the dot and dash line m , and continues at this speed until it reaches a point p 50 where the line m intersects the service cam curve. If at this point p the service brakes are automatically applied, the train will proceed at a speed gradually decreasing, as indicated by the dotted line between the points 55 p and r in Fig. 26, until it reaches the point r where the line $p-r$ merges with the service braking curve, at which point r the brakes have attained their full braking effect. After 60 the brakes have attained their full braking effect the train will have its speed reduced in accordance with the service braking curve so as to be brought to a stop at the point g . The distance at each speed between the cam curve and the service braking curve, which at the 65 speed in the instance assumed is the distance

between the points p and r , is the distance which the train will travel during the time necessary for the brakes to attain their full braking effect. This time is dependent upon the kind of braking equipment and must be determined for each particular kind of braking equipment; but for practicable purposes this time for the same kind of braking equipment may be assumed to be substantially constant at different speeds. However, the speed of the train makes a difference in how far the train will travel in a certain time, and for this reason at high speeds the service cam curve is farther in advance, as regards distance, than at low speeds.

In the same way the curve marked "emergency cam" shows the speed at each point in the travel of the train at which the emergency application of the brakes should be started. In the particular equipment for which the curves in Fig. 26 are supposed to be illustrative, the time required for the brakes in an emergency application to attain their full braking effect is assumed to be less than the time required for the brakes under a service application; and consequently, the emergency cam curve is not shown so far in advance of the emergency braking curve, as regards time, as the service cam curve is in advance of the service braking curve.

From a consideration of these curves shown in Fig. 26 it can be seen that if the actual speed of the train and its distance from the beginning of the block are known at each instant as it travels along the block, it is possible to determine from the service braking curve and the emergency braking curve the point in the travel of the train at which the brakes, either the service or the emergency brakes, should attain their full braking effect in order to bring the train to a stop at the point g . The distance traveled by the train is ascertained by the number of revolutions of its wheels which are connected to the cam shaft 146 by the gearing hereinbefore described, so that, as the train moves, said cam shaft and the cams secured thereto are gradually turned, the amount of angular movement of said cams being directly proportional to the distance traveled by the train. In this way, the angular displacement of the cams from their normal or initial positions, as shown in Fig. 13, corresponds quantitatively with the distance traveled by the vehicle.

From a consideration of the braking curves 120 it is also possible to determine the safe or permissive speed for the train at each point in its travel, this permissive speed for service braking being represented generally in Fig. 26 for each distance traveled by the vehicle 125 by the vertical distances from the horizontal reference line to the point in the service cam curve vertically above the point in said reference line which corresponds to said distance traveled, as will be readily understood by 130

those skilled in the art. By the term permissive speed is meant that there is a speed for each point in the travel of the train at which the train may be moving at that point, and yet may be brought to a stop at or before the point g in the block is reached, provided immediate application of the brakes is made. According to the particular embodiment of the invention shown and described the speed control apparatus is arranged to give an automatic service application of the brakes, and also an automatic emergency application of the brakes, so that with this particular apparatus, strictly speaking, there are two permissive speeds for each point in the travel of the train, one of the permissive speeds being determined with reference to the rate at which the speed of the train can be reduced when a service application of the brakes is made, and the other permissive speed when an emergency application of the brakes is made. From the service braking and emergency braking curves shown in Fig. 26 it can be seen that the train can advance farther into the block X before it is necessary to make an emergency application of the brakes than said train can advance before it is necessary to make a service application of the brakes.

The shape of one cam 240 used for the block X for controlling the service application of the brakes in that block, or blocks having the same physical characteristics, is based on the service braking curve of the block X ; and assuming a certain car equipment the radii of this cam 240 represent quantitatively the permissive speeds at the different points in the travel of the train represented by the angular displacement of the respective radii from the radius of the initial or normal position of said cam. In the same way the shape of the cam 241 for controlling the emergency application of the brakes which is used for the block X is based on the emergency braking curve for that block X . It is noted here that the effect of the multiplier hereinbefore described is to flatten the speed-distance curves represented by the cams, this resulting from the fact that the angular movement of the cams is less for each revolution of the car wheels when the multiplier combination is effective than when said multiplier combination is idle.

The curve designated "audible signal" in Fig. 26 shows for each point in the travel of the train the speed of the train at which the warning signal is sounded and at which the motorman should start to shut off the power and to apply the brakes in order to avoid an automatic application of the brakes. After the warning signal has been sounded there should be sufficient time for the motorman to shut off power and cause an application of the brakes and sufficient time for the brakes to attain their full braking effect before the

train, moving at the same speed, has traveled so far into the block that the service cam will operate to cause an automatic application of the brakes. To illustrate, assume that a train enters the block X at a speed represented by the dot and dash line m of about twenty-eight miles per hour, and that the train continues at this speed until it reaches the point n where the line m intersects the audible signal curve. At this point n the audible signal is automatically sounded to advise the motorman to shut off the power and apply the brakes manually without delay, and if the motorman obeys the audible signal the brakes will attain their full braking effect at the point o , and the train will move under this manual application of the brakes along the speed-distance curve represented by the dot and dash line extending downwardly from the point o to the point o' . As has been pointed out hereinbefore, the time required for the brakes to attain their full braking effect may be assumed to be the same for all speeds, and in the same way the time necessary for the motorman to shut off the power and cause an application of the brakes may also be assumed to be the same for all speeds. Consequently, the audible signal should be sounded a fixed time in advance of the service cam, regardless of the speed at which the train is traveling, this fixed time being equal to the time required for the brakes to attain their full braking effect, added to the time necessary for the motorman to shut off the power and cause a manual application of the brakes. This curve for the audible signal, if a constant time in advance of the service cam curve at all speeds, would be different distances in advance of the service cam curve for different speeds, since the distance traveled by a train in a certain time will be different for different speeds. To obtain this constant time interval between the audible signal curve and the service cam curve it would be necessary with the particular embodiment of the speed control apparatus shown and described to use a cam for the audible signal which would be slightly different in shape than the service cam. In the particular apparatus shown and described the audible signal is controlled by the same cam as the service application of the brakes, namely, cam 240, and in this case the audible signal curve will not necessarily be a fixed time in advance of the service cam curve. A careful analysis of the operation of the particular speed control apparatus, particularly the parts thereof shown in Fig. 13, will show that when the audible signal is controlled by the same cam as the service application of the brakes, the curve for this audible signal will be in advance of the service cam curve a distance at each speed which represents a constant decrement of speed represented by the service cam curve which will be explained fully hereinafter. In other

words, the vertical space between the audible signal curve and the service cam curve is the same at each distance so that, for practicable purposes, the curve of the audible signal is substantially parallel to the service cam curve and a certain fixed distance in advance of said service cam curve. This particular arrangement decreases the facility with which the train can be moved since, if the train is moving 5 at a low speed when the audible signal is sounded, the motorman will have more time to shut off the power and apply the brakes than if the train is moving at a high speed; and if the motorman acts as promptly at low 10 speed as he does at high speed he will cause the brakes to be applied a little sooner at lower speed than is absolutely necessary to avoid an automatic service application of the brakes. In other words, he slows down the 15 train before it is necessary and would delay any following train. It will be understood by one skilled in the art that instead of using the same cam for controlling the service application of the brakes and for sounding the 20 audible signal two separate cams having their appropriate contour may be used, with the result that the audible signal will be sounded a certain time in advance of the service application of the brakes at all speeds, in the 25 manner specifically disclosed and claimed in my co-pending application, Ser. No. 107,355, filed July 3, 1916.

While it might be desirable to bring the train to an absolute stop at the point g in the block X, practicable operating is satisfied if the speed of the train is reduced to not more than a certain low speed at the point g , as for instance, five to ten miles an hour. For this reason the emergency cam curve merges into 25 a horizontal line s representing a certain low speed, which is shown as ten miles per hour in Fig. 26; and in a similar way the service cam curve merges into a horizontal line Y representing a certain low speed, which is shown as 40 about 8 miles per hour in Fig. 26. In case the motorman has properly controlled the speed of the train through the block X so that the speed at all times has been below the permissive speed represented by the service cam 45 curve, that is, no automatic service application of the brakes has occurred, the train may pass the point g at a low speed without interference of the automatic speed control apparatus. However, if the speed of the train at 50 any point in its travel should exceed the permissive speed imposed by the service cam curve and an automatic service application of the brakes has resulted, a train equipped with pneumatic brakes of the ordinary construction 55 will probably be brought to a speed less than the low speed as a penalty to the motorman for disregarding the audible signal. The reason for this is that, although (as pointed out hereinafter) the apparatus is so constructed 60 that the controlling device for the

brakes will be automatically moved to its release position at the point where the service braking curve intersects the horizontal part s of the service cam curve with the ordinary pneumatic braking equipment a certain time is required to release the brakes completely 70 after the operation of the release has commenced. In the same way the audible signal curve merges into a horizontal line t which represents a speed lower than the speed represented by the lines s and y in Fig. 26 and is shown as about 7 miles an hour. 75

The dot and dash line u below the horizontal line t represents the probable speed-distance curve of a train which has been properly 80 controlled by the motorman. To illustrate, assume a train enters the block at a speed represented by the line m , the audible signal is sounded at the point n , the motorman obeys the audible signal, the brakes attain their full 85 braking effect at the point o and the speed of the train is reduced in accordance with the curve represented by the dot and dash line $o-o$ until this curve crosses the audible signal curve whereupon the audible signal which 90 has been sounding all of this time stops and the motorman in response thereto releases the brakes. After the brakes have been fully released, the motorman will probably bring his train to a speed a little less than the speed 95 represented by the line t , that is, the motorman will probably drive the train at a speed as high as possible without causing the audible signal to sound, that is, at the speed represented by the line u . 100

The cams are also preferably designed so as to impose a limitation upon the speed at which the train may enter the block X so that the train cannot attain a speed which will place it beyond the control of the cams, and also so that provision is made for controlling the maximum speed of the train at different points along the track. This limitation upon the maximum speed of the train is obtained by shaping the service cam 240 so that when it 105 is stationary it will require the actual speed of the train when it enters the block X to be less than a certain predetermined maximum speed, which is represented in Fig. 26 by the line w , which is about 45 miles an hour. The 110 emergency cam 241 is also shaped so as to impose a limitation upon the maximum speed, but the speed required by said emergency cam is higher than that required by the service cam, being shown in Fig. 26 by the line v , 115 designating about 48 miles an hour. 120

Having set forth these general considerations a more specific explanation will be given to make it clear how the parts of the speed control apparatus shown and described accomplish these results. 125

Referring to Fig. 13, the cam 240 is shown in its normal position of zero distance traveled by the train, and the speed arm 242 in its position of zero speed. As each cam 130

240 is turned gradually in accordance with the travel of the vehicle, the roller 245 on the upper end of the floating lever 244 associated with that cam will move outwardly 5 relatively to the axis of the cam shaft 146 according to the distance the train had advanced into the block. The actual speed of the train at each point in its travel is determined by the speed indicator SI, which causes each of the speed arms 242 to assume 10 different positions in accordance with the actual speed of the vehicle. Consequently, the lower end of each floating lever 244 takes different positions according to the actual 15 speed of the vehicle. By reason of this arrangement one end of each floating lever 244, namely, the end opposite to the cams 240, takes different positions in accordance with the permissive speed of the train for service 20 braking; and the other end of said floating lever takes different positions in accordance with the actual speed of the train. The speed arm 242 is moved in the direction indicated by the arrow Z in Fig. 13, as the speed 25 of the vehicle increases. It can be seen that as the cam 240 is rotated the upper end of the floating lever 244, which carries the flanged roller 245, is moved toward the left; and also that as the speed of the vehicle is greater the 30 lower end of the floating lever 244 is moved by the speed arm 242 to positions more and more to the left. Consequently, as the cam 240 moves the upper end of the floating lever 244 to the left, the lower end of the speed 35 arm 242 must move correspondingly to the right, that is, the speed of the vehicle must correspondingly decrease, in order to prevent the link 246 attached to the middle of said floating lever from being moved longitudinally to the left.

40 If the speed of the vehicle has not been properly controlled by the motorman the outermost edge portion of the contact closing sector 231 will be brought opposite to the roller 219 by the movement of link 246 due to combined action of the cam 240 and the speed arm 242, and said roller and the outer contact spring 213 will be forced over into contact with the other contact spring 213. 45 During this movement, the outer contact spring 213 rocks on the pin 216 as a fulcrum, and compresses the spring 218, the opening at the bottom of said contact spring, which is larger than the head of the bolt 208, permitting this movement. When the pair of contact springs 213 are brought into contact 50 the circuit through the warning signal is established as follows, assuming that the block combination *b* is set up, as shown in Fig. 21:

Circuit number twenty-five

Local positive wire 275, conductors 373 and 374, contact springs 213, conductors 375 and 65 376, the audible bus running through the en-

tire length of the train, and then in the car from which the train is being directed, along conductor 377, to the audible signal A at the end of the car where the motorman is, through the signal common return 346, at 70 that end of the car, and through the controller switch U and from controller switch bus 347 to the common return 283 as in the partial circuit signal ground number seven- 75 teen hereinbefore set forth.

In case the block combination *a* is selected the circuit for the warning signal A is as follows:

Circuit number twenty-six

Local positive wire 275, conductors 379 and 380, contact springs 213 of the block combination *a*, conductors 381 and 376 to the audible bus, and then as in circuit number twenty-five through the audible signal A.

This warning signal A is preferably an audible signal, a bell, a whistle or the like, which is believed to be more likely than a light or a movable signal to attract the attention of the motorman who may be watching 90 the track ahead.

Assuming that the motorman obeys the warning signal and makes proper service application of the brakes, which is sufficient to bring the speed of the vehicle below the speed 95 required by the audible and service cam 240, the spring 230 (Fig. 13) will pull the link 246 back, providing the position of the middle of the floating lever 244 due to the combined positions assumed by the cam 240 and the speed arm 242, permit such movement, so as to bring the outermost edge of the contact closing sector 231 out of engagement with the roller 219, whereupon the pair of contact springs 213 separate by reason of 100 their inherent resiliency and open the circuit number twenty-five or twenty-six, as the case 105 may be, which circuits cause the sounding of the warning signal A. In this way, the motorman is advised that he has been successful in retarding the speed of his train to the required restricted speed. In case the speed 110 of the train, however, should again exceed the required restricted speed, the audible signal A will again be sounded in the same way as hereinbefore described. In this way, the speed control apparatus provides a warning 115 signal which will be sounded at any time during the travel of the train through a block whenever the permissive speed for a service 120 application of the brakes is nearly reached, and which will persist until obeyed.

With this understanding of the arrangement and operation of the parts of the block combinations, the statement made hereinbefore regarding the quantitative relation of the advance of the audible signal curve from the service cam curve may be more easily understood. Referring to Fig. 13, it can be seen that when the shoulder of the contact closing 130

sector 231 has been moved to a position opposite to the roller 219 so as to press the contact springs 213 together, the audible signal is sounded; and further movement of the contact closing sector 231 will bring the shoulder of the contact closing sector 232 opposite to the roller 219, so as to shift the two contact springs 213 and to press the two contact springs 214 together to cause a service application of the brakes. The movement of the contact closing sectors 231 and 232 is controlled by the link 246, and the above mentioned further movement necessary to cause a service application of the brakes after the audible signal has been sounded, is produced by a proportional movement of the link 246 longitudinally, which movement is the same as that of the middle of the floating link 244. The displacement of the middle of the floating lever 244 results from the combined movements of the two ends of this lever, the cam 240 controlling the movement of one end and the speed arm 242 controlling the movement of the other end. At the time the audible signal is sounded the middle of the floating lever 244 occupies a certain position, which is the same to sound the audible signal for all speeds of the train; and a service application of the brakes results when this middle point of the floating lever 244 has moved a certain distance from this certain position. Assume that the combined movements of the speed arm 242 and the cam 240 have moved the middle point of the floating lever 244 to the position in which the audible signal is sounded; and further assume that the speed of the train remains constant and the speed arm 242 remains stationary, then the above mentioned certain distance which the middle point of the floating lever 244 has to move in order to cause a service application of the brakes will be produced by the movement of the upper end of said floating lever which is controlled by the cam. This movement of the upper end of the floating lever is due to a certain increase in the radii of the cam as it is turned in accordance with the travel of the train. The amount of this increase in the radii of the cam which is necessary to cause a service application of the brakes after the audible signal has first sounded, is the same regardless of the position of the speed arm, that is, it is the same for all speeds of the train, since the movement to be obtained at the middle of the floating lever is constant, the length of the floating lever remains the same and for each speed its lower end is assumed to be fixed and acting merely as a fulcrum. As explained hereinbefore, the cam 240 is designed in accordance with the curve of service braking, and the rate of increase in the radii of the cam varies according to the rate of decrease in speed represented by the service cam curve; and in the service cam curve shown in Fig. 26 the rate of decrease of

speed is not the same for all speeds, but is smaller at high speeds than at low speeds. In other words, at high speeds in order to attain a certain increase in the radii of the cam it is necessary to turn the cam further, that is, the train must move a greater distance, than at a low speed. For this reason the audible signal curve shown in Fig. 26, because it is obtained from the same cam which is used for the service cam curve, is in advance of the service cam curve different distances at different speeds; but this variation in the distances is not so great that there will not be sufficient time at all speeds for the motorman to shut off the power, apply the brakes and for the brakes to attain their full braking effect before the service cam curve is reached.

Automatic application of the service brakes

Assume that the motorman does not obey the warning signal because of negligence, incapacity or for some other reason, and the speed of the train either increases or continues at its former speed; then the outermost edge of the contact closing sector 232 (Fig. 13) will be moved opposite to the roller 219 and the two contact springs 213 will be shifted together still farther until the block 215 of insulating material presses the pair of contact springs 214 together, thereby closing a circuit for automatically applying the service brakes as follows, assuming that the block combination *b* is set up, as shown in Fig. 21:

Circuit number twenty-seven

Local positive wire 275, conductors 373 and 382, contact springs 214, conductors 383 and 384 to the service bus running the entire length of the train and on each car from said service bus by a conductor 385 to a suitable electrically operated valve designated generally as SB, conductor 386, to the controller switch common return 347 and thence along conductor 348 through the selector circuit controllers, *S*¹ and *S*² as in the partial circuit signal ground number seventeen to the common return wire 283.

This circuit (number twenty-seven) energizes the electro-pneumatic valve SB, which may be of any suitable construction capable of opening a restricted passageway from the train pipe 28 to the atmosphere; and when energized the valve SB moves a contact bar 390 connected thereto downwardly to close a normally open circuit through the device P for shutting off the power, which circuit is as follows:

Circuit number twenty-eight

Local positive wire 275, conductors 388 and 389, the contact bar 390 controlled by the valve SB in its lower position, conductors 391 and 392 to a power control bus running

the length of the train and from this bus on each car by a conductor 393 to the device P, and conductor 394 to the common return 283.

5 When this circuit (number twenty-eight) is established by the energizing of the valve SB, the device P is operated to simultaneously shut off on each car the power used for propelling that car.

10 In case the train is being controlled by the block combination *a* the circuit for causing an automatic service application of the brakes is as follows:

Circuit number twenty-nine

15 Local positive wire 275, conductors 379 and 394, contact springs 214, conductors 395 and 384 to the service bus and then as in circuit number twenty-seven through the valve SB.

20 In this way when the valve SB is energized, the air train pipe 28, which is used in the well-known pneumatic brake system, will be vented on each car, sufficient to give a service application of the brakes; and by reason of the fact that the train pipe is vented on each car the motorman will be unable to recharge the train line fast enough to release the service application, until the electro-pneumatic valves SB controlled by the service bus are deenergized and returned to their normal closed position. This deenergizing and closing of the electro-pneumatic valves SB will occur after the speed of the vehicle 25 has been reduced below the speed imposed by the cam 240, whereupon the contact closing sector 232 will be moved to a position to permit the pair of contact springs 213 to relax their pressure against the contact springs 214, thereby permitting said latter pair of contact springs 214 to separate and open the circuits numbers twenty-seven or twenty-nine, as the case may be.

Automatic emergency application of the brakes

45 An additional safeguard may be provided by arranging the speed control apparatus so as to give an automatic emergency application of the brakes in case the service application of the brakes should fail or be inadequate and the train has traveled so far from the point where the speed control was set into operation and is proceeding at such a speed as to make it necessary to apply the emergency brakes in order to stop the train in time. This automatic application of the emergency brakes is controlled by contact closing sector 233 (see Fig. 16) and the corresponding cam 241 therefor, said cam having a different shape than the cam 240 which controls the warning signal and the automatic service application of the brakes so as to correspond with the emergency braking curve, 50 such as shown in Fig. 26. The emergency

application of the brakes is accomplished by quickly venting the train line by opening an electro-pneumatic valve designated generally in Fig. 2 as EB. This electro-pneumatic valve EB is arranged so that it will be closed when energized, but when deenergized a spring or other suitable device will cause it to open.

55 The electrically operated valves EB may be of any design suitable to accomplish its purpose, and in Figs. 24 and 25 is illustrated one form of construction. This valve comprises a lower casing or body portion 396 in which is fixed a coil or solenoid 397 having a movable core 398. To the lower part of the lower casing 396 is secured a valve casing 399, shown enlarged in Fig. 24 and comprising a chamber 400 communicating with the train pipe 28 of the pneumatic braking system. The chamber 400 communicates by a passageway 401 with a valve chamber 402 in which is mounted a cylindrical piston valve 403. The lower portion of the valve 403 is smaller in diameter than the body portion of said valve, and said lower portion cooperates with a valve seat formed by the upper edge of the passageway 401. Surrounding the valve chamber 402 is an annular recess 404 which communicates with said valve chamber by a passageway 405 and with the atmosphere through a hole 406. Fixed to the core 398 of the solenoid 397 is a pin 407 which is adapted to press against the upper face of the valve 403.

60 An upper casing 408 is secured to the lower casing 396, and fastened to the wall of said upper casing and insulated therefrom are two pairs of contacts 409 and 409', only one contact of each pair being shown in Fig. 25. A rod 410 is secured to the upper end of the core 398, and slidably mounted on this rod are two collars 411 of insulating material having contact bars 412 fixed therein. Encircling the rod 410 and interposed between the collars 411 is a compression coil spring 413 and between the lower collar 411 and the upper face of the core 398 is a similar spring 414. The contact bars 412 are arranged below the respective pair of contacts which they control, so that said contacts are electrically connected when the core 398 is in its upper position.

65 The operation of the electrically operated valve shown in Figs. 24 and 25 is as follows: When the solenoid 397 is energized the pin 407 holds the valve 403 on its seat, but when said solenoid is deenergized the pressure of the air in the chamber 400 communicating with the train pipe against the lower portion of said valve 403, pushes said valve and the core 398 upwardly. In the upper position of the valve 403 air may escape from the train pipe through the passages 401, 405, the annular recess 404, and through the hole 406 to the atmosphere. When the valve 403 is in

its upper position the area subject to the air pressure in the chamber 400 is that equivalent to the area of a circle having the same diameter as the body portion of said valve; whereas when said valve is in its lower position the area subject to the air pressure is smaller, being equivalent to the area of a circle having the same diameter as the lower portion of said valve. The solenoid 397 is designed so that it will exert sufficient tractive force, when energized, to hold the valve 403 on its seat against normal pressure in the train pipe pressing against the lower portion of said valve; but when the valve 403 is unseated the tractive force of the solenoid is insufficient to push the valve downwardly against normal pressure in the train pipe and the solenoid will not be able to reseat the valve until the pressure in the train pipe has been reduced to a predetermined amount. In this way, when the solenoid 397 is once de-energized and the valve 403 opened, there will necessarily be a reduction in the train pipe pressure sufficient to cause an emergency application of the brakes, even if the solenoid 397 is immediately reenergized.

There are two controlling circuits for this emergency valve EB, one including an armature 416 of the control relay K and broken when said relay K is deenergized; and the other circuit including an armature 417 of the stop relay S which is in series with the emergency contact springs 220 of the different block combinations, this second circuit being broken when the stop relay S is de-energized, or when the electrical contact between the emergency contact springs 220 of the particular block combination under which the train is running, is interrupted. These two above-mentioned circuits are arranged in parallel so that when either one of them is complete the emergency valve EB will be energized. This first circuit controlled by the armature 416 of the control relay K is as follows:

Circuit number thirty

Local positive wire 275, conductor 418, armature 416 of the control relay K in its upper position, conductors 419, 420 and 421, emergency valve EB, conductor 422 to the common return wire 283. The second circuit which is controlled either by the armature 417 of the stop relay S or the emergency contact springs 220 of the block combination b, is as follows:

Circuit number thirty-one

Local positive bus 275, conductor 424, contact springs 220 of the block combination b, conductors 425 and 426, armature 417 of the stop relay S in its upper position, conductors 427, 420 and 421, emergency valve EB and conductor 422 to common return wire 283.

As shown in Fig. 16, the outermost portion

of the contact closing sector 233 for normal speeds and for the normal stationary position of the cam 241, is disposed opposite to the roller 224, so that when the contact holder 207 is rocked by energizing the electromagnet 198 as hereinbefore pointed out, the contact springs 220 will be pressed together. When the control relay K is deenergized and its armature 416 dropped, the first circuit (number thirty) is interrupted; but the second circuit (number thirty-one) is closed since the armature 417 of the stop relay S is in its raised position and the contact springs 220 are pressed together by reason of the fact that the electromagnet 198 is energized. When the speed of the train, combined with the distance it has traveled from the point at which the speed control apparatus was set into operation, is such that the emergency brakes should be applied, the contact closing sector 233 is swung to a position where the outermost portion of said sector clears the roller 224, so that said roller, under the force of the inherent resiliency of the outer contact spring 220, may move outwardly and allow the contact springs 220 to separate. When the contact springs 220 are separated the second circuit (number thirty-one) is interrupted and the emergency valve EB is deenergized, thereby causing an emergency application of the brakes.

When the train is being controlled by the block combination a the operation is the same; and the circuit for normally energizing the valve EB is as follows:

Circuit number thirty-two

Local positive wire 275, conductor 432, contact springs 220 of the block combination a, conductor 433 and then along conductor 426 as in circuit number thirty-one.

When the valve EB is deenergized it closes a circuit for operating the device P for shutting off the power as follows:

Circuit number thirty-three

Local positive wire 275, conductors 388 and 435, contact bar 436 and controlled by the valve EB in its upper position corresponding to the deenergized condition of the solenoid 397 of the valve EB, conductors 437 and 392 to the power control bus, then in each car along conductor 393, device P, and conductor 394 to the common return wire 283.

The emergency cam 241 is preferably designed so that the speed distance curve described by the train will follow closely the emergency braking curve for the train; and in such case, after the contact springs 220 have been separated, they will remain so until the speed of the train is reduced to a predetermined low speed, whereupon the contact springs 220 are pressed together to re-establish circuit number thirty-one through the electrically operated valve EB and the motor-

man may re-charge the train pipe and release the brakes. With the assumed braking equipment the time required to recharge the train pipe after an emergency application of the brakes would be so long that the train would be brought to a stop in any event and regardless of the motorman's attempts to release the brakes; but after the brakes have been fully released the train may proceed at 10 the low speed.

Absolute stop

Under some conditions it may be necessary or desirable to bring the train to a complete stop before reenergizing the electrically operated valve EB and permitting the brakes to be released, as for example, at a signal for an interlocking plant where even if the train proceeded at a low speed, it might come into the path of a fast moving train and serious 15 damage result. To bring the train to a stop the stop relay S is deenergized by destroying all difference of potential between a ramp and a track rail. A simple means for doing this for the ramp R² is shown in Fig. 22 as a 20 switch 438 which may be operated manually, by the movement of an interlocked signal located adjacent to said ramp, or in some other way. By opening the switch 438 the partial circuit leading to the ramp R² along the 25 wire 439 is interrupted and no difference of potential will exist between this ramp and the track rails. When a train passes the ramp R² and the switch 438 is open, the first shoe of 30 the train will be raised and the direct current holding circuits (numbers two and three) for 35 both the stop relay S and the control relay K will be broken, as hereinbefore described; and since there is no difference of potential between the ramp R² and the track rail 251, the 40 armatures of both car relays will drop. The dropping of the armature 416 of the control relay K interrupts one of the circuits (number thirty) through the emergency valve EB, and the dropping of the armature 417 of the 45 stop relay S interrupts the other circuit (number thirty-one) through the emergency valve EB, so that said valve EB is deprived of current and an emergency application of the brakes will result. As explained hereinbefore, when the armatures of the car relays are once dropped they will remain in their 50 dropped position even after the foot 43 of the shoe of the car has left engagement with the ramp; and consequently, until one or the 55 other of the car relays are reenergized the valve EB will not be automatically energized to permit the brakes to be released. In this way the train will be brought to an absolute 60 stop regardless of the position of the emergency cams 241.

Various arrangements may be made whereby the stop relay S, may be reenergized; and one arrangement of circuits whereby this 65 result may be accomplished is shown in Fig.

21, in which provision is made for supplying to the direct current coil S^a of the stop relay S direct current from the local source of direct current carried by the car through a reset circuit. This reset circuit is controlled by a reset key 440, preferably arranged in each motorman's compartment where it may be conveniently operated. The reset circuit is as follows:

Circuit number thirty-four

Positive bus 270, conductor 441, reset switch 440, conductor 442, reset bus through the entire length of the train, conductor 443, contact springs 173 and 174, conductor 444, contact bar 445 of the electro-pneumatic valve EB in its upper position corresponding to the deenergized condition of the solenoid 397 of the valve EB, conductors 446 and 281, direct current coil S^a of the stop relay S and conductors 282 and 282¹ to the common return conductor 283. It is noted that this reset circuit (number thirty-four) may be broken at two places; one at the contact springs 173 and 174 which are separated unless the speed of the vehicle is less than a predetermined speed, such as ten miles an hour or less, the other place being at the contact bar 445 which is raised if the emergency electro-pneumatic valve EB is in its deenergized and opened position. Consequently, this reset circuit cannot be established unless the speed of the train is below a predetermined speed, and unless the emergency electro-pneumatic valve EB has already been actuated, so that the motorman cannot prevent the application of the emergency brakes by keeping the reset switch closed, nor release the brakes unless the speed is below a predetermined minimum.

In the discussion of the operation hereinbefore given only the movement of the cams 240 and 241 and the speed arm 242 of the block combination b, has been considered; but it should be noted that the cams and the speed arms of all of the block combinations are operated simultaneously; likewise the links 246 and the sectors 226 of the respective block combinations are moved. However, although the cams, the speed arms, and associated movable parts of all of the block combinations are moved, only the moving parts of the block combination selected by the selector are effective to operate the warning signal and automatically apply the brakes. This selection of the particular block combination to be effective, is accomplished by closing a circuit which for the block combination b is number eight, at the selector for the particular block combination selected, which energizes the electromagnet 198 of that block combination and rocks the contact holder 207 thereof so as to move the two pairs of contact springs carried by said contact holder into position to be operated by the

movements of the contact closing sectors 231, 232 and 233 of that particular block combination; whereas, although the cams and their associated parts of the other block combinations are moved, the contact holders 207 of said other block combinations are not rocked and their respective contact springs will not be actuated.

Regardless of whether the speed of the train has been reduced to a safe amount by the automatic application of the brakes, or by the motorman's manual application of the brakes, the cam shaft 146 will be turned by the gearing so as to impose more and more of a restriction upon the permissive speed of the vehicle until the vehicle is brought to a predetermined low speed. Where possible, it is desirable to arrange the length of the blocks and to design the cams so that, when the vehicle is brought to this predetermined low speed, the shoe of the vehicle will be on the ramp controlling passage through the next block, proper distance being allowed for margin of safety and the like; but if the train does not stop with a shoe on a ramp it may proceed at the low speed until a ramp is reached.

Referring to Fig. 22, assume that the train is now at the exit end of the block D. If the dangerous condition, such as the presence of a train, which was before assumed to exist in the block E, has been removed while the train was passing through the block D, the partial circuit for the ramp R¹ at the entrance to the block E is as follows:

Circuit number thirty-five

From the ramp R¹, conductor 261¹, armature 262¹ of the track relay 257¹ in its raised position, and conductor 450¹, to the high voltage tap 451¹ of the transformer 258¹ and conductor 267¹ to the track rail 251. Consequently, the armatures of both car relays will be raised since the high difference of potential between the ramp R¹ and the track rail 251 will send sufficient current through the alternating coil K^a of the control relay K and the impedance 302 to lift the armatures of said control relay. When the armatures of control relay K are raised, the direct current holding circuit (number three) through the direct current coil K^d of said control relay K is established. Before the foot 43 of the shoe B leaves electrical contact with the ramp that is when the front wheels of the train span the rails of the section E, the high difference of potential across the terminals of the transformer T of each car will cease; thereafter the difference of potential across the terminals of the transformer T of each car will be medium. The curvature of the end of the ramp is such that the foot 43 of the shoe B drops far enough to permit the contact disk 60 to engage the contact springs 59 and establish the hold-

ing circuit (number three) before the foot 43 leaves electrical contact with the ramp. Consequently, when the armatures of the control relay K are once raised, they will be held in their upper position until the shoe encounters a ramp between which and the track rails only a low difference of potential exists. When the armatures of the stop relay S are raised, the circuit number thirty-one for the emergency electro-pneumatic valve EB if it has been broken, is reestablished. Also, when the armatures of the control relay K are raised, the circuit (number twenty-two) for the green light is re-established; the shunt circuit (number seven) for the impedance 302 is closed; the circuit (like number eight) by which the selector circuit controllers S¹ and S² are connected to the supply of current is established; a circuit is closed for the electromagnet 198 of the block combination which should be energized due to the particular position in which the selector circuit controllers S¹ and S² are at the time. These selector circuit controllers S¹ and S² will assume a position corresponding to the position to which they are moved by the selector ramps 93 for the block E; the stick circuit (number nine) for the block combination selected is simultaneously broken; the circuit (number twenty-four) for disconnecting the cam starter is established; the circuit (number twenty-three) for the yellow light is broken; and the circuit (number thirty) through the emergency electro-pneumatic valve EB is established. In this way the parts are restored to their normal position.

As the first wheels and axle of the vehicle enter the block E the track relay 257¹ is de-energized, and its armature 262¹ dropped and interrupts circuit number thirty-five. If a dangerous condition exists in the block F, a low difference of potential between the ramp R¹ and the track rail 251 will exist instead of the prior high difference of potential; and in the same way as hereinbefore described the armatures of the control relay K will be dropped so as to set the speed control apparatus into operation.

In case no dangerous conditions exist in the block F, medium voltage will be applied across the terminals of the transformer T, on each car of the train according to the following circuit:

Circuit number thirty-six

One side of the transformer 258², conductor 267², track rail 251, through the wheels and axle, primary of transformer T, and shoe B to the ramp R¹, conductor 261¹, armature 262¹ of the track relay 257¹ in its lower position, conductor 263¹, armature 264² of track relay 257² in its upper position, conductor 458² to the medium voltage tap 459² of the transformer 258². This medium voltage will send sufficient current through the alternat-

ing current coil K^a of the control relay K , since the impedance 302 is shunted, to hold the armatures of said control relay in their raised position, and the train may proceed 5 along the block E without being required by the speed control apparatus to slow down before the entrance to the block F is reached.

In case the dangerous condition which existed in the block E still exists at the moment 10 the train is about to enter block E, the track relay 257¹ is deenergized and its armature 262¹ dropped, so that there is a break in the circuit number thirty-five, hereinbefore set forth, by which the ramp R^1 is supplied with 15 high voltage. Consequently, the armatures of the car relays are not picked up in the way hereinbefore described, but will remain in their lower position, and the operation of the speed control mechanism continues under the 20 same block combination for the block D as before. This block combination requires that the vehicle shall not exceed a predetermined constant low speed if it proceeds into the block E. The motorman may bring his train 25 to a complete stop with one of the shoes on the train in contact with the ramp R^1 and wait until the dangerous condition in the block E is removed; or the motorman may take the train through the block E at the 30 low speed. In order to inform the motorman that his train has reached the ramp R^1 and that he must decide whether to stop and wait or proceed through the block E at a constant 35 low speed, the circuit (number twenty-three) for the yellow lamp Y includes the contact springs 59 and the contact disk 60 of the shoe B, so that when the shoe B strikes the ramps R^1 , the circuit for the yellow lamp Y is interrupted and the yellow light in the motorman's compartment is extinguished to inform 40 the motorman his train has reached the ramp R^1 .

To prevent any damage to the gearing or the cams because of this prolonged distance 45 of travel of the train before the parts are restored to their normal position, the cut-away portion 149 (Fig. 11) is provided in the gear 148 so that after said gear has been turned one-half of a revolution (which is sufficient to cover the greatest block distance required) this cut-away portion will come opposite the small gear 145, and the movement 50 of said gear 148 will be arrested, it being, however, held in its moved position until the 55 small gear 145 is retracted.

Car cutout

Sometimes it may occur that the speed control apparatus on a car will be out of order, 60 and yet the car may be used for ordinary transportation service; and in such case it is desirable to provide a suitable mechanism whereby the speed control apparatus may be cut out of service and at the same time permit 65 the car to be used in connection with other

cars equipped with the speed control apparatus. However, it is important that it should not be too easy for the trainman to cut the speed control apparatus on a car out of service; otherwise, there is liability that the speed 70 control apparatus on all of the cars of a train might be carelessly cut out and the train run without proper protection. Consequently, the device for cutting the speed control apparatus out of service is arranged according 75 to this invention so that certain manipulations are necessary in order to cut the speed control apparatus on any car out of service.

The parts of the car cutout device are shown diagrammatically in Fig. 21. A 80 plunger 460 extends out through the casing 26 enclosing the parts of the cutout device, said plunger being normally pressed outwardly by a spring 461, and encased by a frangible shield 460¹ which must be shattered 85 in order to obtain access to the plunger 460. A lug 462 of insulated material is fixed to said plunger, and is arranged to engage the contact spring 272 and separate said contact spring from the contact spring 273 when the plunger 460 is pushed in. An angle member 463 is pivoted to the casing 26, one end being arranged to engage the rod 410 of the emergency electro-pneumatic valve EB and the other end being connected to the plunger 460. 90 By reason of this construction, when the plunger 460 is pushed in the angle member 463 will be rocked to hold the electro-pneumatic valve EB in its closed position. The plunger 460 is also provided with a tooth or 95 projection 464; and a pivoted latch 465 is arranged to cooperate with this tooth and hold said plunger in its inner position. An electromagnet J is arranged to lift the latch 465 out of engagement with the tooth 464. 100

The manipulations necessary to cut the speed control apparatus of a car out of service are as follows: The glass shield 460¹ is broken and the plunger 460 of the defective car is pushed in, the latch 465 automatically 110 dropping and holding said plunger in its inner position; and this movement of the plunger 460 separates the contact springs 272 and 273 and holds the electro-pneumatic valve EB closed. Subsequently when the 115 defective car is coupled together with other cars into a train, it may be made compulsory by the rules to close a reset switch 440 to supply current to the reset bus which energizes the electromagnet J by the following circuit: 120

Circuit number thirty-seven

Positive bus 270, conductor 441, reset switch 440, conductor 442, reset bus, conductor 466, electromagnet J, and conductor 467 125 to common return wire 283. By energizing the electromagnet J the latch 465 is raised and the spring 461 throws the plunger 460 to its outer position, thereby releasing the valve EB and closing the contact springs 272 130

and 273 so as to put the speed control apparatus back into service. The armatures of the car relays are in their lower position when the plunger 460 is in its inner position 5 since the current supply to the car relays is interrupted at the contact springs 272 and 273; and, consequently, when the speed control apparatus is put back into service an emergency application of the brakes is made, 10 thus compelling the trainman to cut the speed control apparatus on the defective car out of service again before the train can proceed. Naturally the trainman will not cut the speed control apparatus out of service on 15 any more cars than are necessary to start the train; and by taking advantage this natural tendency of a trainman to move along the line of least resistance, suitable provision is made so that the speed control apparatus on 20 the different cars of a train cannot be carelessly cut out of service. Furthermore, the speed control apparatus on a car cannot be cut out of service while the car is on the road without detection, because it is necessary to 25 break the glass casing 460¹ to obtain access to the car cut-out device. The cars may be inspected each time they return to the terminal and the motorman can be required to give a satisfactory explanation for the breaking 30 of each casing 460¹ found broken.

The particular arrangement of the parts of the device for cutting the speed control apparatus of a car out of service is such that a defective speed control apparatus will 35 manifest itself in other ways. To illustrate, the circuit number thirty-seven for energizing the electromagnet J is completed whenever the reset switch 440 is closed. Consequently, if one of the cars of a train has its speed control apparatus cut out of service 40 and the plunger 460 latched in its inner position, if the motorman should close the reset switch 440, either carelessly or for any other reason, the plunger 460 will be released and an emergency application of the brakes will 45 result. Also, assuming one of the cars of a train has its speed control mechanism cut out and that an automatic emergency application of the brakes is given, then the motorman by 50 closing the reset switch 440 energizes the stop relays S to energize the electro-pneumatic valves EB. However, as regards the car having its speed control apparatus cut out of service, the valve EB can not be energized 55 if the condition still exists which was the reason why the speed control apparatus on that car was cut out of service, and by closing the reset switch 440, the electromagnet J of the car having the defective speed control apparatus is operated to release the plunger 460 on that car and permit the valve EB to open. Under these circumstances, the motorman, in 60 order to proceed must cut out the defective speed control apparatus again; but this additional annoyance makes it less liable that

a train will be composed of cars each having its speed control apparatus defective.

Running into unsigned territory

It may happen that the train may proceed 70 along a railroad, part of which is provided with ramps for operating the speed control apparatus and part of which is not so provided; and to prevent wrong signals from being displayed on the train to confuse or 75 mislead the motorman, suitable arrangements are made according to this invention whereby all signals are extinguished and rendered inoperative, and at the same time a distinctive signal, such as a white light, or 80 a special indicator, is displayed to inform the motorman that he is running through an unsignalled territory. The circuits for the audible signal A, for the green lamp G, for the yellow lamp Y, and for the block indicators as set forth hereinbefore, are all controlled by the selector circuit controllers according to circuits hereinbefore set forth in 85 the partial signal ground circuit designated as circuit number seventeen.

Consequently, when the selector circuit controllers S¹ and S² are actuated to their upper or third position, all of these signal circuits are broken. At the same time a circuit for 90 displaying the no-signal indication, N. S. is 95 established as follows:

Circuit number thirty-eight

Local positive wire 275, conductor 470, upper contact bar 351 of the selector circuit controller S¹ in its third or upper position, conductor 471, upper contact bar 359 of the selector circuit controller S² in its third or upper position, conductors 472, 473 to the no-signal indicator N. S., conductors 474 and 475 to the common return wire 283.

Also, when the selector circuit controllers S¹ and S² are moved to their third, upper or no-signal position, the emergency electro-pneumatic valve EB is energized according 100 to the circuit as follows:

Circuit number thirty-nine

Local positive wire 275, conductor 480, middle contact bar 333 of the circuit controller S² in its upper or third position, conductor 481, middle contact bar 326 of the circuit controller S¹ in its upper or third position, conductors 482 and 421, valve EB and conductor 422 to the common return wire 283. This circuit thirty-nine prevents the emergency valve EB from being deenergized, if, for any reason, the circuits (number thirty and thirty-one) hereinbefore traced for energizing the valve EB should be interrupted while the train is in unsignaled territory. Also, the local circuit (number twenty-seven) for the service valve SB is interrupted on each car, by reason of the fact that the circuit controllers S¹ and S² have been moved to their upper 115 120 125 130 135

or third position, thereby interrupting the connection through the selector circuit controllers S^1 and S^2 from the controller switch bus 347 to the common return wire 283, as set forth in the partial signal ground circuit number seventeen. Consequently, the operation of the valve SB in unsignaled territory is prevented.

10 *Running against the normal direction of traffic*

Ordinarily the speed control apparatus need be effective only when the vehicle is proceeding in the normal direction of traffic, since the movements made against the normal direction of traffic must be done with great caution and under special orders; but it is necessary to make special arrangements whereby the speed control apparatus will not be set into operation when the vehicle is making a movement against the normal direction of traffic,—otherwise, the vehicle itself would be deenergizing the ramps before it passed over them. In this invention the foot 43 of the shoe B is mounted to swing in a horizontal plane about a vertical axis, this swinging movement being produced by the friction of said foot on the ramp. When the vehicle is moving in the normal direction of traffic, the movable arm 42 of the shoe B will be automatically swung in a direction opposite to the direction in which the vehicle is moving, so as to occupy the position shown in full lines in Fig. 5; but when the vehicle is moving against the normal direction of traffic said movable arm 42 will be swung in the opposite direction so as to assume the position shown in dotted lines in Fig. 5. In this latter position of the movable arm 42, the contact block 61 secured to the turning stud 47 is brought into contact with the two contact springs 62 and 63, thereby closing a circuit, illustrated diagrammatically in Fig. 23, to shunt the contact springs 59, so that when the movable arm 42 of the shoe is raised and the contact disk 60 moved out of contact with the contact springs 59, the circuits numbers two and three will not be broken, since current may flow from conductor 276 along conductor 476, contact spring 63, contact block 61, contact spring 62 and conductor 477 to the conductor 277. Consequently, when the vehicle is moving against the normal direction of traffic, although the shoe is raised each time it passes over a ramp, the above mentioned shunt circuit is also closed to keep the circuits numbers two and three through the direct current holding coils S^1 and K^1 of the car relays intact and prevent their armatures from dropping and setting the speed control apparatus into operation or causing an emergency application of the brakes.

Maximum speed control

65 The speed control apparatus hereinbefore

described will also operate to sound a warning signal and automatically apply the brakes in case the speed of a train exceeds a predetermined maximum speed at any time, and said predetermined speed may be the same for all of the blocks or may be different for the different blocks. Referring to Fig. 13, and assuming the block combination b is set up, it can be seen that even if the cam 240 is stationary, the speed arm 242 could not move to the left (corresponding to greater speeds) more than a certain distance without bringing the outermost edge of the contact closing sector 231 opposite to the roller 219, and thereby closing the circuit number twenty-five to sound the warning signal; and also, if the speed of the vehicle is increased beyond this point, the outermost edge portion of the contact closing sector 232 will be brought opposite to the roller 219 to close the circuit number twenty-seven and give an automatic service application of the brakes. In this way, a warning signal is sounded whenever the speed of the vehicle exceeds a predetermined speed and the brakes are automatically applied if the speed exceeds a little greater predetermined speed. The parts may be so arranged and proportioned that this predetermined maximum speed will be the same for each block combination, or each block combination may have a particular maximum speed. This arrangement, in addition to avoiding any damage which might be caused by excessive speed, assures that the speed of the train cannot exceed a point where the cams of the automatic speed control apparatus cannot adequately control the speed of the train.

It is to be noted that the selector has bilateral symmetry so that engagement with the selector ramps 93 produces the same effect whichever end foremost the car proceeds along the track.

Among some of the features of the speed control apparatus whereby is prevented false signals, or a failure to control the train properly, which may be occasioned by the breaking of an important part, or by the failure of some important part to act properly, the apparatus and controlling circuits therefor are so arranged that if the supply of current or the circuits along the trackway are deranged, there will be no difference of potential between the ramps and the track rails, and, consequently, an emergency application of the brakes will result. Also, if the shoe fails to make proper electrical contact with any of the ramps the result will be on the side of safety. Also, if the supply of direct current carried on the train is interrupted, the car relays will be deprived of current which normally holds their armatures raised, and an automatic application of the brakes will result. Also, the current for energizing the car relays must pass through the car transformer T, and, consequently, must be alternating in its character;

so that the apparatus will not be falsely affected by any stray direct current which may be supplied to the ramps by leakage from the wires carrying the propulsion current, or from any other source. If this selector, after having been returned to its normal position, is not operated to set up another selection, the train will continue under the block combination corresponding to the selection made by the selector in its normal position; and since this block combination regulates the speed of the train according to worst conditions, the speed of the train will be controlled with ample margin of safety. Also, while the system of speed control embodying the invention has been shown, and its operation described in connection with an automatic block system, it may be modified, and suitable selector ramps and control ramps may be properly placed at points along the trackway so as to control the speed of the vehicle around curves or near fixed hazards. Also, while the apparatus provides for automatically giving both a service and an emergency application in case the permissive speeds for said service application and emergency application respectively are exceeded, provision may be made, if desired, for only service or emergency application of the brakes.

Although I have particularly described the construction of one physical embodiment of my invention, and explained the operation and principle thereof; nevertheless, I desire to have it understood that the form selected is merely illustrative, but does not exhaust the possible physical embodiments of the idea of means underlying my invention.

What I claim as new and desire to secure by Letters Patent of the United States, is:

1. A system for automatically controlling railway vehicles comprising means for indicating the actual speed of said vehicle, a plurality of elements each representing a predetermined functional relation between the distance traveled by said vehicle and its speed, said elements being moved in accordance with the distance traveled by said vehicle, mechanism responsive to a predetermined cooperation of said means and any one of said elements for controlling the movement of said vehicle, said mechanism being set into operation whenever the speed of said vehicle at any point in its travel exceeds the speed determined by the element with which said means is cooperating, and means for selectively determining the element to cooperate with said means.

2. A system for automatically controlling railway vehicles comprising means for indicating the actual speed of said vehicle, a plurality of elements each representing a predetermined functional relation between the distance traveled by said vehicle and its speed, said elements being moved in accordance with the distance traveled by said vehicle,

a warning signal, means for operating said warning signal which is responsive to a predetermined cooperation of said first-mentioned means and any one of said elements, and means for selectively determining the element to cooperate with said last-mentioned means. 70

3. A system for automatically controlling railway vehicles comprising means assuming different positions at different points in the travel of said vehicle in accordance with the speed of said vehicle at these respective points, means assuming a position at each of these points according to a permissive speed for said vehicle at that point, mechanism controlled jointly by both of said means for controlling the movement of said vehicle, and means partly on the vehicle and partly on the track for controlling the movement of said second means, whereby the position assumed by said second means may be varied to conform to the different braking conditions along the track. 75

4. A system for automatically controlling railway vehicles comprising means on the vehicle assuming different positions in accordance with variations in the actual speed of the vehicle, a plurality of elements on the vehicle arranged to be operatively connected to the wheels thereof, each of said elements, when so connected, assuming different positions as said vehicle progresses, in accordance with a predetermined variation in the permissive speed of said vehicle, mechanism for controlling the movement of said vehicle, said mechanism being responsive to a predetermined relative position of said means and one of said elements, and means for selectively determining the element to cooperate with said means. 90

5. A system for automatically controlling railway vehicles comprising means on the vehicle which assumes different positions in accordance with variations in the actual speed of the vehicle, a plurality of elements on the vehicle arranged to be operatively connected to the wheels of said vehicle, each of said elements when so connected, assuming different positions as said vehicle progresses in accordance with a predetermined variation in the permissive speed of said vehicle, mechanism for controlling the movement of said vehicle, a circuit controller associated with each element for controlling said mechanism, means associated with each element and responsive to the combined action of said first-mentioned means and said element for operating the circuit controller of that element, and means for selectively controlling said circuit controllers. 105

6. A system for automatically controlling railway vehicles comprising means for indicating the actual speed of said vehicle, an element representing a predetermined functional relation between the distance traveled 110

by said vehicle and its speed, gearing adapted to drive said element from the wheels of the vehicle, a normally energized magnet controlling the operating condition of said gearing, a normally energized stick relay governing said magnet, traffic controlled means partly on the vehicle and partly on the track for governing said relay, an electrically operated warning signal, electrically operated mechanism for controlling the movement of said vehicle, circuit controlling devices for controlling the operation of said warning signal and said mechanism, and means responsive to the combined action of said first mentioned means and said element for operating said circuit controlling devices.

7. A system for automatically controlling railway vehicles comprising means for indicating the actual speed of said vehicle, a plurality of elements representing a predetermined functional relation between the distance traveled by said vehicle and its speed, an electrically operated warning signal, electrically operated mechanism for controlling the movement of said vehicle, circuit controlling devices associated with each element for controlling the operation of said warning signal and said mechanism, said circuit controlling devices being responsive to the combined action of said first mentioned means and the corresponding element, and operating devices on the vehicle and along the trackway for selectively determining which of said circuit controlling devices shall be effective.

8. A system for automatically controlling railway vehicles comprising a movable member which moves in accordance with the actual speed of the vehicle, a plurality of cams arranged to be operatively connected to the wheels of said vehicle, circuit controllers associated with each cam, means associated with each cam and responsive to the combined movement of said member and said cam for operating the circuit controllers associated with that cam successively at predetermined intervals, a warning signal controlled by one of said circuit controllers of each cam, means for controlling the movement of said vehicle controlled by another circuit controller of each cam, and cooperating devices on said vehicle and arranged along the trackway for selectively controlling the operation of the circuit controllers associated with the respective cams.

9. A system for automatically controlling railway vehicles comprising means for indicating the actual speed of a vehicle, a plurality of elements each representing a predetermined functional relation between the distance traveled by said vehicle and its speed, a warning signal, mechanism for controlling the movement of said vehicle, means associated with each element and operated jointly by said first mentioned means and that ele-

ment for operating said warning signal and said mechanism successively after a predetermined interval, and cooperating devices on the vehicle and along the trackway for selectively controlling the operation of said last mentioned means.

10. A system for automatically controlling railway vehicles comprising means for indicating the actual speed of said vehicle, an element representing a predetermined functional relation of the distance traveled by said vehicle and its speed, traffic controlled means partly on the vehicle and partly on the track for at times connecting said element to the wheels of said vehicle, a warning signal, mechanism for controlling the movement of said vehicle, normally inactive means responsive to a predetermined cooperation of said means and said element for operating said warning signal and said mechanism successively after a predetermined interval, and means for rendering the last mentioned means active.

11. A system for automatically controlling railway vehicles comprising means for indicating the actual speed of said vehicle, two elements representing different functional relations between the distance traveled by said vehicle and its speed, a warning signal, mechanism for controlling the movement of said vehicle, and means responsive to a predetermined cooperation of said first-mentioned means and one of said elements for operating said warning signal, and means responsive to a predetermined cooperation of said first-mentioned means and the other of said elements for operating said mechanism.

12. A system for automatically controlling railway vehicles comprising means for indicating the actual speed of said vehicle, two elements representing different functional relations between the distance traveled by said vehicle and its speed, mechanism for braking said vehicle, means responsive to a predetermined cooperation of said first-mentioned means and one of said elements for operating said mechanism to cause a service application of the brakes, and means responsive to a predetermined cooperation of said first-mentioned means and the other of said elements for operating said mechanism to cause an emergency application of the brakes.

13. A system for automatically controlling railway vehicles comprising means for indicating the actual speed of said vehicle, a plurality of elements, each element representing a predetermined functional relation between the distance traveled by said vehicle and its speed, said element being arranged to be operatively connected to the wheels of said vehicle, movable members controlled simultaneously by said means and said elements, circuit controllers operated by said members, a mechanism for controlling

the movement of said vehicle controlled by said circuit controllers, and cooperating devices on the vehicle and arranged along the trackway for selectively controlling the operation of said circuit controllers by said members.

14. A system for automatically controlling railway vehicles comprising means for indicating the instantaneous speed of the vehicle, a plurality of elements each representing a predetermined functional relation between the distance traveled by said vehicle and its speed, a device for moving said elements in accordance with the distance traveled by said vehicle, a mechanism for controlling the movement of said vehicle, means responsive to a predetermined cooperation of said means and one of said elements for setting said mechanism into operation when the speed of said vehicle at any point in its travel exceeds the speed determined by the element with which said means is cooperating, means for restoring said elements to their normal positions, and means for selectively controlling the operation of said elements.

15. A system for automatically controlling railway vehicles comprising means for indicating the actual speed of said vehicle, a plurality of cams each representing a predetermined functional relation between the distance traveled by said vehicle and its speed, floating levers each having one end operatively connected to said speed indicating means and moving in accordance with the variations in the actual speed of said vehicle, the other end of each of said floating levers being controlled by one of said cams, mechanism for controlling the movement of said vehicle, means associated with each floating lever and operated thereby for setting said mechanism into operation, and cooperating devices on said vehicle and arranged along the trackway for selectively controlling said last-mentioned means.

16. A system for automatically controlling railway vehicles comprising means for indicating the actual speed of said vehicle, a cam representing a predetermined functional relation between the distance traveled by said vehicle and its speed, a floating lever having one end operatively connected to said speed indicating means and its other end controlled by said cam, mechanism for controlling the movement of said vehicle, means associated with said floating lever and operated thereby for controlling said mechanism, and cooperating devices on said vehicle and along the trackway for connecting and disconnecting the cam to the car wheels.

17. A system for automatically controlling the speed of railway vehicles comprising a plurality of cams arranged to be operatively connected to the wheels of the vehicle, a member which takes different positions in accordance with the actual speed of said vehicle, means associated with each cam and responsive to the combined movements of said member and that cam for controlling the movement of said vehicle, and means for

selectively controlling said last mentioned means.

18. A system for automatically controlling railway vehicles, means for indicating the instantaneous speed of said vehicle, a plurality of elements each representing a predetermined functional relation between the distance traveled by said vehicle and its speed, a device for moving said elements in accordance with the distance traveled by said vehicle, a mechanism for controlling the movement of said vehicle, means responsive to a predetermined cooperation of said means and one of said elements for setting said mechanism into operation when the speed of said vehicle at any point in its travel exceeds the speed determined by the element with which said means is cooperating, means for restoring said elements to their normal positions, and means for selectively controlling the operation of said elements.

19. A system for automatically controlling railway vehicles comprising means for indicating the actual speed of the vehicle, an element representing a predetermined functional relation between the distance traveled by the vehicle and its speed, means for moving said element in accordance with the distance traveled by said vehicle, and means for varying the rate of movement of said element relatively to the distance traveled by said vehicle.

20. A system for automatically controlling the speed of railway vehicles comprising means on the vehicle assuming different positions in accordance with variations in the actual speed of the vehicle, an element representing a predetermined decrease in the speed of said vehicle corresponding to the distance traveled by said vehicle, means for moving said element in accordance with the distance traveled by said vehicle, and means for controlling said last mentioned means to vary the rate of movement of said element relatively to the distance traveled by said vehicle.

21. A system for automatically controlling the speed of railway vehicles comprising an element on said vehicle representing a predetermined functional relation between the distance traveled by said vehicle and its speed, gearing operatively connected to the wheels of said vehicle, means operable to connect said gearing and said element, a device for restoring said element to its normal position when said means is in position to disconnect said gearing and said element, means for changing the ratio of said gearing relatively to the wheels of said vehicle, and cooperating devices on said vehicle and arranged along the trackway for selectively controlling both of said means.

22. In a system for automatically controlling railway vehicles, in combination: a plurality of cams, brake control means governed by said cams, traffic controlled means for at times operatively connecting the cams to the

wheels of the vehicle, and cooperating means on the vehicle and on the track for selectively determining which cam shall be effective to control said brake control means.

5. 23. A system for controlling vehicles comprising means for indicating the actual speed of said vehicle, two cams each having symmetrical contours each representing a predetermined functional relation between the 10 distance traveled by said vehicle and its speed, mechanism for controlling the movement of said vehicle, means responsive to the conjoint action of said means and each of said cams for controlling said mechanism, and means 15 operable to connect said cams to the wheels of said vehicle, the action of said cams being the same when said vehicle moves in either direction.

24. A system for automatically controlling 20 railway vehicles comprising means for indicating the actual speed of said vehicle, a plurality of cams each having symmetrical contours and each representing a predetermined functional relation between the distance traveled by said vehicle and its speed, mechanism 25 for controlling the movement of said vehicle, means responsive to a predetermined cooperation of said means and any one of said cams for controlling said mechanism, cooperating 30 devices on said vehicle and along the trackway for selecting the cam to cooperate with said means, and cooperating devices on the vehicle and along the trackway for controlling said last-mentioned means, the action of said 35 cams being the same when said vehicle is moving in either direction.

25. In a system for automatically controlling railway vehicles, in combination: a cam shaft, a gear fixed to said cam shaft and having a portion of its periphery cut away, a second gear movably mounted adjacent to said gear and adapted to mesh therewith, means for moving said second gear into and out of mesh with said first mentioned gear, a gear 40 train to drive said second gear from the vehicle wheel, and means to change the resultant gear ratio of said gear train.

26. In a system for automatically controlling railway vehicles in combination: a cam 50 shaft, a gear fixed thereto, a second gear mounted on a shaft adjacent to said first gear, an arm journaled on said shaft and carrying two intermeshing gears, one of which meshes with said second gear, and means for moving 55 said arm to bring the other gear of said two intermeshing gears into and out of mesh with the said first gear fixed to said cam shaft.

27. In a system for automatically controlling railway vehicles, in combination: a cam 60 shaft, a gear fixed thereto, a second gear journaled adjacent to said first gear, a swinging arm journaled on the same axis as said second gear and carrying two intermeshing gears, one of which meshes with said second gear, 65 a spring normally tending to move said arm

to bring the other gear of said two intermeshing gears thereon into mesh with said first gear on said cam shaft, and electromagnetic means for moving said arm in the opposite direction.

70 28. In a system for automatically controlling railway vehicles, in combination: a cam shaft, gearing operatively connected to the wheels of the vehicle, a device operable to connect said gearing to said cam shaft, means 75 for changing the ratio of said gearing between said cam shaft and the wheels of said vehicle, and cooperating devices on said vehicle and arranged along the trackway for controlling said device and said means.

80 29. In a system for automatically controlling railway vehicles, in combination: a cam shaft, a driving gear, a rocker arm having the same axis as said driving gear and carrying two concentric gears of different sizes at 85 one end and a single gear at its other end, said single gear and one of said two concentric gears meshing with said driving gear, at all times, a driven gear, said single gear and the other one of said two concentric gears 90 being arranged to mesh alternately with said driven gear, and means for actuating said rocker arm.

95 30. In a system for automatically controlling railway vehicles, in combination: a cam shaft having a plurality of cams secured thereto, means controlled by cooperating devices on the vehicle and along the trackway for turning said cam shaft in accordance with the distance travelled by said vehicle in either 100 direction corresponding to the direction in which said vehicle is moving, said cams being symmetrical on each side of an initial point, means for restoring said cams to their initial positions, a safety appliance for excessive 105 speed, and means to control it from a particular cam selectively.

110 31. A system for automatically controlling railway vehicles comprising means for indicating the instantaneous speed of the vehicle, a plurality of elements each representing a predetermined functional relation between the distance traveled by said vehicle and its speed, mechanism for actuating said elements in accordance with the distance traveled by 115 said vehicle, means for restoring said elements to their normal positions, means responsive to a predetermined cooperation of said means and one of said elements for controlling the movement of said vehicle, cooperating devices on the vehicle and along the trackway for selectively controlling the operation of said elements, and other cooperating devices on the vehicle and along the trackway for controlling said mechanism.

120 32. In a system for automatically controlling railway vehicles, in combination: a cam shaft, gearing operatively connected to the wheels of said vehicle, means for operatively connecting said cam shaft and said gearing,

- a pinion secured to said cam shaft, a toothed sector meshing with said pinion, and springs for normally holding said sector in its middle position.
33. In a system for automatically controlling railway vehicles, in combination: a cam shaft, a plurality of cams operatively connected to said cam shaft, means of varying character associated with said cams respectively for controlling said vehicle, selective means to render a particular cam effective, means for moving said cam shaft in accordance with the distance traveled by said vehicle, and means for restoring said cam shaft to its normal or initial position. 70
34. In a system for automatically controlling railway vehicles, in combination: a support, a contact holder pivotally mounted on said support and having contact springs secured thereto, a movable member adapted to move said contact springs, said movable member being responsive to the conjoint action of the permissive speed of the vehicle and its actual speed, and electromagnetic means for 75
- 20 rocking said contact holder to move said contact springs into position to be actuated by said movable member.
35. In an automatic train control system, in combination: a support, a contact holder pivotally mounted on said support, contact springs secured to said contact holder, a sector-shaped movable member pivotally mounted adjacent to the upper ends of said contact springs and having portions of its outer edge 80
- 30 at different distances from its pivot axis, means carried by the contact spring nearest said movable member and adapted to be engaged by the edge of said movable member, and electromagnetic means for rocking said 85
- 25 contact holder and thereby bringing said contact springs into position to be actuated by said movable member. 90
36. In a system for automatically controlling railway vehicles, in combination: a support, a contact holder pivotally mounted on said support, two pairs of contact springs secured to said contact holder, a sector-shaped movable member pivotally mounted on said support adjacent to the upper ends of said 95
- 30 contact springs and having shoulders at its outer edge, one of the contact springs of the pair nearest said movable member having secured thereto a roller adapted to be engaged by the edge of said movable member, means 100
- 35 on the other contact spring of said pair for actuating the other pair of contact springs after said first mentioned pair have been actuated, electromagnetic means for rocking said contact holder to bring said roller into the path of movement of the shoulders of said movable member, and means for moving said movable member. 105
37. In a system for automatically controlling railway vehicles, in combination: circuit controlling devices, a movable member hav- 110

38. In a system for automatically controlling railway vehicles, in combination: a plurality of block combinations, each comprising circuit controlling devices and two cams representing different predetermined functional relations of the distance traveled by said vehicle and its speed, means for indicating the actual speed of the vehicle, two movable members associated with each block combination for actuating said circuit controlling devices, means associated with each cam and responsive to the conjoint action of that cam and said speed indicating means for operating one of said movable members, and cooperating devices on the vehicle and along the trackway for selectively controlling the operation of said block combinations. 80
39. In a system for automatically controlling railway vehicles, in combination: a plurality of block combinations, each comprising circuit controlling devices, and two cams representing different predetermined functional relations of the distance traveled by said vehicle and its speed, means for indicating the instantaneous actual speed of the vehicle, two movable members for actuating said circuit controlling devices of each block combination, means associated with each cam and responsive to the conjoint action of that cam and said speed indicating means for operating one of said movable members, and cooperating devices on the vehicle and along the trackway for selectively moving said circuit controlling devices of said block combination into position to be actuated by said movable members. 90
40. A system for automatically controlling railway vehicles comprising means for indicating the actual speed of a vehicle, a plurality of cams each representing a predetermined functional relation between the distance traveled by said vehicle and its speed, a warning signal, a normally open circuit for operating said warning signal, a device adapted to give a service application of the brakes of said vehicle, a normally open circuit for operating said device, a device for giving an emergency application of the brakes of said vehicle, a normally closed circuit for operating said last mentioned device, and means responsive to different cooperating positions of said speed indicating means and said cams for closing the two first mentioned circuits and for opening said last mentioned circuit successively. 115
41. A system for automatically controlling railway vehicles comprising means for indicating the actual speed of the vehicle, a plurality of block combinations, elements 130

associated with said block combinations and representing permissive speeds at different points along the trackway, a movable member associated with each of said elements and operated conjointly by that element and said speed indicating means, circuit controlling devices for each block combination and arranged to be moved into and out of operative position relatively to the corresponding movable member, an electromagnet associated with each block combination for moving said circuit controlling devices into their operative position, means moving in accordance with the distance traveled by said vehicle, mechanism for connecting said elements to said last mentioned means, cooperating devices on the vehicle and along the trackway for operating said mechanism, and a stick circuit for the electromagnet of each block combination which is closed when said electromagnet of that block combination is energized and said mechanism is operated.

42. In a system for automatically controlling railway vehicles, in combination: a shoe carried by said vehicle, ramps located along the trackway with which said shoe cooperates as said vehicle passes said ramps, means associated with the trackway to apply an alternating electromotive force to said ramps, an automatic vehicle controlling mechanism, an electrically operated device for controlling said mechanism, and a transformer on said vehicle, the primary circuit of said transformer including said shoe and the body of said vehicle, the secondary circuit of said transformer including said electrically operated device.

43. In a system for automatically controlling railway vehicles, in combination: a plurality of vehicles each carrying a shoe, ramps located along the trackway with which said shoe cooperates, automatic vehicle controlling means carried by each of said vehicles, electrically operated devices for controlling said mechanisms, a transformer on each vehicle, the primary circuit of said transformer including the shoe and the body of said vehicle, the secondary circuit of said transformer including the electrically operated device on said vehicle, and a continuous electrical conductor connecting the shoes of all of said vehicles.

44. A system for automatically controlling railway vehicles comprising means for indicating the instantaneous speed of the vehicle, a plurality of block combinations each having an element representing a predetermined functional relation between the distance traveled by said vehicle and its speed, a movable member for each block combination operated by the conjoint action of said speed indicating means and said element of that block combination, circuit controlling devices associated with each block combination, electromagnetic means for moving

said circuit controlling devices into an operative position relatively to the corresponding movable member, a circuit for each electromagnet means, a selector for controlling the circuits of said electromagnetic means selectively, a stick circuit for each electromagnetic means, a local supply of electric current, and means for connecting said selector to said supply current and for controlling said stick circuits.

45. In a system for automatically controlling railway vehicles, in combination: a plurality of elements each representing a predetermined functional relation between the distance traveled by said vehicle and its speed, a safety appliance for excessive speed, means selectively to establish an operative connection between one of said elements and said appliance, gearing driven in accordance with the distance traveled by said vehicle, means for operatively connecting said gearing to said elements, an electromagnet for controlling said means, said electromagnet when energized operating to disconnect said elements and said gearing, a normally closed circuit for said electromagnet and cooperating devices on the vehicle and arranged along the trackway for controlling said circuit.

46. In a system for automatically controlling railway vehicles, in combination: one or more vehicles each having a compartment for the operator of the vehicle, a car controller in each compartment, a plurality of signals in each compartment, an automatic vehicle controlling apparatus for operating said signals, a switch in each compartment for controlling the signals therein, and means associated with each car controller and operated by the movement of said controller to the position to start the car for closing said switch.

47. In a system for automatically controlling railway vehicles, in combination: a plurality of vehicles, automatic vehicle controlling apparatus on each vehicle, an electricaly operated warning signal and an electricaly operated brake controlling mechanism on each vehicle and controlled by said apparatus and continuous electrical conductors extending through all of the vehicles and connected to said warning signal and to said brake controlling mechanism respectively, whereby the vehicle controlling apparatus on all of the vehicles may operate jointly to actuate said warning signal and control the movement of said vehicles.

48. In a system for automatically controlling railway vehicles, in combination: a plurality of vehicles each having automatic vehicle controlling apparatus mounted thereon, an electrically operated brake controlling mechanism and an associated power cut-off on each vehicle controlled by said apparatus, and an electrical conductor connecting said brake controlling mechanisms on all of

- said vehicles, whereby said vehicle controlling apparatus on said vehicles may operate said brake controlling mechanism and the power cut-offs simultaneously.
5. In a system for automatically controlling railway vehicles, in combination: a plurality of vehicles, automatic vehicle controlling apparatus on each vehicle, an electrically operated warning signal and an electrically operated brake controlling mechanism on each vehicle and controlled by said apparatus, continuous electrical conductors extending through all of the vehicles and connected to said warning signal and to said brake controlling mechanism respectively, whereby the vehicle controlling apparatus on all of the vehicles may operate jointly to control the movement of said vehicles, and means on each vehicle for disconnecting said warning signal from said continuous conductor. 70
10. 49. In a system for automatically controlling railway vehicles, in combination: a vehicle, automatic vehicle controlling apparatus thereon, signals on said vehicle controlled by said apparatus, and cooperating devices on said vehicle and along the trackway for rendering all of said signals inoperative. 75
15. 50. In a system for automatically controlling railway vehicles, in combination: a vehicle, automatic vehicle controlling apparatus thereon, signals on said vehicle controlled by said apparatus, and cooperating devices on said vehicle and along the trackway for rendering all of said signals inoperative. 80
20. 51. In a system for automatically controlling railway vehicles, in combination: a vehicle, automatic vehicle controlling apparatus thereon, signals on said vehicle controlled by said apparatus, a distinctive signal for indicating when the vehicle is passing through an unsignalled territory, and cooperating devices on said vehicle and along the trackway for rendering all of said first mentioned signals inoperative and for displaying said distinctive signal. 85
25. 52. In a system for automatically controlling railway vehicles, in combination: a vehicle, brakes for said vehicle, means biased for causing an emergency application of said brakes, an electromagnet normally energized to restrain said means, automatic vehicle controlling apparatus on said vehicle for controlling said means, a source of electric current for said electromagnet and other apparatus, and a car cut-out device operable to disconnect said source of current from said apparatus and to prevent the operation of said means. 90
30. 53. In a system for automatically controlling railway vehicles, in combination: a vehicle, brakes for said vehicle, means for causing an emergency application of said brakes, automatic vehicle controlling apparatus on said vehicle for controlling said means, a source of electric current for said apparatus, a car cut-out device operable to disconnect said source of current from said apparatus to prevent the operation of said means, said car cut-out device being normally urged to its normal position, a detent for holding said cut-out device in its operated position and means for controlling said detent. 95
35. 54. In a system for automatically controlling railway vehicles, in combination: a vehicle and two contact shoes carried thereby, one of said contact shoes being located on each side of said vehicle, each shoe having a horizontal contact face adapted to engage a horizontal contact face of a ramp or rail, said shoes being mounted to swing on a vertical axis in opposite directions longitudinally of the car. 100
40. 55. Car apparatus for automatic speed control systems comprising a plurality of different shaped cams, means adapted to be controlled from the trackway for operatively connecting said cams to the running gear of the vehicle, a brake setting appliance, a speed responsive device, circuit controlling means for each cam operated by the joint action of that cam and the speed responsive device, and automatic means for selecting the circuit controlling means to govern the brake setting appliance. 105
45. 56. Car apparatus for train control systems, comprising a plurality of different shaped cams biased to the same initial position, means adapted to be controlled from the trackway for simultaneously moving said cams slowly, circuit controllers actuated separately by the cams, a normally closed brake control circuit, and automatic means for selectively placing said circuit under the control of a selected one of said circuit controllers. 110
50. 57. An automatic speed control system for railroads having blocks of different length and different grades, comprising a plurality of speed governed brake control devices on a vehicle each corresponding to a block of a particular length and grade, and means partly on the vehicle and partly on the track for selectively placing said devices in control of the vehicle in conformity with the length and grade of the respective block in which the vehicle is traveling. 115
55. 58. In a system for automatically controlling railway vehicles, in combination: a plurality of block combinations and a selector for selectively controlling the operation of said block combinations, said selector comprising a plurality of tappets, and ramps arranged along the trackway for actuating said tappets selectively. 120
60. 59. A selector for automatic railway vehicle controlling systems comprising a plurality of floating levers, tappets arranged in pairs and connected one to each end of each lever, and circuit controllers operatively connected to said levers between the ends thereof. 125
65. 60. A selector for automatic railway vehicle controlling systems comprising a plurality of floating levers, tappets arranged in pairs and connected one to each end of each lever, and circuit controllers operatively connected to said levers between the ends thereof, 130

and means for holding each actuating tappet in its actuated position.

61. A selector for automatic railway vehicle controlling systems comprising a plurality of floating levers, tappets arranged in pairs and connected one to each end of each lever, and circuit controllers operatively connected to said levers between the ends thereof, means for holding each actuating tappet in its actuated position, and means for releasing said last mentioned means.

62. In a system for automatically controlling railway vehicles, in combination: an axle of said vehicle, a speed indicator and a distance responsive member carried by said vehicle and a gearing connecting both said speed indicator and said distance responsive member with said axle and comprising a shaft operatively connected to said axle, said shaft having universal joints therein and being extensible.

63. Train control apparatus for railway vehicles comprising a movable element supported on the body of the vehicle, and gearing connecting said element to an axle of the vehicle and including a vertically disposed shaft having universal joints therein and extensible in length to compensate for movement of the axle relative to the body of the vehicle, the gear ratio of said gearing being adjustable to make the movement of said element correspond with the actual distance travelled by the vehicle.

64. In a system for automatically controlling railway vehicles, in combination: a vehicle, ramps secured between the rails of the trackway of said vehicle, springs for supporting said ramps, tappets carried by said vehicle and adapted to engage said ramps, and circuit controllers operated selectively by said tappets.

65. In combination, a track, a car thereon, mechanism on the car driven from the car wheel, a safety appliance for excessive speed adapted to be actuated by said mechanism, means carried by the car adapted to adjust said mechanism, and means associated with the track to actuate said means carried by the car.

66. In combination, a track, a car thereon, a safety appliance for excessive speed, an element on the car adapted by continued displacement to actuate said appliance, means carried by the car adapted to be driven by the car's motion gradually to displace said element, and means associated with the track adapted to adjust said means carried by the car and to initiate its operation to displace said element.

67. In combination, a track, a car thereon, a safety appliance for excessive speed, means adapted to effect a delayed actuation thereof, and means associated with the track adapted

to adjust said first mentioned means and to initiate the operation thereof.

68. In combination, a track, a car thereon, mechanism on the car adapted to be driven from the car wheel, means partly on the vehicle and partly on the track to adjust said mechanism in accordance with permanent conditions on the track, means to initiate the driving of said mechanism in accordance with transient danger conditions on the track, and a safety appliance for excessive speed adapted to be actuated by said mechanism.

69. In combination, a track, ramps associated therewith adapted to be energized in accordance with the presence or absence of cars on said track, other ramps not so energized, a car on said track, a safety appliance for excessive speed on said car, and means to actuate said appliance adapted to be adjusted by said other ramps and adapted to be initially actuated by said first mentioned energized ramps.

70. In combination, a sectional trackway, ramps along said track adapted to be energized in accordance with the presence or absence of cars on said sectional trackway, other ramps not so energized, a car on said track, a safety appliance for excessive speed on said car, means to actuate said appliance adapted to be adjusted by said other ramps and to be initially actuated by said energized ramps, and means carried by the car to continue the actuation of said appliance after it has been initially actuated.

71. In combination, a track, two classes of ramps associated with said track, a car on said track, a safety appliance for excessive speed on said car, and means to actuate said appliance adapted to be adjusted by the ramps of one class and to be initially actuated by the ramps of the other class.

72. In combination, a track, a car thereon, a safety appliance for excessive speed on said car, apparatus having an initial condition and an ultimate condition and requiring an interval to change from the initial condition for controlling the operation of said appliance to the ultimate condition, means partly on the vehicle and partly on the track to adjust the apparatus to vary said interval, and means to start and continue a change of the apparatus from its initial condition to its ultimate condition.

73. In combination, a track divided into blocks of different characteristics, a car on said track, a safety appliance for excessive speed on said car, apparatus to actuate said appliance, and means to adjust said apparatus to correspond to the characteristics of the different blocks.

74. In combination, a track divided into blocks of different characteristics, a car on said track, a safety appliance for excessive speed on said car, apparatus to actuate said

- appliance, means to adjust said apparatus to correspond to the characteristics of the different blocks, and ramps associated with the blocks to actuate said means.
75. In combination, a track divided into blocks of different characteristics, a car on said track, a safety appliance for excessive speed on said car, mechanism driven from the car wheel adapted to effect a delayed actuation of said appliance, means to adjust said mechanism to vary the period of delay in its action, ramps to actuate said adjusting means, and other ramps to initiate the driving of said mechanism.
76. In combination, a track divided into blocks of various lengths, a car thereon, a safety appliance for excessive speed on said car, mechanism driven from the car wheel and adapted to actuate said appliance subject to an interval of delay, means to adjust said mechanism to vary the interval of delay in accordance with the lengths of the blocks, ramps associated with the blocks and corresponding in character with the lengths of the respective blocks and adapted to actuate said means, and other ramps adapted to initiate the operation of said mechanism at the beginning of each block.
77. In combination, a track divided into blocks of various lengths, a car thereon, a safety appliance for excessive speed on said car, a plurality of trains of mechanism driven from the car wheel and each adapted to actuate said appliance subject to an interval of delay, and means partly on the car and partly associated with each block to select a train of mechanism that will give an interval of delay corresponding to the length of the block.
78. In combination, a track, a car thereon, a member on the car which moves in accordance with the permissive speed of the car, means dependent for movement on the movement of the car for moving such member from a maximum speed position toward a minimum speed position, a safety appliance for excessive speed adapted to be actuated by said member, and means controlled by apparatus outside the car for adjusting the rate of movement of said member and for restoring it to a maximum speed position while the car is at different places along the track.
79. In combination, a track, a car thereon, a speed responsive device on the car, mechanism driven from the car wheel, a safety appliance for excessive speed adapted to be actuated by said device and said mechanism conjointly, and means associated partly with the car and partly with the track adapted to modify the action of said mechanism.
80. In combination, a track, a car thereon, a speed responsive device on the car, mechanism on the car driven from the car wheel, a safety appliance for excessive speed adapted to be actuated by said device and said mechanism conjointly, means carried by the car
- adapted to modify the action of said mechanism, and means associated with the track adapted to engage said means carried by the car and actuate the same.
81. In combination, a track, a car thereon, means on the car adapted to assume different positions at different points in the travel of said car, other means on the car assuming different positions according to the speed of the car, a safety appliance for excessive speed actuated conjointly by both of said means, and apparatus for adjusting the movement of said first mentioned means in accordance with the conditions along the track.
82. In combination, a track, a car thereon, a speed responsive device on the car, an element on the car representing a predetermined functional relation between the distance traveled by the car and its speed, means for moving said element in accordance with the distance traveled by said car, means for adjusting the rate of movement of said element, and a safety appliance for excessive speed actuated conjointly by said speed responsive device and said element.
83. In combination, a track, a car thereon, a speed responsive device on the car, a safety appliance for excessive speed, means to actuate said appliance from said device and from the car wheel conjointly, members associated with the track, and means carried by the car adapted to engage said members and thereby alter the operative connection from the car wheel to said appliance.
84. In combination, a track, a car thereon, a speed responsive device on the car, a safety appliance for excessive speed, a device initially actuatable by the movement of the car past a particular portion of said track, means carried by the car to impart additional movement to said device, means dependent on a predetermined cooperation between said speed responsive device and said device actuatable by the movement of the car for actuating the safety appliance, and means carried by the car actuatable by its passing a particular part of the track to adjust said means for imparting additional movement.
85. In an automatic train control system for railroads having portions of track on which the vehicles require different distances to be stopped by their brakes, the combination with a brake control appliance on a vehicle, of apparatus on the vehicle including a speed responsive device for governing said appliance, means partly on the vehicle and partly on the track for automatically controlling the operation of said apparatus in accordance with the presence or absence of other vehicles ahead, and means for automatically adjusting said apparatus to conform with the varying effect of the vehicle brakes as it travels over said different portions of the track.
86. In combination, a track, a car thereon, a

speed responsive apparatus on the car, a safety appliance for excessive speed, a series of separated structures spaced along the track, a device adjustable by the relation of the vehicle to at least one of said structures and initially actuatable by its relation to other of said structures, means for imparting a predetermined additional movement to said device, and means upon said device cooperating with said speed responsive apparatus to bring said appliance into operation only when the train proceeds at more than a predetermined speed after the completion of said additional movement of said device.

87. In combination, a track, a car thereon, a speed responsive device on the car, permissive speed means on the car driven by the running gear thereof which moves in accordance with the permissive speed of the car, means partly on the car and partly on the track to adjust said permissive speed means in accordance with track braking conditions, a safety appliance for excessive speed, and means adapted to actuate said appliance when the speed of the car as registered by the speed responsive device exceeds the speed corresponding to the position of the permissive speed means.

88. In combination, a track, a car thereon, a speed responsive device on the car, permissive speed means on the car driven by the running gear thereof which moves in accordance with the permissive speed of the car, means partly on the car and partly on the track to adjust said permissive speed means in accordance with permanent track conditions, a safety appliance for excessive speed, and means adapted to actuate said appliance when the relation of the speed responsive device and the permissive speed means goes beyond a predetermined limit.

89. In combination, a track, a car thereon, a speed responsive device on the car, mechanism on the car adapted to be driven from the car wheel, means partly on the vehicle and partly on the track to adjust said mechanism in accordance with permanent track conditions, means to initiate the driving of said mechanism in accordance with transient danger conditions on the track, and a safety appliance for excessive speed adapted to be actuated by said device and said mechanism conjointly.

90. In combination, a track, a car thereon, a speed responsive device on the car, mechanism on the car adapted to be driven from the car wheel, two kinds of members associated with said track, parts carried by the car adapted to engage said members, means actuated by one kind of members to adjust said mechanism in accordance with permanent track conditions, means actuated by the other kind of members to initiate the driving of said mechanism in accordance with transient danger conditions on the track, and a

safety appliance for excessive speed adapted to be actuated by said speed responsive device and said mechanism conjointly.

91. In combination, a track, a car thereon, a speed responsive device on the car, mechanism on the car adapted to be driven from the car wheel, means to adjust said mechanism, members associated with the track adapted to engage said adjusting means and actuate the same in accordance with permanent track conditions, means to initiate the driving of said mechanism, other members associated with the track adapted to engage said last mentioned means and actuate the same in accordance with transient danger conditions on the track, and a safety appliance for excessive speed adapted to be actuated by said speed responsive device and said mechanism conjointly.

92. In combination, a track, a car thereon, a speed responsive device on the car, mechanism on the car adapted to be driven from the car wheel, means to adjust said mechanism, members associated with the track adapted to engage said means and actuate the same, other means to initiate the driving of said mechanism, other members associated with the track adapted to engage said other means to initiate the driving of said mechanism in accordance with transient danger conditions on the track, and a safety appliance for excessive speed adapted to be actuated by said speed responsive device and said mechanism conjointly.

93. In combination, a track, a car thereon, a safety appliance for excessive speed, an element on the car adapted by continued displacement to actuate said appliance, car carried means adapted to be driven by the car's motion gradually to displace said element, track means adapted to adjust said means and to initiate such displacement, and a speed responsive device carried by the car adapted to act cooperatively with said element on said appliance.

94. In combination, a track, a car thereon, a safety appliance for excessive speed, a plurality of trains of mechanism any one of them being adapted to be connected operatively from the car wheel to said appliance, and means on the track to effect such a connection of a particular one of said trains of mechanism.

95. In combination, a track, a car thereon, a safety appliance for excessive speed, a movable member carried by the car, a plurality of different alternative connections from said member to actuate said appliance, and means associated with the track selectively to establish a particular connection in accordance with track conditions.

96. In combination, a track, a car thereon, a safety appliance for excessive speed on the car, mechanism adapted to be driven from the car wheel to actuate said appliance, such

mechanism comprising a plurality of different alternative connections, means associated with the track selectively to establish a particular connection, and means associated with the track to initiate the driving of said mechanism.

97. In combination, a track, a car thereon, a safety appliance for excessive speed on the car, apparatus for actuating said appliance, a transverse row of members carried by the car, ramps to be engaged by said members respectively, and connecting means from said members to said apparatus adapted to modify the action of the latter, said members being connected together in pairs symmetrically whereby their effect on such connection is the same with either end of the car foremost.

98. In combination, a track, a car thereon, a safety appliance for excessive speed carried by the car, apparatus to actuate said appliance, a selector adapted to modify the action of said apparatus, said selector comprising a transverse row of members, and ramps adapted to be engaged by said members, said members being connected together in pairs symmetrically whereby the action of each member of a pair is the same as of the other member of that pair.

99. In combination, a track, a car thereon, a safety appliance for excessive speed carried by the car, apparatus to actuate said appliance, a selector adapted to modify the action of said apparatus, said selector comprising a transverse row of members, and ramps adapted to be engaged by said members, each member on one side being connected to a corresponding member on the other side whereby the action of each member of a pair is the same as for the other member of that pair.

100. In combination, a track, a car thereon, a pair of members carried by the car and spaced equally on either side of the center line, a safety appliance for excessive speed carried by the car, apparatus to actuate said appliance, like connections thereto from both members whereby said members can impart additive effects to said apparatus, and corresponding ramps associated with the track adapted to engage said members.

101. In combination, a track, a car thereon, a safety appliance for excessive speed on the car, apparatus to actuate said appliance, two members carried by the car spaced equally on either side of its center line, mechanism for transmitting an effect from said members to said apparatus, said members being connected alike to said mechanism so that their effects will be alike and additive, and ramps correspondingly placed on the track to actuate said members.

102. In combination, a track, a car thereon, a safety appliance for excessive speed on the car, apparatus to actuate said appliance, a floating lever connected at its middle point

to actuate said apparatus, members carried by the car and spaced equally on either side of its center line and connected to the ends of said floating lever, and ramps adapted to engage said members and actuate them.

103. In combination, a track, a car thereon, a safety appliance for excessive speed on the car, apparatus to actuate said appliance, a floating lever with one point operatively connected to actuate said apparatus, two members on the car spaced equally on either side of its center line and connected each to another point of said floating lever, and ramps associated with the track adapted to engage said members.

104. In combination, a track, a car thereon, a safety appliance for excessive speed on the car, apparatus to actuate said appliance, a selector adapted to modify the action of said apparatus, said selector comprising a transverse row of members, ramps adapted to be engaged by said members, and floating levers, each member on one side and a corresponding member on the other side being connected to the respective ends of one such floating lever.

105. In combination, a track, a car thereon, a safety appliance for excessive speed on the car, apparatus to actuate said appliance, a selector adapted to modify the action of said apparatus, said selector comprising a transverse row of members, ramps adapted to be engaged by said members, floating levers, each member on one side and the corresponding member on the other side being connected to the ends of one such floating lever, and an independent central member and a corresponding ramp therefor.

106. In combination, a track, a car thereon, a safety appliance for excessive speed on the car, apparatus to actuate said appliance, a selector carried by the car adapted to modify the action of said apparatus, said selector comprising a transverse row of members, and a group of ramps to be engaged by said members, the middle ramp of each group being set in advance of the others and adapted to release the selector and thereby put it in proper condition to be affected by the remaining ramps of the group.

107. In combination, a track, a car thereon, a safety appliance for excessive speed on the car, apparatus to actuate said appliance, a selector carried by the car adapted to modify the action of said apparatus, said selector comprising a transverse row of members, there being an odd number of these members, one of them on the center line of the car and the others in pairs symmetrically disposed on each side of said center line, the two members of each pair being connected to operate similarly and additively, and ramps to operate with said members.

108. In combination, a track, a car thereon, a safety appliance for excessive speed on the car, apparatus to actuate said appliance,

- 5 a selector to modify said apparatus, said selector comprising a circuit controller with three positions, a floating lever connected to said circuit controller, two symmetrically placed members also connected to said floating lever, ramps to actuate said members, a third member adapted to release said circuit controller and bring it to an initial position, and a ramp to coact with said third member.
- 10 109. In combination, a track, a car thereon, a safety appliance for excessive speed on the car, apparatus to actuate said appliance, a selector to modify said apparatus, said selector comprising a circuit controller with three positions, a floating lever connected to said circuit controller, two symmetrically placed members also connected alike to said floating lever, whereby actuation of either member will move said controller from an initial position to a second position, and actuation of both members will move it to a third position, and ramps to actuate said members.
- 15 110. In combination, a track, a car thereon, a safety appliance for excessive speed on the car, apparatus to actuate said appliance, a selector to modify said apparatus, said selector comprising a circuit controller with three positions, two symmetrically placed members connected alike to said controller, whereby actuation of either member will move said controller from an initial position to a second position, and actuation of both members will move it to a third position, and ramps to actuate said members.
- 20 111. In combination, a track, a car thereon, a safety appliance for excessive speed on the car, apparatus to actuate said appliance, a selector to adjust said apparatus, said selector comprising a pair of members equally spaced on either side of the center line of the car, a floating lever with its ends connected to said members, a circuit controller connected to the middle point of said lever, a latch to hold said circuit controller, ramps to engage said members, a third central member to release said latch, and a corresponding ramp for said third member.
- 25 112. In combination, a track, a car thereon, a speed responsive device on the car, a safety appliance for excessive speed, a plurality of alternative connections from said device to said appliance, each adapted to enforce a different maximum speed limit, and means associated with the trackway selectively to establish one such connection.
- 30 113. In combination, a track, a car thereon, a safety appliance for excessive speed, a speed responsive device adapted to actuate said appliance when the car speed exceeds a certain limit, means to adjust the connection of said device to said appliance to vary said limit, and means associated with the track to actuate said adjusting means.
- 35 114. In combination, a track, a car thereon, a speed responsive device carried by the car, a safety appliance for excessive speed, a plurality of connections from said device to said appliance, each adapted to actuate the appliance for a particular limiting speed, ramps, and a selector comprising means to be engaged by said ramps, said selector being adapted to establish a particular one of said connections.
- 40 115. In combination, a track, a car thereon, a speed responsive device on the car, a safety appliance for excessive speed adapted to be actuated thereby, means to adjust the connection of said appliance to said device for various permissible maximum speeds along the trackway, and ramps to actuate said adjusting means.
- 45 116. In combination, a track, a car thereon, a speed responsive device carried by said car, a safety appliance for excessive speed, a plurality of operative connections from said device to said appliance, each adapted to actuate the appliance for a different maximum speed, and means partly on the car and partly on the track to select a particular one of said connections.
- 50 117. In combination, a track, a car thereon, a safety appliance for excessive speed on the car, apparatus to actuate said appliance, a selector to modify the action of said apparatus, means associated with the track at one point to actuate said selector, and means associated with the track at another point to initiate the action of said apparatus as modified by the selector.
- 55 118. In combination, a track, a car thereon, a safety appliance for excessive speed on the car, apparatus to actuate said appliance, means for producing a delayed actuation of said apparatus, means partly on the car and partly on the track to modify the operative character of said apparatus, and other means partly on the car and partly on the track to initiate actuation of said apparatus.
- 60 119. In combination, a track, a train thereon, a safety appliance for excessive speed on a car of the train, apparatus to actuate said appliance, said apparatus being duplicated to some extent on different cars of the train, selectors to adjust said apparatus, means associated with the track at one point to actuate said selectors, and means associated with the track at a point more than a train length ahead in the direction of travel to initiate the action of said apparatus as modified by the selectors.
- 65 120. In combination, a track, a train thereon, a safety appliance for excessive speed on a car of the train, apparatus to actuate said appliance, said apparatus being duplicated to some extent on different cars of the train, means on the train to adjust said apparatus, means associated with the track at one point to actuate said adjusting means, and means

associated with the track at a point more than a train length ahead in the direction of travel to initiate the action of said apparatus as adjusted.

5 121. In an automatic train control system for railroads having signalled territory equipped for the automatic control of cars thereon and un signalled territory not so equipped, the combination with a car, brake 70
10 controlling apparatus on the car operated at excessive speeds, ramps on the track adjacent to the ends of un signalled territory, and means carried by the car and co-operating with said ramps to render said apparatus in- 75
15 effective and effective respectively as the vehicle enters and leaves un signalled territory.

122. In combination, a track, a car thereon, a safety appliance for excessive speed on the car, apparatus to actuate said appliance, a 80
20 selector comprising a circuit controller, and ramps to actuate said circuit controller to different positions, certain of said positions of the circuit controller being adapted to give different adjustments to said apparatus, and 85
25 one of said positions being adapted to render said apparatus ineffective.

123. In an automatic train control system for railroads having blocks of different length, the combination with automatic 90
30 brake control apparatus on a vehicle capable of enforcing speed restrictions of a varying character suitable for the different length blocks, of means partly on the vehicle and partly on the track for governing the operation 95
35 of said apparatus in accordance with traffic conditions, and automatic means for adjusting said apparatus to select the character of speed restrictions enforced thereby to conform with the length of block in which 100
40 the vehicle is running.

124. In an automatic train control system for railroads having blocks of different length, the combination with automatic apparatus on a vehicle adapted when set into operation to cause an automatic brake application if the vehicle during its progress through a block exceeds predetermined speed restrictions, said apparatus being adjustable 105
45 to vary such speed restrictions to conform with the different length of blocks, means for selecting the adjustment of said apparatus, and traffic controlled means for governing the operation of said apparatus.

50 125. In an automatic train control system for railroads having blocks of different length, speed control apparatus on a vehicle including permissive speed means changeable from a maximum speed condition to a 110
55 minimum speed condition during the progress of a vehicle through a block, and automatic means partly on the vehicle and partly on the track for governing said apparatus in accordance with traffic conditions and caus- 115
60 ing the change of said permissive speed

means to conform with the length of block in which the vehicle is running.

126. In an automatic train control system for railroads having blocks of different length, speed control apparatus on a vehicle including a brake control appliance and speed governed means for actuating said appliance, said apparatus being adapted when set into operation to cause actuation of the appliance when the vehicle exceeds predetermined lower speed limits during its progress through a block, means for automatically adjusting said apparatus to vary the speed limits prescribed thereby to conform to the different length of the blocks, and traffic controlled means for governing the operation of said apparatus. 120
75
80

127. In an automatic train control system for railroads having different length blocks, speed governed brake control apparatus on a vehicle having a cycle of operation during which predetermined speed limits for the vehicle are established, and means partly on the vehicle and partly on the track for initiating and restoring said apparatus in accordance with traffic conditions and for adjusting its cycle of operation to cause it to terminate at the exit end of each block regardless of the length thereof. 125
90

128. In an automatic train control system for railroads having tracks divided into blocks of the same grade but different in length, the combination with a brake control appliance upon a vehicle, of means including a speed responsive device for governing said appliance, and means partly on the track and partly on the vehicle for influencing the operation of said vehicle carried means, said last mentioned means acting to establish a number of speed limits for the vehicle at 130
100 substantially the same respective distances from the exit end of each block regardless of the length of that block. 105

129. In an automatic train control system for railroads having blocks of different length, speed control apparatus for railway vehicles including a speed responsive device and adapted when active to establish a number of different speed limits for the vehicle, and automatic means for governing said apparatus to establish the same speed limit at substantially the same point with respect to the exit end of each block regardless of the length of that block. 110
115

130. A train control system for railroads having blocks of different length comprising, a brake setting appliance on a vehicle, a speed responsive device on the vehicle driven from the wheels thereof and adapted to actuate said appliance, and automatic means partly 120
125 on the vehicle and partly on the track responsive to traffic conditions ahead for automatically establishing a low speed limit above which said appliance will be actuated, said means acting differently in the different 130

length blocks to establish such low speed limit at substantially the same point in each block regardless of its length, said point being at least braking distance for that low speed from the end of the block.

5 131. A train control system for railroads having different length blocks, the combination with automatic speed control apparatus on a vehicle for governing the brakes and 10 including permissive speed means changeable from a maximum speed condition through successive intermediate speed conditions to a predetermined low speed condition, of means partly on the vehicle and 15 partly on the track responsive to traffic conditions in advance of the vehicle for regulating the change of the permissive speed means thereon, said last mentioned means acting to cause the permissive speed means on the vehicle to assume its low speed condition a 20 short distance from the exit end of the respective blocks regardless of their length.

132. In a train control system for railroads having blocks of different length, the combination with automatic brake control apparatus on a vehicle including a speed responsive device and operable to establish different limiting speeds above which the brakes are automatically applied, and automatic means 25 for governing said apparatus in the several blocks to cause successively lower speed limits to be established on the vehicle at a number of different points in each block, said speed limits at the respective points of the 30 several blocks corresponding approximately with the braking distance of the vehicle between that point and the exit end of the block regardless of the length of that block.

133. An automatic train control system for 40 railroads having portions of track on which vehicles have different braking curves, comprising train control apparatus on a vehicle for governing the brakes thereof, means for modifying the action of said apparatus as 45 the vehicle travels over said portions of track to conform to the different braking curves of said portions, and traffic controlled means for governing the operation of said apparatus.

50 134. An automatic train control system for railroads having portions of track with different braking characteristics for the vehicles traveling thereon, comprising speed control apparatus on a vehicle including a 55 speed responsive device and adapted to cause an automatic brake application when the vehicle exceeds predetermined limiting speeds, and automatic means for adjusting said apparatus to vary the limiting speeds 60 established over said different portions of track to conform with the braking characteristics of said portions.

135. An automatic train control system for 65 railroads having tracks divided into blocks in which the vehicles have different

braking curves, speed control apparatus on a vehicle adapted when active to cause an automatic brake application when the vehicle exceeds certain limiting speeds varying with the location of the vehicle in the 70 block, automatic means for adjusting said apparatus to vary said limiting speeds in the several blocks to conform with the respective braking curves therefor, and traffic controlled means for governing the operation of said apparatus.

136. In an automatic train control system for railroads divided into blocks differing in length, speed control apparatus on a vehicle adapted when active to change to an 80 ultimate condition in which it establishes a minimum speed limit, said apparatus continuing in its active condition until restored, and means partly on the vehicle and partly 85 on the track for rendering said apparatus active under dangerous traffic conditions and for restoring it under safe traffic conditions, said means automatically regulating said apparatus to cause it to assume its ultimate condition near the exit end of the block regardless of the length of that block.

137. In a train control system for railroads, in combination: speed control apparatus on a vehicle adapted when active to cause an automatic brake application unless the vehicle in its subsequent travel maintains speeds below a predetermined speed-distance curve, said apparatus being adapted to establish such automatic control in conformity with anyone of a number of speed-distance 95 curves of different shape, and means for automatically selecting the speed-distance curve to be effective at different points along the track.

138. In a system for automatically controlling railway vehicles, the combination with a railway vehicle consisting of a railway truck and a vehicle body spring mounted thereon so as to be movable relatively to said truck, a casing spring supported on said vehicle body, a vehicle speed responsive device contained in said casing, electro-responsive circuit controlling devices in said casing, train control means on said vehicle controlled by said speed-responsive device and 105 said circuit controlling devices, and a transmission operatively connecting an axle of said truck and said speed responsive device 110 constructed to transmit rotation of said axle to said speed responsive device in spite of relative movement of said truck with respect to said casing, whereby said speed-responsive device and said electro-responsive devices will 115 not be improperly operated by jars and vibration of said vehicle body.

139. In combination, a track, a car thereon, a safety appliance for excessive speed, apparatus to actuate said appliance, and selecting means operatively associated with said apparatus and controlled from the trackway 130

for modifying the operating influence of said apparatus on said appliance.

140. Train control apparatus for vehicles traveling on railroads having blocks of different length, comprising a plurality of block combinations each adapted to provide a control for the vehicle conforming to a particular length of blocks, and means for selecting the block combination to be effective to control the vehicle.

141. Train control apparatus for railway vehicles comprising, speed governed means for setting into operation the brakes of the vehicle, a multiplier combination for modifying the effective action of said means, and selecting means adapted to be actuated from the trackway for governing the multiplier combination.

142. Train control car equipment for governing the movement of vehicles through blocks of different length comprising, a plurality of block combinations each adapted to provide a control conforming to a particular length block, a multiplier combination adapted to modify the effective action of one or more of said block combinations, and automatic means for selectively placing the vehicle under the control of said combinations.

143. In a train control system, brake control apparatus on a vehicle, a source of direct current on a vehicle, a relay energized from said source and maintaining said apparatus inactive, means on the vehicle adapted to be influenced from the trackway and responsive only to alternating current for also maintaining said apparatus inactive, and traffic controlled trackway means acting at control points along the track to disconnect the relay from its source of direct current and also to influence said means simultaneously under clear traffic conditions.

144. A train control system comprising, speed governed brake control apparatus on a vehicle, stopping mechanism for arresting the movement of the vehicle regardless of its speed, means partly on the vehicle and partly on the track for governing said apparatus and said mechanism at different control points, and means automatically preventing operation of the mechanism while said apparatus is inactive.

145. In a train control system, speed governed apparatus on a vehicle operable to apply the brakes when the vehicle exceeds certain limiting speeds prescribed by the condition of said apparatus, emergency brake control mechanism operable to arrest the movement of the vehicle regardless of its speed, means whereby the operation of the emergency mechanism is prevented while the speed governed apparatus is not acting, and means partly on the vehicle and partly along the track for selectively influencing said apparatus and said mechanism at different control points along the track.

146. Speed control apparatus for governing the cars on railroads having different length blocks comprising a safety appliance for excessive speed on the car, apparatus to actuate said appliance, said apparatus comprising a plurality of block combinations corresponding to the different length blocks, a speed responsive device to actuate said block combinations, and a selector to select one of said block combinations.

147. Train control car equipment for governing the movement of a vehicle through different length blocks comprising, a brake control appliance, apparatus comprising a plurality of block combinations corresponding to the different length blocks and a speed responsive device acting on said block combinations, and automatic means for operatively connecting the brake control appliance selectively with said block combinations.

148. A train control system comprising, a car-carried brake control appliance, car-carried apparatus comprising a plurality of block combinations adapted to enforce the desired control for different portions of the track, a speed responsive device connected to the block combinations, traffic controlled means for initiating the operation of the several block combinations and for restoring them to normal, and automatic means partly on the vehicle and partly on the track for operatively connecting the brake control appliance selectively with said block combinations.

149. A train control system comprising, a brake control appliance on a vehicle, apparatus on a vehicle comprising a plurality of block combinations corresponding to the blocks of different characteristics through which a vehicle passes, automatic selecting means for determining the block combination to govern the brake control appliance, and means governed from the trackway in accordance with transient traffic conditions for initiating the operation of said block combinations and for restoring them to normal, said means when actuated preventing the effective action of said selective means.

150. Car apparatus for train control systems comprising a plurality of block combinations adapted to enforce speed restrictions of different characters, means including a speed responsive device and changeable permissive speed means adapted to be connected to the car wheels for acting on said block combinations, means adapted to be influenced from the trackway for establishing the operative connection from the car wheels to said permissive speed means, and automatic selecting means for determining which block combinations shall be effective to govern the car.

151. In combination, a track, a car thereon, a safety appliance for excessive speed on the car, apparatus to actuate said appliance comprising a plurality of block combinations

for governing the car over portions of the track having different permanent characteristics, a selector, a speed responsive device, a control relay and a gear train from the car wheel, said last four mentioned elements all acting on said block combinations, and a multiplier combination acting on said gear train and acted upon by said selector and said control relay.

152. In combination, a track, a car thereon, a safety appliance for excessive speed on the car, apparatus to actuate said appliance comprising a gear train driven from the car wheel, a multiplier combination acting on said gear train, and a selector acting on said multiplier combination.

153. In combination, a track, a car thereon, a safety appliance for excessive speed on the car, apparatus to actuate said appliance comprising a gear train driven from the car wheel, a multiplier combination acting on said gear train, a selector acting in a preparatory way on said multiplier combination, and a control relay to act further on said combination.

154. In combination, a track, a car thereon, a safety appliance for excessive speed on said car, apparatus to actuate said appliance, said apparatus comprising a plurality of combinations adapted to control the car over portions of the track having different braking characteristics, and a selector to act on said combinations.

155. Car apparatus comprising a plurality of devices each capable of enforcing predetermined speed restrictions for the car, a plurality of electro-magnetic means each adapted to render a particular one of said devices effective to control the car, automatic means for selectively governing the energization of said electro-magnetic means, maintaining circuits for said electro-magnetic means, and control means governed from the trackway in accordance with transient traffic conditions for governing said maintaining circuits simultaneously.

156. In combination, a track, a car thereon, a safety appliance for excessive speed on the car, and apparatus to actuate said appliance, said apparatus comprising a shoe, a selector, cables from said shoe and said selector, a junction box to which said cables lead, and cables from said junction box to other elements of said apparatus.

157. In combination, a railway track, a car thereon, a safety appliance for excessive speed on said car, and apparatus to actuate said appliance, said apparatus comprising a shoe, a selector, cables from said shoe and selector, and the following named elements of apparatus to which said cables lead, namely, a control relay, a stop relay, block combinations, a multiplier combination, and a signal panel.

158. In combination, a railway track, a

car thereon, a safety appliance for excessive speed on the car, and apparatus to actuate said appliance, said apparatus comprising a shoe and a selector, means associated with the track to actuate said shoe and selector, said apparatus also comprising a gear train and a speed responsive device driven from the car wheel, and said apparatus also comprising the following named elements acted upon by said shoe, selector, gear train, and speed responsive device, namely, a control relay, a stop relay, a signal panel, a multiplier combination, block combinations, and a cam starter.

159. In an automatic train control system for railroads having portions of track divided into blocks of different length over which the vehicles should travel at different maximum speeds under clear traffic conditions, permissive speed means on a vehicle adapted to establish different maintained maximum speed limits corresponding to the braking distance afforded by the blocks of different length, brake control means causing an automatic brake application when the vehicle exceeds the maximum speed limit prescribed by the permissive speed means, and means on the vehicle influenced from the trackway for determining the maximum speed limit established by the permissive speed means automatically as the vehicle enters the different length blocks.

160. In an automatic train control system for railroads having blocks of different length corresponding to braking distance for different speeds, automatic speed control apparatus on a vehicle including a speed responsive device adapted to establish different maximum speed limits for the vehicle for normally running under clear traffic conditions, said apparatus acting to cause an automatic brake application when the vehicle exceeds such speed limits, and means for adjusting said apparatus as the vehicle approaches the blocks of different length to select the maximum speed limit corresponding to the braking distance afforded by that particular block.

161. In combination, a railway track, a car thereon, a safety appliance for excessive speed on said car, and apparatus to actuate said appliance, said apparatus comprising a shoe, a selector, cables from said shoe and selector, and the following named elements of apparatus to which said cables lead, namely, a control relay and a plurality of combinations.

162. In an automatic train control system for railroads having portions of track over which the vehicles should run at different maximum speeds under clear traffic conditions, said portions of track being divided into blocks of different length, speed control apparatus on a vehicle adapted to establish different maximum speed limits for normal

running under clear traffic conditions and also adapted when active to establish a number of decreasing speed limits during the progress of a vehicle through a block when 5 dangerous traffic conditions ahead exist, traffic controlled means for governing the operation of said apparatus, and automatic means influencing said apparatus and acting to automatically select the effective maximum 10 speed limit as the vehicle travels over said different portions of track.

163. In combination, a railway track, a car thereon, a safety appliance for excessive speed on said car, and apparatus to actuate 15 said appliance, said apparatus comprising a shoe, a selector, cables from said shoe and selector, and the following named elements of apparatus to which said cables lead, namely, a control relay, a signal panel and a plurality 20 of block combinations.

164. In combination, a railway track, a car thereon, a safety appliance for excessive speed on the car, and apparatus to actuate said appliance, said apparatus comprising a shoe and 25 a selector, means associated with the track to actuate said shoe and selector, said apparatus also comprising a gear train and a speed responsive device driven from the car wheel, and said apparatus also comprising the following 30 named elements acted upon by said shoe, selector, gear train, and speed responsive device, namely, a control relay, and a plurality of combinations.

165. In combination, a railway track, a car 35 thereon, a safety appliance for excessive speed on the car, and apparatus to actuate said appliance, said apparatus comprising a shoe and a selector, means associated with the track to actuate said shoe and selector, 40 said apparatus also comprising a gear train and a speed responsive device driven from the car wheel, and said apparatus also comprising the following named elements acted upon by said shoe, selector, gear train, and speed responsive device, namely, a control relay, a signal panel and a plurality of combinations.

166. In combination, a railway track, a car 45 thereon, a safety appliance for excessive speed on the car, and apparatus to actuate said appliance, said apparatus comprising a shoe and a selector, means associated with the track to actuate said shoe and selector, said apparatus also comprising a gear train and a speed responsive device driven from the car wheel, and said apparatus also comprising the following named elements acted upon by said shoe, selector, gear train and speed responsive device, namely, a control relay, a plurality 55 of combinations and a cam starter.

167. In combination, a railway track, a car 60 thereon, a safety appliance for excessive speed on the car, a shoe, a selector, ramps to actuate said shoe and selector, a gear train and a speed responsive device both driven from the car wheel, and other apparatus on which said

shoe and selector and gear train and speed responsive device act, said other apparatus acting on said safety appliance.

168. In combination, a railway track, a car thereon, a safety appliance for excessive speed on the car, a shoe, a selector, ramps to actuate 70 said shoe and selector, a gear train and a speed responsive device both driven from the car wheel, and other apparatus on which said shoe and selector and gear train and speed responsive device act, said other apparatus acting on said safety appliance and comprising a control relay and block and multiplier combinations.

169. In combination, a track, a car thereon, 80 a safety appliance for excessive speed on the car, and apparatus to actuate said appliance, said apparatus comprising a control relay, a stop relay, a plurality of block combinations and a multiplier combination.

170. A train control system for railroads having blocks of different length, speed control apparatus on a vehicle for regulating the movement thereof and including permissive speed means adapted to be driven from the 90 axle, and automatic means for adjusting said apparatus to vary the distance of travel of the vehicle corresponding to the same movement of the permissive speed means.

171. Speed control apparatus for railway vehicles including a changeable permissive speed element for determining several limiting speeds for the vehicle, and automatic means for causing said element to change to a varying extent for the same distance of 100 travel of the vehicle.

172. Train control apparatus for railway vehicles including a movable permissive speed element, an operating connection for at times connecting said element to the car wheels, and means beyond the control of the operator of the vehicle for adjusting said operating connection.

173. Train control apparatus for vehicles comprising, a permissive speed cam, gearing 110 for driving the cam from the car axle, and means beyond the control of the operator of the vehicle for adjusting the gear ratio of said gearing and thereby produce the same movement of the cam by different numbers of 115 revolutions of the car axle.

174. Speed control apparatus for railway vehicles for governing the movement thereon on portions of track having different grades, comprising speed governed means changeable 120 from an initial maximum speed condition to an ultimate minimum speed condition, and automatic means partly on the vehicle and partly on the track for causing said change of the element to take place during different distances of travel of the vehicle and thereby conform to the different braking distances required for the different grades.

175. In a train control system, a normally 130 energized brake control device, means partly

on the vehicle and partly on the track for de-energizing said device under dangerous traffic conditions, a pair of contacts closed when the speed of the vehicle is below a predetermined speed, and an energizing circuit for said brake control device including in series 5 said pairs of contacts.

176. In a train control system, a brake control device, speed governed means for operating said device, and manually operable means effective only when the speed governed means is in condition corresponding to speeds less than a predetermined minimum for independently governing said device. 10

177. In combination, a track, a car thereon, a safety appliance for excessive speed on the car, apparatus to actuate said appliance, said apparatus comprising a gear train driven from the car wheel, and means to change the 20 gear ratio of said gear train.

178. In combination, a track, a car thereon, a safety appliance for excessive speed on the car, a gear train driven from the car wheel adapted to actuate said appliance subject to an interval of delay, means to change the gear ratio of said gear train and thereby change said interval, and means partly on the car and partly on the track for changing the gear ratio and for connecting said gear train 30 to actuate said appliance or for disconnecting it.

179. In combination, a track, a car thereon, a safety appliance for excessive speed on the car, a plurality of alternative gear trains 35 driven from the car wheel adapted to actuate said appliance subject to a corresponding interval of delay, means selectively to establish one of said trains, and means partly on the car and partly on the track for connecting such 40 selected gear train to actuate said appliance or for disconnecting it.

180. In combination, a track, a car thereon, a safety appliance for excessive speed on the car, apparatus driven from the car wheel to 45 actuate said appliance subject to an interval of delay, said apparatus being capable of adjustment to vary such interval, and means partly on the car and partly on the track to effect such adjustment and to establish or dis- 50 establish an operative connection between the car wheel and the said appliance through said apparatus.

181. In combination, a track, a car thereon, a safety appliance for excessive speed on the car, apparatus to actuate said appliance, said apparatus comprising a gear train driven 55 from the car wheel, means to change the gear ratio of said gear train, a cab indicator, and means to change said indicator to correspond with the change of said gear train. 60

182. In combination, a track, a car thereon, a safety appliance for excessive speed on the car, apparatus to actuate said appliance, said apparatus comprising a gear train driven 65 from the car wheel, means to change the gear

ratio of said gear train, a cab signal circuit, and means to control said circuit by said means.

183. In combination, a track, a car thereon, a safety appliance for excessive speed on the car, a gear train driven from the car wheel adapted to actuate said appliance subject to an interval of delay, means to change the gear ratio of said gear train and thereby change said interval, an electromagnet to actuate said means, and a signal circuit controlled by said electromagnet. 70 75

184. In combination, a track, a car thereon, a safety appliance for excessive speed on said car, a gear train driven from the car wheel, change gear mechanism to give alternative resultant gear ratios to the train, a member to actuate said appliance subject to an interval of delay, and means to connect the last gear of the train to drive said member. 80 85

185. In combination, a track, a car thereon, a safety appliance for excessive speed on said car, a gear train driven from the car wheel, change gear mechanism to give alternative resultant gear ratios to the train, a speed responsive device driven from said gear train at a point between the car wheel and the change gear mechanism, a movable member to actuate said appliance after a certain 90 range of idle movement, said speed responsive device being permanently connected to said member, and means to connect the last gear of said train cooperatively with the speed responsive device to drive said member. 95 100

186. In combination, a track, a car thereon, a safety appliance for excessive speed on the car, and apparatus to actuate said appliance, said apparatus comprising a double cam, two spring-held members acting oppositely on 105 said cam, and stops for said members placed so that when both members engage their respective stops, the cam will occupy an intermediate position.

187. In combination, a track, a car thereon, a safety appliance for excessive speed on the car, and apparatus to actuate said appliance, said apparatus comprising a double cam, a sector geared to said cam, two levers fulcrumed on the same axis with the cam, co-operating abutments on the sector and each lever, means to exert force on said levers, and stops for said levers placed so that when each lever engages its respective stop, the sector and the cam will be held thereby at an 110 intermediate position. 115

188. Car apparatus for automatic train control systems comprising, a brake control device, a normally energized stick relay governing said device and having a stick circuit, traffic controlled means for breaking said stick circuit, a pick-up circuit for the relay, manually operable means for closing said pick-up circuit at one point, and means for closing said pick-up circuit at another point 125 130

while the brake control device is operating.

189. Car apparatus for automatic train control systems comprising, a brake control device, a normally energized stick relay governing said device, and having a stick circuit, traffic controlled means for breaking the stick circuit, a manually operable circuit controller, a speed responsive device, contacts operated by the speed responsive device and closed at speeds below a predetermined low speed, other contacts automatically closed while the brake control device is operating, and a pick-up circuit for said relay including in series the manually operable circuit controller, the contacts of the speed responsive device, and the contacts operated by the brake control device.

190. Train control apparatus comprising a brake control device, control means for said device adapted when set into operation to continue until restored, manually operable means effective only when the brake control device is operating for restoring said control means.

191. Car apparatus for automatic train control systems comprising, a brake control device, a normally energized stick relay governing said device, a speed responsive device, contacts operated by the speed responsive device and closed at speeds below a predetermined speed, a manually operable switch, and a pick-up circuit for the stick relay including in series said switch and said contacts.

192. In a train control system, the combination with brake control apparatus on a vehicle, of traffic controlled means for governing said apparatus and manually operable means for restoring said apparatus, said manually operable means being effective only when the speed of the vehicle is below a predetermined speed, and said apparatus has operated.

193. Speed control apparatus for railway vehicles comprising, a brake control appliance, a normally closed energizing circuit for said appliance, a normally energized stick relay influenced from the trackway for breaking said circuit at one point, speed governed means also influenced from the trackway for breaking said circuit at another point dependent upon the speed of the vehicle, and manually operable means for restoring said stick relay.

194. In combination, a track, a car thereon, a safety appliance for excessive speed on the car, a plurality of block combinations adapted to be connected alternatively to actuate said appliance, a floating lever for each block combination, a speed responsive device connected to one point of each floating lever, a plurality of cams each engaging another point of a respective floating lever, and a gear train adapted to drive said cams and be driven from the car wheel.

195. In combination, a track, a car thereon, a safety appliance for excessive speed on the car, a plurality of floating levers adapted to be connected alternatively to actuate said appliance, a speed responsive device connected to one point of each floating lever, cams of different contour adapted to engage another point of each floating lever respectively, and a gear train adapted to actuate said cams and be driven from the car wheel.

196. Brake control apparatus for railway vehicles including a speed responsive device and cooperating changeable permissive speed means adapted to cause an automatic brake application when the vehicle exceeds any one of a plurality of different speed limits, control means on the car for governing the operation of said permissive speed means, means on the car adapted to connect the control means on other cars when coupled together in a train for simultaneous operation, and traffic controlled trackway means for supplying energy to last mentioned means and cause simultaneous operation of the control means from the several cars of the train.

197. In combination, a track, a car thereon, a safety appliance for excessive speed on the car, a plurality of members each having a certain range of movement and adapted at the end of such range to actuate said appliance, respective floating levers connected to said members, a speed responsive device connected to all said floating levers, respective cams of different contour also adapted to act on said floating levers, and a gear train driven from the car wheel adapted to actuate said cams.

198. Train control equipment for multi-car trains comprising speed control apparatus on each car including a speed responsive device, said apparatus being normally inactive and adapted when set into operation to cause an automatic brake application for the whole train when the speed as determined by the speed responsive device on that car exceeds a predetermined limit corresponding to the existing condition of said apparatus, and means including a bus line between the cars for coupling the apparatus on several cars for simultaneous operation.

199. In combination, a track, a car thereon, a safety appliance for excessive speed on the car, a circuit to actuate said appliance, a plurality of circuit controllers for said circuit, respective members each having a range of movement, means selectively to bring any one of said circuit controllers and its respective member into operative relation and a speed responsive device and a gear train driven from the car wheel both connected additively to actuate said members.

200. In combination, a track, a car thereon, a safety appliance for excessive speed on the car, a circuit to actuate said appliance, a plurality of circuit controllers for said circuit,

respective members adapted to actuate said controllers, an electromagnet associated with each controller and adapted to shift it in or out of operative relationship to its respective member, means to energize one of said electromagnets selectively, a speed responsive device acting on all of said members, a gear train driven from the car wheel, and cams of different contour driven by said gear train and 5 respectively acting on said members cooperatively with said speed responsive device.

201. In combination, a track, a car thereon, a safety appliance for excessive speed on the car, a plurality of block combinations 15 adapted alternatively to act on said appliance, a speed responsive device acting on all the block combinations, a gear train driven from the car wheel also acting cooperatively with the speed responsive device on all the block combinations, a selector adapted to bring one 20 of said block combinations into operative relationship with said safety appliance, and means associated with the track to actuate said selector.

202. In combination, a track, a car thereon, a speed responsive device on the car, an automatic brake setting appliance governed by said speed responsive device and adapted to continue in operation until restored, and 25 manually operable means for restoring said appliance actuatable only when the speed responsive device is in a condition corresponding to low speed, said manually operable means being ineffective to prevent initial operation of the brake controlled appliance.

203. In combination, a track, a car thereon, a speed responsive device, a pair of contacts adapted to be closed by the speed responsive device below a certain slow speed, an emergency brake, a circuit adapted when energized 40 to release said emergency brake, and a manually operated circuit closer thereto, said circuit comprising said pair of contacts.

204. In combination, a track, a car thereon, a speed responsive device on the car, an emergency brake, a releasing circuit for said brake, said circuit being controlled concurrently by three circuit controllers, namely, a manual 45 switch, another switch controlled by the speed responsive device and a third switch operatively associated with the emergency brake.

205. In combination, a track, a car thereon, a speed responsive device on the car, an emergency brake, a releasing circuit for said emergency brake, and a manual switch for said circuit, said circuit also comprising contacts controlled by said speed responsive device 55 to render the circuit inoperative above a certain speed.

206. In combination, a track, a car thereon, a safety appliance for excessive speed on the car, apparatus to actuate said appliance, 60 means to adjust said apparatus in accordance

with permanent track conditions, and cab signals to indicate such adjustment.

207. In combination, a track, a car thereon, a safety appliance for excessive speed on the car, a plurality of block combinations adapted alternatively to actuate said appliance, a selector to select one of said combinations and a cab signal to indicate which combination is selected. 70

208. In combination, a track, a car thereon, a safety appliance for excessive speed on the car, a plurality of alternative trains of mechanism to actuate said appliance, means selectively to render one of such train of mechanism operative, and a cab signal to give a 75 corresponding indication.

209. In combination, a track, a car thereon, a safety appliance for excessive speed on the car, apparatus to actuate said appliance, a selector to modify said apparatus, cab signals, 80 and circuits for said cab signals adapted to be correspondingly modified by said selector.

210. In combination, a track, a car thereon, a safety appliance for excessive speed on the car, apparatus to actuate said appliance, a selector to adjust said apparatus, a control relay to start said apparatus in operation and a signal circuit controlled at one point by said selector and at another point by said control relay. 90

211. In combination, a track, a car thereon, a safety appliance for excessive speed on the car, apparatus to actuate said appliance, a selector to adjust said apparatus, a control relay to start said apparatus in action, a signal circuit controlled both by said selector and said control relay, and a holding shunt for said circuit around said selector controlled by said control relay. 100

212. In combination, a track, a car thereon, a safety appliance for excessive speed on the car, apparatus to actuate said appliance, a plurality of electromagnets adapted to be energized alternatively to adjust said apparatus, circuits for said electromagnets, a selector adapted selectively to control said circuits and a control relay adapted to make or break the circuit selected by the selector. 105

213. In combination, a track, a car thereon, a safety appliance for excessive speed on the car, a plurality of sets of apparatus any one of them being adapted to actuate said appliance, respective circuits to make such sets of apparatus operative, a selector to select such a circuit, and a control relay to control such selected circuit jointly with said selector. 115

214. In combination, a track, a car thereon, a safety appliance for excessive speed on the car, apparatus to actuate said appliance, electromagnets adapted to adjust said apparatus, a selector to control the circuits of said electromagnets, cab signals to indicate the nature of the adjustment, and circuits for said signals, said signal circuits being controlled by said selector and by said electromagnets. 125

215. In combination, a track, a car thereon, a safety appliance for excessive speed on the car, apparatus to actuate said appliance, electromagnets adapted to adjust said apparatus, circuits therefor, a selector to control said 5 circuits, and holding shunts for said electromagnets around the selector with contacts controlled by said electromagnets respectively. 70
216. In combination, a track, a car thereon, a safety appliance for excessive speed on the car, apparatus to actuate said appliance, electromagnets adapted to adjust said apparatus, circuits therefor, a selector selectively to control said circuits, a control relay having front and back contacts, with the front contacts in said circuits, and holding shunts around said selector with the back contacts in said shunts. 75
217. In combination, a track, a car thereon, a safety appliance for excessive speed on the car, apparatus to actuate said appliance, a selector to adjust said apparatus, and indicators to show the selector adjustment. 80
218. In combination, a track, a car thereon, a safety appliance for excessive speed on the car, apparatus to actuate said appliance, a selector to adjust said apparatus, indicators to show the selector adjustment, and actuating circuits for said indicators through the 85 selector. 90
219. In combination, a track, a car thereon, a safety appliance for excessive speed on the car, apparatus to actuate said appliance, a selector to adjust said apparatus, indicators to show the selector adjustment, actuating 95 circuits for said indicators through the selector, a control relay with front and back contacts and with its front contacts in said circuits, and holding shunts for said circuits around the selector and with said back contacts comprised therein. 100
220. In combination, a track, a car thereon, a safety appliance for excessive speed on said car, apparatus to actuate said appliance, a plurality of electromagnets adapted selectively to adjust said apparatus, corresponding 105 circuits for said electromagnets, a selector adapted selectively to prepare one such circuit, and a control relay adapted to open or close the selectively prepared circuit. 110
221. In combination, a track, a car thereon, a safety appliance for excessive speed on said car, apparatus to actuate said appliance, a plurality of electromagnets adapted selectively to adjust said apparatus, corresponding circuits for said electromagnets, a selector adapted selectively to prepare one such circuit, a control relay adapted to open or close the selectively prepared circuit, and branch 115 circuits through the respective electromagnets around the selector, each governed in part by its corresponding electromagnet, and each branch circuit governed further by said control relay. 120
222. In combination, a track, a car thereon, a safety appliance for excessive speed, sig- 125

nals, multiple circuits through said appliance and said signals, all said circuits have a common portion, an indicator for inoperativeness of said appliance, and signals and a selector to open said common part of said multiple circuits and simultaneously to actuate said indicator.

228. In combination, a track, a car thereon, a safety appliance for excessive speed on said car, a plurality of signals on said car, multiple branch circuits through said appliance and said signals and a common manual switch for said multiple branch circuits.

229. In combination, a track, a car thereon, a safety appliance for excessive speed on the car at each end thereof, a set of signals at each end of the car, respective multiple branch circuits for said appliances and for each signal, and a common manual switch for each set of signals and for the associated appliance.

230. In combination, a track, a car thereon, a safety appliance for excessive speed on the car, a circuit to actuate said appliance, a manual switch controlling said circuit, and automatic means responsive to excessive speed also controlling said circuit.

231. In combination, a railway vehicle consisting of a railway truck and a vehicle body, electro-responsive train control mechanism mounted on said vehicle body, influence receiving means supported by said truck, a conduit leading from same mechanism and a readily detachable coupling for electrically connecting a plurality of wires contained in said conduit to said receiving means.

232. In combination, a railway vehicle consisting of a railway truck and a vehicle body, electro-responsive train control means mounted on said vehicle body, influence receiving means supported by said truck, a flexible conduit containing a plurality of wires leading to said train control mechanism, and a readily detachable plug coupler for detachably electrically connecting said wires to said influence receiving means.

233. In combination, a railway vehicle, a casing, electrical train control means in said casing, a socket for a plug coupler associated with said casing and having its open end disposed downwardly, and a flexible conduit containing a plurality of wires leading from apparatus mounted movably with respect to said casing and having a plug coupler at the free end thereof connected to said wires and for insertion into said socket to establish electrical circuits.

234. In combination, a railway vehicle, a casing on said vehicle, electrical train control means in said casing, a socket for a plug coupler associated with said casing and having its open end disposed downwardly, another casing, train control mechanism in said another casing, and a flexible conduit having wires therein leading from said another casing and

having a plug coupler complementary to said socket at the end thereof, said coupler being adapted to be inserted into said socket.

235. In combination, a track, a train of cars thereon, a warning signal for excessive speed on one of said cars, a circuit for said signal, a train bus connected to said circuit and means responsive to excessive speed on each car adapted to close said circuit through said bus.

236. In combination, a track, a train of cars thereon, a warning signal for excessive speed on one of said cars, a circuit for said signal, a bus from car to car connected to said circuit, a branch from said bus on each car, a respective circuit closer for the branch on each car, and means on each car conjointly responsive to car speed and distance of travel to actuate said circuit closer.

237. In combination, a track, a train of cars thereon, a service brake valve on one of said cars, a circuit to actuate said valve, a bus connected to said circuit and extending from car to car, branches on each car from said bus and means on each car responsive conjointly to excessive speed and distance of travel to control said circuit through the respective branch.

238. Car equipment for train control systems comprising speed governed means for causing an automatic service brake application, other means for causing an automatic emergency brake application, a device for controlling the supply of propelling power for the vehicle, and means for operating said device by either of said first mentioned means.

239. A train control system for multi-car trains comprising speed governed service brake control means and emergency brake control means on each car, a bus line connecting the service brake control means on the several cars for simultaneous operation, a power control bus line between the cars, and means for governing the energization of the power control bus line by the operation of either the service or the emergency brake control means.

240. In combination, a track, a car thereon, a power cut-off device on the car, an automatic service brake appliance, an automatic emergency brake appliance, a circuit for said power cut-off, and means to control said circuit by the operation of either of said brakes.

241. In combination, a track, a train of cars thereon, a power control bus extending from car to car of the train, a power controlling device electrically connected to said bus on each car, an automatic brake on each car, and a branch conductor from said bus on each car with a switch therein controlled by the operation of said brake valve.

242. In combination, a track, a train of cars thereon, a power cut-off device on each car, a bus running from car to car with branches therefrom through each power cut-off, an

automatic brake appliance on each car responsive to excessive speed and branch conductors controlled by the operation of said automatic brakes respectively connected to 5 said bus.

243. In combination, a track, a car thereon, an emergency brake device on said car, a circuit to control said device, three multiple branches for said circuit, a control relay governing one such branch, a selector governing another branch and a stop relay governing the third branch. 10

244. Train control apparatus comprising a brake setting device, speed governed means adapted when set into operation to actuate 15 said device when the vehicle exceeds the limiting speed prescribed thereby, and a relay influenced from the trackway for governing said means and also the brake setting device 20 directly.

245. In combination, a track, a car thereon, an emergency brake device on said car, a normally energized circuit restraining said device, a stop relay, a circuit controller in said 25 circuit governed by said stop relay, another circuit controller in said circuit, and a speed responsive device governing said last mentioned circuit controller.

246. A train control system comprising, a 30 brake setting device on a vehicle, a normally closed circuit energizing said device, speed governed means automatically controlled in accordance with traffic conditions for opening said circuit at one point at excessive 35 speeds, and other means partly on the vehicle and partly on the track for independently opening said circuit at another point regardless of the speed of the vehicle.

247. In combination, a track, a car thereon, 40 automatic safety apparatus on the car, a normally open circuit adapted when closed at one point to render part of said apparatus effective, a normally closed circuit adapted when opened at one point to render another part of said apparatus effective, and a switch 45 adapted to open the first mentioned circuit at another point and close the second mentioned circuit at another point under certain conditions.

248. In combination, a track, a car thereon, 50 automatic safety apparatus on the car, a normally open circuit adapted when closed at one point to render part of said apparatus effective, a normally closed circuit adapted 55 when opened at one point to render another part of said apparatus effective, a switch adapted to open the first mentioned circuit at another point and close the second mentioned circuit at another point under certain 60 conditions, and means located at a certain point of the track to actuate said switch.

249. In combination, a track, a car thereon, 65 automatic safety apparatus on the car, a normally open circuit adapted when closed at one point to render part of said apparatus

effective, a normally closed circuit adapted when opened at one point to render another part of said apparatus effective, a switch adapted to open the first mentioned circuit at another point and close the second mentioned circuit at another point under certain 70 conditions, means located at a certain point of the track to actuate said switch, and a no signal indicator also governed by said switch.

250. In combination, a track divided into 75 blocks, a car thereon, a ramp at the entrance to each block, a shoe adapted to engage said ramp, a control relay governed by said shoe and a signal circuit governed by said shoe and by said control relay.

251. In combination, a track divided into 80 blocks, a car thereon, a ramp, a shoe adapted to engage said ramp and be lifted thereby, a control relay actuated by electrical contact with the ramp, a circuit controller actuated by the lifting of the shoe and a signal circuit controlled by both said circuit controller and said control relay. 85

252. In combination, a track, a car thereon, a ramp, a shoe adapted to engage said ramp 90 and be affected thereby in two different ways, a control relay controlled by said shoe in one way, a circuit controller actuated by said shoe in the other way, and a signal circuit governed by both said control relay and said 95 circuit controller.

253. Car apparatus for automatic train control systems comprising, a brake control device, a normally energized stick relay governing said device, traffic controlled means 100 partly on the vehicle and partly on the track for deenergizing the relay under dangerous traffic conditions, and manually controlled means for restoring said relay, said manually controlled means being effective only after the brake control device has operated. 105

254. In combination, a track, a car thereon, a stop relay on the car, a circuit for said relay, a shoe controlling said circuit, a branch circuit through said relay, a manual switch 110 controlling said branch circuit, a speed responsive device on the car, and cooperating contacts governed by said speed responsive device also adapted to control said branch circuit. 115

255. In combination, a track, a car thereon, a safety appliance for excessive speed on said car, apparatus to actuate said appliance, a manually controlled cut-out adapted to render said apparatus inoperative, a circuit 120 adapted to release said cut-out and restore the apparatus to operative condition, and a manual circuit controller for said circuit.

256. In combination, a track, a train of cars 125 thereon, a safety appliance for excessive speed on each car, apparatus on each car to actuate said appliance, a manually operated cut-out on each car to render said apparatus on such car inoperative, a circuit on each car adapted to restore said apparatus to its operative condition. 130

dition, a bus extending from car to car and connecting said circuits in multiple and a manually operated re-set switch connected to the bus on each car.

- 5 257. In combination, a track, a train of cars thereon, each car having a stop relay and a respective control circuit therefor, each car also having a speed responsive device with contacts governing said circuit respectively, 10 a bus running from car to car and connecting said circuits in multiple, and manually operated switches on the cars, any one of them adapted to close said circuits in multiple through said bus.
- 15 258. A train control system for multi-car trains comprising stop relays on the several cars, means on each car for controlling its stop relay, a bus line through the train, a normally open energizing circuit on each car 20 for the stop relay thereon, said circuit being connected to the bus line, a manually operable switch for energizing said bus line, and means on each car for closing the normally open energizing circuit thereon when its stop 25 relay operates.

259. In combination, a track, a car thereon, a safety appliance for excessive speed, an emergency brake appliance, a speed responsive device acting on both appliances and two 30 different distance responsive devices acting on the respective appliances, the action of said devices on each appliance being additive.

260. In combination, a track, a car thereon, two different safety appliances for excessive 35 speed, a speed responsive device acting on both appliances, and two different distance responsive devices acting on the respective appliances, the action of said devices on each appliance being additive.

40 261. A safety apparatus for the control of the speed of a vehicle moving along a trackway, comprising a device on the vehicle moved from the running gear thereof in accordance with the actual speed, a second device also on the vehicle moved intermittently from the running gear of the vehicle in accordance with a permissible speed, means for automatically retarding the vehicle whenever 45 the actual speed equals or exceeds the permissible speed, in combination with a power transmitting mechanism for moving the permissible speed device from the actual speed device, and means for automatically controlling the movement of such mechanism, whereby the permissible speed device when 50 actuated is moved at a rate of speed corresponding to a safe braking distance for such 55 vehicle at the place along the trackway at which such actuation takes place.

262. In apparatus of the character set forth, the combination with a vehicle, of a movable permissive speed device, and means 60 for moving the permissive speed device at

different rates of speed with respect to the speed of the vehicle.

263. In apparatus of the character set forth, the combination with a vehicle, of a movable permissive speed device thereon, and 70 means driven by a moving part of the vehicle for moving the permissive speed device at different rates of speed with respect to the speed of the vehicle.

264. In apparatus of the character set 75 forth, the combination with a vehicle, of a movable permissive speed device, different combinations of driving gearing for moving the permissive speed device, and means for selecting said combinations to operate the so 80 permissive speed device in accordance with hazards of different characters.

265. In apparatus of the character set forth, the combination with a vehicle, of a movable permissive speed device, means for 85 moving the permissive speed device at different rates of speed with respect to the speed of the vehicle, and track-side mechanism for determining the rate of speed of the permissive speed device with respect to the movement of the vehicle according to the different 90 hazards along the line of travel of the vehicle.

266. In apparatus of the character set 95 forth, the combination with a vehicle, of a permissive speed device movably mounted thereon, a driving member operating with the vehicle, a driven member connected to the permissive speed device, a plurality of sets 100 of transmitting gearing of different ratios between the driving and driven members, and means for selectively causing any of the sets of gearing to transmit movement from the driving member to the driven member.

267. In apparatus of the character set 105 forth, the combination with a vehicle, of a movable permissive speed device, means for moving the permissive speed device at different rates of speed with respect to the speed of the vehicle, and means for indicating the rate of speed at which the permissive speed device is operated.

268. In apparatus of the character set 115 forth, the combination with a vehicle, of a permissive speed device movably mounted thereon, a driving member operating with the vehicle, a driven member connected to the permissive speed device, a plurality of sets of transmitting gearing of different ratios between the driving and driven members, 120 means including trackside mechanism for automatically and selectively causing any of the sets of gearing to transmit movement from the driving member to the driven member according to the different hazards along 125 the line of travel of the vehicle, and means controlled by said selecting means for indicating the speed selected thereby.

269. In an automatic train control system 130 for railroads having signalled territory

equipped for the automatic control of vehicles thereon and un signalled territory not so equipped, the combination with automatic brake control apparatus on a vehicle, of 5 means for governing the apparatus in signalled territory in accordance with traffic conditions, and means for automatically rendering the apparatus ineffective to control the vehicle while it is travelling in un signalled territory.

270. A railway traffic controlling system comprising brake control apparatus on a vehicle, traffic controlled means on the track-way for governing said apparatus, the rail-way over which the vehicle runs having a portion of the track equipped with such traffic controlled means and a portion of track not so equipped, means partly on the vehicle and partly on the track at the entrance to the unequipped portion of track for rendering said apparatus ineffective to retard the vehicle while it is travelling through said un equipped portion.

271. A railway traffic controlling system comprising brake control apparatus on a vehicle, traffic controlled means on the track-way for governing said apparatus, the rail-way over which the vehicle runs having a portion of the track equipped with such traffic controlled means and a portion of track not so equipped, means adjacent to the entrance end of the unequipped portion of the track for rendering said apparatus ineffective to retard the vehicle while it is travelling through said unequipped portion, and means adjacent to the exit end of said unequipped portion of the track for automatically restoring said apparatus to condition to govern the vehicle.

272. In an automatic train control system for railroads having signalled territory equipped for the automatic control of vehicles thereon and un signalled territory not so equipped, the combination with a normally energized electromagnetic device on a vehicle adapted when deenergized to cause an automatic brake application, of means for controlling said device in signalled territory in accordance with traffic conditions, a normally open vehicle-carried circuit for said device, and means partly on the vehicle and partly on the track for closing said circuit when the vehicle enters un signalled territory and for maintaining it closed while the vehicle travels through said un signalled territory.

273. In an automatic train control system for railroads having signalled territory equipped for the automatic control of vehicles thereon and un signalled territory not so equipped, the combination with a normally energized brake control device on the vehicle adapted when deenergized to cause an automatic brake application, of a normally open circuit adapted when closed to

70 maintain said device energized, and means for closing said circuit when the vehicle passes from signalled territory to un signalled territory and for opening said circuit when the vehicle passes from un signalled to signalled territory.

274. In an automatic train control system for railroads having signalled territory equipped for the automatic control of trains thereon and un signalled territory not so equipped, the combination with automatic train control apparatus on a vehicle for governing the brakes thereof, means for automatically rendering said apparatus ineffective to control the vehicle when it enters un signalled territory and for holding it ineffective until restored, and means adjacent to the exit end of un signalled territory for restoring said means to normal.

275. In an automatic train control system for railroads having signalled territory equipped for the automatic control of trains thereon and un signalled territory not so equipped, the combination with a normally energized brake control device, of speed control apparatus on a vehicle including a speed responsive device driven from the wheels thereof for governing the brake control device, a normally open circuit for maintaining the brake control device energized independently of its control by said apparatus, and means for automatically maintaining said normally open circuit closed while the vehicle is travelling in un signalled territory.

276. In an automatic train control system for railroads having signalled territory equipped for the automatic control of trains thereon and un signalled territory not so equipped, a normally energized brake control magnet on a vehicle adapted when deenergized to cause an automatic brake application, a control relay on the vehicle for maintaining said magnet energized, speed control apparatus controlled by said relay and also governing said magnet, traffic controlled means for controlling said control relay, and automatic means for maintaining said magnet energized independently of its control by the control relay and said apparatus while the vehicle is travelling in un signalled territory.

277. In an automatic train control system for railroads having a portion of track equipped for the automatic control of vehicles thereon, and another portion of track unequipped, cab signal means on a vehicle, traffic controlled means for governing the cab signal means in the equipped portion of track, and automatic means for extinguishing the indications of said cab signal means when the vehicle enters the unequipped portion of track.

278. In an automatic train control system for railroads having signalled and un signalled territory, traffic controlled signal

means on the vehicle, and automatic means partly on the vehicle and partly on the track for rendering said signal means inactive while the vehicle is travelling in unsignalled territory.

279. In an automatic train control system for railroads having signalled territory equipped for the automatic control of trains thereon and unsignalled territory not so equipped, speed control apparatus on a vehicle including a speed responsive device and adapted to cause an automatic brake application when the vehicles exceed predetermined limiting speeds, a warning signal automatically operated prior to the brake application, and automatic means for rendering said apparatus ineffective to apply the brakes and for preventing operation of the warning signal while the vehicle is travelling in unsignalled territory.

280. In an automatic train control system for railroads having signalled territory equipped for the automatic control of trains thereon and unsignalled territory not so equipped, automatic speed control apparatus on a vehicle including a speed responsive device for causing an automatic brake application when the vehicle exceeds predetermined limiting speeds, a warning signal automatically operated by said apparatus prior to the automatic brake application, a distinctive signal on the vehicle for indicating that it is travelling in unsignalled territory, and automatic means partly on the vehicle and partly on the track for rendering the speed control apparatus ineffective to apply the brakes and for giving said distinctive signal, said last mentioned means also rendering the warning signal inactive.

281. In an automatic train control system for railroads having signalled and unsignalled territory, traffic controlled cab signal means on a vehicle, an electrically operable distinctive signal on the vehicle, and automatic means for extinguishing the indications of the cab signal means and for operating said distinctive signal when the vehicle enters unsignalled territory.

282. In an automatic train control system for railroads having signalled and unsignalled territory, a normally inactive distinctive signal on a vehicle for indicating that it is travelling in unsignalled territory, and automatic means for rendering said signal active while the vehicle is travelling in unsignalled territory.

283. In an automatic train control system for railroads having signalled territory equipped for the automatic control of trains thereon and unsignalled territory not so equipped, train control apparatus and cab signal means on a vehicle, and automatic means partly on the vehicle and partly on the track for rendering said apparatus ineffective and for extinguishing the indications of the

cab signal means while the vehicle is travelling in unsignalled territory.

284. In an automatic train control system for railroads having signalled territory equipped for the automatic control of trains thereon and unsignalled territory not so equipped, train control apparatus and cab signal means on a vehicle, a normally inactive distinctive signal for indicating that the vehicle is travelling in unsignalled territory, and automatic means for rendering said apparatus ineffective, for extinguishing the indications of the cab signal means, and for giving said distinctive signal while the vehicle is travelling in unsignalled territory.

285. In an automatic train control system for railroads having signalled territory equipped for the automatic control of trains thereon and unsignalled territory not so equipped, the combination with automatic brake control apparatus on a vehicle, of a distinctive signal on the vehicle, and automatic means for rendering said apparatus ineffective and for operating said distinctive signal while the vehicle is travelling in unsignalled territory.

286. In an automatic train control system for railroads having signalled territory equipped for the automatic control of trains thereon and unsignalled territory not so equipped, the combination with a normally energized brake control device, a normally open car-carried circuit adapted when closed to prevent operation of the brake control device, a distinctive signal for indicating that the vehicle is travelling in unsignalled territory, and automatic means for closing said circuit and for operating the distinctive signal when the vehicle enters unsignalled territory and for opening said circuit and extinguishing the indication of the distinctive signal when the vehicle passes from unsignalled back into signalled territory.

287. In an automatic train control system for railroads having signalled territory equipped for the automatic control of trains thereon and unsignalled territory not so equipped, a distinctive signal on the vehicle, a circuit for controlling said signal, and trackway means adjacent to the ends of unsignalled territory for controlling said circuit to establish the distinctive signal while the vehicle is travelling in unsignalled territory.

288. In an automatic train control system for railroads having signalled and unsignalled territories, the combination of car-carried speed control apparatus, wayside traffic controlled means governing said apparatus in signalled territory, and means acting independently of the wayside means for preventing operation of said apparatus, said preventing means operating automatically upon the exit of the car from signalled terri-

tory and automatically becoming inactive upon the entrance of the car into signalled territory.

289. In an automatic train control system for railroads having signalled and unsignalled territory, a normally inactive distinctive signal on a vehicle for indicating that it is travelling in unsignalled territory, a normally open circuit for controlling said signal, and means partly on the vehicle and partly on the track for closing said circuit as the vehicle passes from signalled to unsignalled territory and for maintaining it closed while the vehicle is travelling through unsignalled territory.

290. In a system of control for vehicles movable upon a trackway, in combination: a vehicle, a trackway; means on the vehicle conditioned by means on the trackway for initially establishing a maintained maximum permissible speed or a maintained submaximum permissible speed for the vehicle; means for at times connecting said first mentioned means to the running gear of the vehicle to be operated thereby so as to establish a maximum permissible speed gradually reducing from either of the initially established permissible speeds according to which is initially established and means for utilizing said first mentioned means for controlling the vehicle.

291. In a system of control for vehicles movable upon a trackway, in combination: a vehicle; a trackway, means on the vehicle conditioned by means on the trackway for initially establishing over different portions of the trackway different maintained maximum permissible speeds for the vehicle; means for at times connecting said first mentioned means to the running gear of the vehicle to be operated thereby so as to establish a maximum permissible speed gradually reducing from any initially established maintained maximum permissible speed according to which is initially established and means for utilizing said first mentioned means for controlling the vehicle.

292. In a system of control for moving vehicles, in combination: a vehicle, a roadway; means on the vehicle driven by the running gear thereof which moves in accordance with the actual speed thereof; means on the vehicle for initially establishing different predetermined persisting permissible speeds; means for at times connecting said second mentioned means to the running gear of the vehicle to be operated thereby so as to establish a maximum permissible speed gradually reducing from any predetermined persisting permissible speed according to which is initially established; means on the roadway for actuating said second and third named means; a brake and means for actuating said brake by the co-operation of the first and second mentioned means.

293. In a system of control for vehicles

movable upon a trackway, in combination: a vehicle, a trackway for the vehicle; means on the vehicle adapted to be conditioned for initially establishing a maintained maximum permissible speed and a maintained submaximum permissible speed for the vehicle; electro-magnetic means on the vehicle for conditioning the first mentioned means; means on the trackway for governing the second mentioned means; means for at times connecting said first mentioned means to the running gear of the vehicle to be operated thereby so as to establish a maximum permissible speed gradually reducing from either of the initially established permissible speeds according to which is initially established and means for utilizing said first mentioned means for controlling the vehicle.

294. In a system for automatically controlling railway vehicles, the combination with a railway vehicle consisting of a railway truck and a vehicle body mounted thereon so as to be movable relatively to said truck, a casing spring supported on said vehicle body, a speed responsive device contained in said casing, a telescopic transmission including a universal joint operatively connecting the axle of said truck and said speed responsive device, and a telescopic casing for housing said transmission.

295. In combination, a railway vehicle, vehicle controlling means thereon, means on the vehicle for controlling said vehicle controlling means comprising a speed-controlled means and a speed limit device capable of being set for any one of a plurality of speeds, means spaced along the trackway for setting said speed limit device for a determined speed, and other means along the trackway for operating said speed limit device.
